UNITED STATES PATENT OFFICE

2,341,879

TELEPHONE SYSTEM

Seth E. Peterson, Bogota, Colombia, and Vincent A. Johnson, Evanston, Ill., assignors to Automatic Electric Laboratories, Inc., Chicago, Ill., a corporation of Delaware

Application April 16, 1942, Serial No. 439,218

78 Claims. (Cl. 179—27)

The present invention relates to telephone systems and, more particularly, to improvements in apparatus for converting a system of the semi-automatic type, wherein operator controlled register markers are utilized in the directive control of automatic switches to extend a connection to a called line, to a system of the fully automatic type, wherein all switch directing operations are performed by the calling subscribers without operator intervention.

In effecting a system conversion of the character indicated, it is economically desirable to utilize, so far as possible, the installed switchgear of the semi-automatic system with but a minimum of changes in the arrangement thereof. In practice, this means that the existing switchgear of the system must be so modified that the register senders of the system may be directly controlled from the calling substations rather than from an operator position, and that the register senders themselves must be completely reorganized to accept dial pulses received from the calling substations and automatically to render services previously handled by an operator. It may also be desirable in effecting a system conversion of this character to add new directly controllable automatic switching equipment or to replace existing equipment of this form with new equipment. The new or added equipment may or may not be arranged for the same type of directive control by the register senders as the existing equipment. For example, the existing switching equipment may be arranged for revertive control of the register senders during a call forwarding operation, while the new or added equipment may be arranged to receive switch directing pulses directly from a register sender during a call forwarding operation without exercising any control whatever over the impulse sending equipment of the register sender in use. This means that the register senders provided in the converted system must be equipped to furnish two or more types of directive control of the automatic switching equipment and that the register sender used in forwarding any given call must be equipped to switch from one type of directive control to the other after the call has progressed to a given switching stage. Moreover, the new automatic switches may be added at different switching stages of the system so that in forwarding different calls the change from one type of directive control to the other must be effected in the register senders after different numbers of the digits registered

therein have been utilized in the directive control of the switching equipment.

It is an object of the present invention, therefore, to provide improved facilities for converting a telephone system of the semi-automatic type into a system of the fully automatic type with but a minimum number of changes in the existing equipment and with the addition of a minimum amount of new equipment.

10 According to another object of the invention, an improved arrangement is provided whereby the directory number designations produced under the control of a calling device located at a calling substation may be transmitted to the register sender occupied with a call at a point preceding the first directly controlled switching stage of the system.

According to a further object of the invention, an improved arrangement is provided for locking out of service the links having access to the calling lines of the system when the register senders to which these links have access are all busy.

It is a further object of the invention to provide for use in a system of the character described, improved register senders which are so arranged that the installed automatic switching equipment of the system may be retained with but slight modification thereof and new equipment of the same or a different type may be added to the system as required.

According to another object of the invention, each register sender is arranged to exercise either of two types of directive control over the associated automatic switches, and the character of the directive control exercised thereby in forwarding a call to its destination is automatically adapted to the type or types of directive control required by the automatic switches through which the call must be routed.

40 In accordance with another object of the invention, each register sender is equipped with facilities controlled in accordance with the numerical value of one of the digits transmitted to the register sender during a directory number dialing operation for automatically setting the type pattern for the directive control of the automatic switches through which the call must be extended.

It is another object of the invention to provide 50 register senders which are each equipped with improved facilities for transmitting to a calling substation those signals which are commonly utilized to enable the calling subscriber to follow the progress of a call.

55 According to another object of the invention,

provisions are made in each register sender for automatically transmitting to a subscriber initiating a reverting call a signal which indicates that the calling subscriber is to hang up his receiver for the purpose of initiating the ringing operation.

In accordance with another object of the invention, each register sender is equipped with facilities for automatically transmitting to the party answering a reverting call a signal which indicates that the answered call is of the reverting type.

According to still another object of the invention, each register sender is equipped automatically to transmit a ring-back tone signal to a calling substation immediately after the dialing operation is completed at the calling substation and before the sender has completed its operation to direct the call through the associated switching apparatus to the called line.

According to still another object of the invention, each register sender is provided with facilities for automatically withholding from the associated switching equipment the last digit of a received reverting call directory number until the calling party hangs up his receiver.

In accordance with a further object of the invention, the facilities provided in each register sender for withholding the last digit of a received reverting call directory number and for transmitting the required signals over the line occupied with the reverting call, are conditioned for operation by transmitting to the register sender a predetermined prefix digit which identifies the character of the call.

It is a still further object of the invention to provide for use in a converted system of the character described, an improved register sender which is equipped with facilities controlled in accordance with the numerical value of one of the digits of a received plural digit directory number for indicating the number of digits of the directory number.

According to another object of the invention, provisions are made in the register sender for automatically releasing the sender after the indicated number of digits have been transmitted therefrom to the associated automatic switching apparatus.

In accordance with still another object of the invention, the register sender is equipped with facilities for rendering the digit registers of the sender non-responsive to received impulses after the indicated number of digits have been received.

The invention, both as to its organization and method of operation, together with further objects and advantages thereof, will best be understood by reference to the specification taken in connection with the accompanying drawings in which Figs. 1 to 17, inclusive, when laid side by side in numerical order, illustrate a telephone system characterized by the features of the invention briefly referred to above.

Referring now more particularly to the drawings, the telephone system there illustrated comprises a central exchange which terminates a number of subscriber lines and may be trunk-connected to a number of smaller exchanges, certain of which may be of the fully automatic type. The central exchange is illustrated as terminating two subscriber lines 10 and 11, the first of which is of the multiparty type serving the substations A and E and the last of which is of the single party type serving only the substa-

tion B. Each of the subscriber lines extending to the central exchange is terminated in a line circuit of conventional character, those associated with the lines 10 and 11 being schematically illustrated at 10a and 11a, respectively. The central exchange is also provided with a toll switchboard 30 at which outgoing and incoming toll calls are handled. For the purpose of setting up local connections between the subscriber lines 10 and 11 terminated at the central exchange, and of handling certain interexchange calls in the manner more fully pointed out below, the central exchange is equipped with automatic switching equipment which, in the main, may comprise automatic switches previously in use when the exchange was operated on an auto-manual basis. In brief, this equipment comprises a plurality of groups of finder-selector-links, one of which includes the link 15, shown in Figs. 2, 3 and 4 of the drawings; a plurality of groups of second selectors, two of which respectively include the selectors 16 and 20; and a plurality of groups of connectors, one of which includes the connector 17. Each group of finder-selector-links is arranged to serve a particular group of one hundred subscriber lines and has associated therewith a link distributor and common equipment. Thus the lines 10 and 11 are illustrated as being served by the link group which includes the link 15. This group of links has associated therewith a link distributor and common equipment of conventional form, schematically indicated at 14. For the purpose of directly controlling the indicated automatic switches of the central exchange, a plurality of groups of register senders are provided therein, the various groups being individual to the different groups of finder-selector-links. Thus the illustrated register sender 19 of Figs. 6 to 17, inclusive, is shown as being included in the sender group associated with the group of links in which the link 15 is included. In order operatively to associate an idle one of the register senders with a link to which a call is extended, each of the links has associated therewith a register selector that has access only to the register senders of the associated sender group. Thus the link 15 is shown as having associated therewith a register selector 18 which has access to the register senders in the group including the register sender 19.

The directly controllable selectors of the finder-selector-links, the second selectors and the connectors provided in the central exchange may all be a part of the switching equipment installed in the exchange prior to its conversion from an auto-manual system to a fully automatic system. As is commonly the practice in most of the installed exchanges of this character, each of these directly controllable switches is arranged for reverting control of the register senders or register markers initially provided in the exchange for directing these switches in their operation to extend connections therethrough. Accordingly, each of the register senders provided in the exchange as converted is arranged in the novel manner more fully described hereinafter to provide this type of directive control in extending connections through the original switches of the exchange.

As a necessary adjunct of the conversion, it may occur that the subscribers served by the central exchange are to be provided with free service to the subscribers served by other automatic exchanges in which the automatic switching equipment is arranged to be directly respon-

sive to received dial impulses. Alternatively, it may be expedient in modernizing the equipment of the central exchange to replace certain of the switches beyond the first directly controlled switching stage with automatic switches which are arranged to respond directly to received dial impulses. In order to illustrate these possibilities, the system is shown as comprising a four digit direct pulse connector 21 which is accessible to the selector portion of the link 15 and has access to a line 12 extending to the substation C. This connector may, for example, be of the all-relay type disclosed in copending application Serial No. 344,870, filed July 11, 1940, John H. Voss, and may be located in a distant smaller exchange. As installed, it is, of course, preceded by a non-numerical finder switch and the usual trunk repeaters, as indicated by the dash lines inserted in the trunk 24 incoming thereto. For reasons which will become apparent as the description proceeds, this connector is provided with facilities for absorbing a received first digit of nine impulses. Further to illustrate the two possibilities mentioned above, the revertive pulse second selector 20 is shown as having access to a four digit direct pulse switch train 22 over the trunk 26. This switch train is also arranged to respond directly to received dial impulses and may be provided in an exchange of the fully automatic type remote from the central exchange under consideration. It may, for example, comprise an incoming selector which has access to a three digit connector through which connections may be routed to the line 13 serving the substation D.

The finder-selector-links provided in the central exchange are identical in arrangement. Briefly considered, the illustrated link 15 comprises a finder switch of the all-relay type, a selector switch of the two-motion step-by-step type, and a group of control relays. More specifically, the finder switch comprises ten group relays, each of which is individual to the lines forming a ten line subgroup, and ten unit relays each of which is individual to a particular line in each subgroup. The illustrated group and unit relays R210 and R220 are shown as having contacts through which the conductors of the line 10 may be connected to the control equipment of the link. The selector switching mechanism of the link is of the type wherein the wipers are first rotated under the control of a rotary magnet and then elevated under the control of a vertical magnet. In brief, this mechanism comprises a contact field which is divided into eleven contact levels; wipers 470 to 473, inclusive, for making connections with the contacts in any desired contact set; a rotary magnet 474 for rotating the enumerated wipers to position same opposite a desired vertical row of contacts; a vertical magnet 475 for elevating the wipers to a position wherein they engage the contacts forming the desired contact set in the selected vertical row; a release magnet 476 which, when energized, permits the enumerated wipers to be returned to vertical and rotary normal; vertical off-normal springs 477, 478 and 479 which are operated away from the illustrated normal positions thereof when the enumerated wipers are moved off-normal in the vertical direction; and rotary off-normal springs 480 which are moved into engagement when the enumerated wipers are rotated away from the normal positions thereof. The relay equipment provided in the link comprises, in addition to the finder group

and unit relays, a start relay R200, a marginal lockout relay R230, a switching relay R300, a line relay R330, a slow-acting release relay R400, a trunk hunting relay R430, a slow-acting transfer relay R440, a revertive pulse relay R450, a pulsing relay R460, and nine additional control relays R240, R250, R310, R320, R340, R350, R360, R410 and R420. The link also comprises an impedance element 335 having an impedance which balances that of the line relay R330 after a connection has been established between the talking conductors of the link and the conductors of a calling line. A permanent signal lamp 265 is also provided therein which is controlled in the manner more fully explained below to indicate that the link has been locked out of service and is thus non-accessible to the lines associated therewith.

The register selectors individually associated with the finder-selector-links are also of identical arrangement. In brief, the illustrated register selector 18 comprises a selecting switch 550 of the well-known rotary type, a line relay R520, a test relay R530, and a control relay R510. More specifically, the switch 550 comprises four sets of contacts 551, 552, 553 and 554 of ten points each, wipers 556, 557, 558 and 559 individually associated with the enumerated contact sets, and an operating magnet 560 for driving the indicated wipers over the contacts of their respectively associated contact sets.

The register senders accessible to the register selector 18 and the other register selectors in the same group have commonly associated therewith an all-busy relay R500 which is arranged to control one or more lockout relays R540. These relays are provided for the purpose of indicating an all-busy condition of the register senders in the associated sender group and function to prevent useless seizure of the associated finder-selector-links during a period when no register senders are available for controlling the links to extend connections therethrough.

The register senders provided in the central exchange are also identical in arrangement. Briefly considered, the register sender 19 comprises three digit registers or groups of storing relays, respectively illustrated in Figs. 13, 14 and 15 of the drawings as including six relays per group; a group of impulse counting relays, shown in Fig. 16 of the drawings as including the relays R1630, R1650, R1660, R1670 and R1680; three slow-acting connect relays R1600, R1610 and R1620 for successively associating the storing relay groups with the counting relays; and a group of impulse sending relays through operation of which the digits set up in the storing relay groups and transferred to the counting relays are transmitted from the register sender. The last-mentioned group of relays includes a change pulse relay R1700, a slow-to-operate start relay R1710, a slow-to-operate release relay R1720, a pair of pulsing relays R1750 and R1760, and a pair of control relays R1730 and R1740, the last of which is of the slow-to-operate type. This group of relays together with the corresponding relays of the other register senders have commonly associated therewith a pulse generator 33, which may be of any desired type well known in the art.

The register sender 19 further comprises an incoming digit counting switch 1100, having the function of successively directing the received digits of a plural digit directory number to the three groups of storing relays; an outgoing digit

counting switch 950, having the function of controlling the transmission of the registered digits from the register sender; and a group of digit marking relays R840, R940, R1000, R1010, R1020, R1030, R1040, R1050 and R1060, which may selectively be controlled in accordance with the setting of either the No. 1 or the No. 2 group of impulse storing relays to indicate the number of digits which are to be received by the register sender during a directory number dialing operation. The two digit counting switches 950 and 1100 are of the well-known minor type. More specifically, the incoming digit counting switch 1100 comprises four contact sets 1101, 1102, 1103 and 1104 of eleven points each; two wipers 1105 and 1106, the first of which is arranged to traverse the contacts of the contact sets 1101 and 1102 and the second of which is arranged to traverse the contacts of the contact sets 1103 and 1104; an operating magnet 1107 for driving the two wipers over the contacts of their associated contact sets; a release magnet 1108; and a set of off-normal springs 1109. The outgoing digit counting switch 950 similarly comprises four contact sets 951, 952, 953 and 954 of eleven points each; wipers 955 and 956, the first of which is arranged to traverse the contacts of the contact sets 951 and 952 and the second of which is arranged to traverse the contacts of the contact sets 953 and 954; an operating magnet 957 for driving the wipers 955 and 956 over their associated contact sets; a release magnet 958; and a set of off-normal springs 959.

The register sender 19 also includes a number of relays for effecting general control operations described with particularity hereinafter. These control relays include a line relay R700, a slow-acting hold relay R710, a pair of lock pulsing relays R730 and R740, a slow-acting digit relay R750, a slow-acting hold slave relay R600, three timing relays R620, R630 and R650, three reverting call relays R640, R860 and R910, three slow-to-operate register sequence relays R610, R720 and R810, a pair of control relays R800 and R820, a send alarm relay R830, a second digit test relay R900, a one digit reverting pulse relay R920, a two digit reverting pulse relay R930, a release relay R850 and the ninth digit marking relay R840 which also functions as a start sending relay. For the purpose of selectively controlling the nine digit marking relays, the second digit test relay R900, the reverting call relay R910 and the two reverting pulse relays R920 and R930 in accordance with the numerical values of first or second digits registered in the first and second storing relay groups shown in Figs. 13 and 14, respectively, the terminal block and four connect relays illustrated in Fig. 12 of the drawings are provided. The indicated terminal block includes four different rows of terminals, to which four separate sets of marking leads extend. More specifically, the terminals forming terminal row 3 are arranged to be connected through the contacts of the first digit connect relays R1220 and R1230 to the marking leads controlled by the No. 1 group of storing relays, and the terminals forming terminal row 4 are arranged to be connected to the marking leads controlled by the No. 2 group of storing relays through the make contacts controlled by the second digit connect relays R1200 and R1210. The terminals in terminal row 1 are utilized in the circuits for controlling the nine digit marking relays. Finally, the terminals in terminal

row 2 are utilized in the control of the second digit test relay R900, the one and two digit reverting pulse relays R920 and R930, and the reverting call relay R910. There is also provided in the register sender 19 a send alarm key 105 having the function of selectively controlling the send alarm relay R830. This relay, in turn, is arranged to control the circuit for energizing an alarm signal lamp 834 having the function of indicating that the register sender is not in proper working order.

The several register senders of the exchange have commonly associated therewith certain auxiliary apparatus which is entirely conventional in character and, accordingly, has been only schematically shown in the drawings. This auxiliary apparatus includes three different timers of conventional arrangement, which are collectively indicated as comprising the timing equipment 31. It also includes the ringing current and tone generating equipment 32. The latter equipment comprises, in addition to the usual ringing current, busy tone current and dial tone current generators, a special current source for providing a distinctive tone signal which is utilized by the register sender in its operation to handle calls of the reverting type. It will be understood that all of the control equipment of the exchange is supplied with energizing current from a common current source, such, for example, as an exchange battery.

Extending a connection to the link 15

In considering the operation of the system it may be assumed that a call is originated at the substation A at a time when the illustrated finder-selector-link 15 is set up for use by the link allotter relays of the common equipment 14. When the call is initiated a calling circuit is established by way of the line 10 to cause the operation of the line relay conventionally embodied in the line circuit 10A. This relay in operating closes a circuit for energizing the start relay of the common equipment 14 and also circuits for energizing those tens and units marking relays of this equipment which correspond to the line 10. In response to these relay operations in the common equipment 14, the link start lead 272 is connected to ground to energize the start relay R200, and ground potential is applied to the units and tens marking leads 269 and 270. In operating, the relay R200 closes its contacts 206 and 207 to complete circuits respectively including the grounded units and tens marking leads 55 269 and 270 for energizing the unit and group relays R220 and R210. At its contacts 208 and 209 the relay R200 completes obvious circuits for energizing the slow-acting relays R240, R310 and R350.

The unit relay R220 and the group relay R210, in operating, extend the calling loop circuit from the conductors of the line 10 through the contacts 211, 212, 221, 222 and 304 to the windings of the impedance element 335 and the line relay R330 whereby the latter relay is energized. In operating, the group and unit relays also prepare a path through the contacts 213 and 223 for impressing ground potential upon the control conductor 268. At its contacts 214, the group relay R210 also prepares a locking circuit for itself. At its contacts 224, the unit relay R220 similarly prepares a locking circuit for itself.

The relay R310, upon operating, closes its contacts 311 to complete the prepared locking cir-

cuits for the group and unit relays R210 and R220, that for the relay R210 extending from ground by way of the contacts 311 and 332, the resistor 261, the contacts 214 and the winding of R210 to battery, and that for the unit relay R220 extending from ground by way of the contacts 311, 332 and 237, the resistor 262, the contacts 224 and the winding of R220 to battery. At its contacts 312 the relay R310 opens a point in an incomplete path for marking the illustrated link 15 as busy in the link allotter relays of the common equipment 14. The slow-acting relay R350, upon operating, opens its contacts 351 to interrupt an incomplete circuit for energizing the slow-acting relay R400. At its contacts 352 the relay R350 opens a point in an available path for impressing ground potential upon the E. C. wiper 473 of the selector switching mechanism.

The relay R240, upon operating, closes its contacts 241 to prepare certain of the operating and locking circuits for the relays R230, R250 and R330. At its contacts 242, the relay R240 completes a circuit for energizing the relay R320 in series with the cut-off relay of the line circuit 10a, this circuit extending from ground by way of the winding of R320, the contacts 235, 242, 223 and 213, the control conductor 268, and the winding of the cut-off relay in the line circuit 10a to battery. When ground potential is impressed upon the control conductor 268 over the circuit just traced, the line 10 is obviously marked as busy in the bank contacts of the connectors to which it is accessible. At its contacts 243 the relay R240 opens a point in one of the operating circuits for the relay R230. At its contacts 244 the relay R240 prepares a circuit for energizing the switching relay R300. At its contacts 245 the relay R240 prepares a path for impressing ground potential upon the two trunk conductors 35a and 35d.

The switching relay R320 operates when energized in series with the cut-off relay of the line circuit 10a. At its contacts 322, the relay R320 completes multiple locking circuits for the group and unit relays R210 and R220, which circuits commonly extend to ground through the contacts 405 of the relay R400. At its contacts 323, the relay R320 prepares the above-mentioned path for marking the illustrated link 15 as busy in the link allotter relays of the common equipment 14. At its contacts 324 the relay R320 opens the operating circuit for the start relay R200. At its contacts 321, the relay R320 prepares certain operating and locking circuits described more fully below.

When energized in the calling loop circuit, the line relay R330 opens its contacts 332 to interrupt the initially completed locking circuits for the group and unit relays R210 and R220. At its contacts 333, the relay R330 completes obvious holding circuits for the two relays R240 and R350. At its contacts 331, the relay R330 prepares the operating circuit for the two relays R260 and R410 and closes the above-mentioned path for impressing ground potential upon the two trunk conductors 35a and 35d. This path may be traced as extending from ground by way of the off-normal springs 471 and 478 and the contacts 321, 331, 403 and 412 to the contacts 245 where it divides, one branch extending through the contacts 255 to the conductor 35d and the second branch extending through the contacts 267 and 302 to the conductor 35a. When ground potential is applied to the trunk conductor 35d, the lower winding of the line relay R520 of the asso-

ciated register selector 18 is energized in an obvious circuit.

As indicated above, the cut-off relay of the line circuit 10a is energized and operates in response to the operation of the relay R240. In operating, this cut-off relay releases the common equipment 14, thus rendering this equipment available for use in handling another call. Incident to the release of this equipment, the start conductor 272 and the units and tens marking conductors 269 and 270 are disconnected from ground to interrupt the operating circuits for the start relay R200, the unit relay R220 and the group relay R210. When deenergized, the relay R200 opens its contacts 203 to deenergize the relay R310. The latter relay, upon restoring, closes its contacts 312 to complete the prepared path for marking the illustrated link 15 as busy in the allotter relays of the common equipment 14, and opens its contacts 311 further to interrupt the initially completed locking circuits for the group and unit relays R210 and R220. Following the release of the relay R310, no further operation of the equipment provided in the link 15 occurs until the register selector 18 operates to seize an idle one of the registered senders to which it has access.

Seizing a register sender

When energized over the trunk conductor 35d from the link 15, the line relay R520 of the register selector 18 closes its contacts 521 to prepare a locking circuit for itself. At its contacts 524 the relay R520 opens the path normally short-circuiting the test relay R530. At its contacts 522 the relay R520 prepares or completes a circuit for energizing the operating magnet 560 of the rotary switch 550. In this regard it will be noted that when the illustrated register sender 19 is idle, the test conductor 36d of the trunk 36 is open-circuited. On the other hand, when this sender is occupied with a call, the test conductor 36d is connected to ground through the contact 602 of the hold slave relay R600. It will be understood, therefore, that if the wipers of the rotary switch 550 stand in a position corresponding to a busy register sender at the time the line relay R520 operates, the test relay R530 is short-circuited and a circuit is provided for energizing the operating magnet 560. In such case, the path short-circuiting the winding of the test relay R530 extends from ground by way of the contacts 523, the winding of R530 and the contacts 535 and 522 to the grounded test wiper 559, while the circuit for energizing the operating magnet 560 extends from the grounded test wiper 559 through the contacts 522, 535 and 560a, and the winding of the magnet 560 to battery. When thus energized, the magnet 560 operates to advance the wipers 556 to 559, inclusive, into engagement with the contacts terminating the trunk conductors extending to another register sender. In operating, the magnet 560 also opens its contacts 560a to deenergize its own winding. If the second register sender is also busy, ground potential is maintained upon the test wiper 559 to prevent the energization of the test relay R530 and to cause the reoperation of the magnet 560 when this magnet releases. In reoperating, the magnet 560 advances the wipers 556 to 559, inclusive, to select a third register sender. From the above explanation it will be understood that the magnet 560 continues to step the wipers of the rotary switch 550 until an idle register sender is found. Assuming that the illustrated register

sender 19 is the first idle register sender tested by the selector 18, the stepping operation of the rotary switch 550 is arrested when the wipers 556 to 559, inclusive, are operated to engage the contacts terminating the conductors of the trunk 36. With the wipers standing in this position, the test wiper 559 is disconnected from ground to interrupt the path short-circuiting the winding of the test relay R530 and to prevent further operation of the magnet 560. When the path short-circuiting the winding of the test relay R530 is interrupted, this relay is energized in series with the winding of the magnet 560 over a circuit which includes the contacts 523 and 560a. The current flow over this circuit is insufficient to cause the reoperation of the magnet 560. The relay R530, however, operates when energized in this circuit. At its contacts 538, the relay R530 completes an obvious locking circuit for itself. At its contacts 537, the relay R530 prepares a locking circuit for the relay R510. At its contacts 535, the relay R530 further interrupts the operating circuit for the magnet 560 and the path for short-circuiting its own winding. At its contacts 536, the relay R530 completes a path through the contacts 522 and the wiper 559 for marking the register sender 19 against seizure by the other register selectors having access thereto. At its contacts 531 and 532, the relay R530 connects the trunk conductors 35b and 35a through the wipers 556 and 557 to the trunk conductors 36b and 36a of the trunk 36 extending to the register sender 19. Incident to this operation, a circuit including the grounded conductor 35a and the contacts 621 is completed for energizing the line relay R700 of the sender 19. At its contacts 534, the relay R530 prepares the operating circuit for the relay R510 and a locking circuit for the line relay R520.

When the register sender 19 is seized over the trunk 36 in the manner just explained, certain of the relays embodied therein operate to condition this sender to direct the operation of the selector portion of the link 15 and the succeeding automatic switches in the extension of the call to the desired substation. Incident to the seizure of this register sender, the hold slave relay R600 operates to complete the prepared operating circuit for the relay R510, this circuit extending from ground by way of the 200 ohm resistor 635, the contacts 607 and 627, the trunk conductor 36c, the wiper 558, the contacts 534 and 511, and the winding of R510 to battery. When thus energized, the relay R510 first opens its Z contacts 515 to interrupt the available path for directly connecting the trunk conductor 35c to ground in the register selector 18 and then closes its contacts 514 to complete the prepared locking circuit for itself. At its contacts 511, the relay R510 next interrupts its operating circuit as traced above. At its contacts 512, the relay R510 completes a holding circuit for the line relay R520, this circuit extending from ground by way of the resistor 635, the contacts 607 and 627, the conductor 36c, the wiper 558, the contacts 534, 512 and 521 and the upper winding of R520 to battery. At its Y contacts 513, the relay R510 finally opens the previously traced operating circuit for the line relay R520.

At its contacts 512, the relay R510 also completes the prepared operating circuit for the switching relay R300 of the finder-selector-link 15. This circuit extends from ground by way of the resistor 635, the contacts 607 and 627, the conductor 36c, the wiper 558, the contacts 534

and 512, the conductor 35c the contacts 244 and 254, and the winding of R300 to battery. It will be noted that a branch of this circuit extends through the resistor 264 and the contacts 236 to energize the relay R230. Due to the current limiting action of the resistor 264, the relay R230 is insufficiently energized in this branch circuit to operate. The switching relay R300, however, operates and closes its contacts 307 to complete an obvious locking circuit for itself. At its contacts 303, the relay R300 completes a holding circuit for the line relay R330, this circuit extending from ground by way of the contacts 241, the resistor 308, the contacts 303, and the winding of R330 to battery. After this circuit is completed, the relay R300 opens its contacts 304 to disconnect the line relay R330 from the negative side of the line 10. At its contacts 301, the relay R300 establishes a pulsing circuit over which impulses may be transmitted from the calling substation A to the line relay R700 of the seized register sender 19. This circuit may be traced as extending from ground by way of the winding of the impedance coil 335, the positive side of the loop circuit extending to the substation A, the bridge established between the conductors of the line 10 at this substation, the negative side of the loop circuit, the contacts 301, the conductor 35a, the contacts 532, the wiper 557, the conductor 36a, the contacts 621 and the winding of R700 to battery. After this circuit is established to maintain the energization of the line relay R700, the operating circuit of this relay is opened at the contacts 302. At its contacts 306, the relay R300 completes the prepared operating circuit for the two relays R360 and R410, this circuit extending from ground by way of the off-normal springs 477 and 478, the contacts 321, 331 and 403, the winding of R410, the winding of R360, and the contacts 306 to battery. At its contacts 305, the relay R300 completes a circuit including the resistor 309 and the contacts 252 and 241 for energizing the relay R250.

In operating, the relay R250 first locks to ground through its preliminary make contacts 251 and the contacts 241, and then opens its contacts 252 to interrupt its operating circuit as traced above. At its contacts 253, the relay R250 completes a path including the contacts 241 and 305 and shunts the winding of the impedance element 335 with the resistor 309, thereby to reduce the series resistance of the loop circuit over which the line relay R700 of the register sender 19 is energized. At its contacts 254, the relay R250 opens the above-traced operating circuit for the switching relay R300. At its contacts 255, the relay R250 disconnects the trunk conductor 35d from ground, thereby to open another point in the operating circuit for the line relay R520 of the register selector 18. At its contacts 257, the relay R250 opens another point in the previously traced operating circuit for the line relay R700 of the register sender 19. At its contacts 256, the relay R250 completes a circuit for energizing the permanent signal lamp 265, this circuit extending from ground by way of the off-normal springs 477 and 478, the contacts 321, 331, 403, 412, 245 and 256 and the filament of the lamp 265 to battery.

The relay R410, upon operating, closes its contacts 411 to connect the negative wiper 471 of the selector switching mechanism to ground over a path including the contacts 422 and 232. At its contacts 413, the relay R410 prepares a reverse pulsing circuit which is utilized to clear

the register sender 19 of digits registered therein in the event a trunk hunting operation on the part of the selector switching mechanism is initiated at a time when all of the trunks of the selected group are busy. At its contacts 412, the relay R410 opens another point in the above-traced path for impressing ground potential upon trunk conductors 35a and 35d and deenergizes the permanent signal lamp 265.

The relay R360, upon operating, closes its contacts 362 to prepare a circuit over which the pulsing relay R460 may be controlled from the register sender 19 and the pulse sending relays of the register sender may be revertively controlled by the revertive pulse relay R450. At its contacts 361, the relay R360 opens a point in the talking channel through the line, thereby to prevent the pulses transmitted between the register sender and the link during the extension of the connection from being reproduced as clicks by the receiver provided at the calling substation. At its contacts 363, the relay R360 completes an obvious circuit for energizing the relay R340. The latter relay, upon operating, locks to ground over a path including the contacts 341 and 321, and the off-normal springs 477 and 478. At its contacts 342, the relay R340 opens a point in the operating circuit for the relay R400. At its contacts 341 and 343, the relay R340 completes a holding circuit for the two relays R410 and R360, this circuit extending from ground by way of the contacts 363, 341, 343 and 403, the winding of R410, the winding of R360 and the contacts 306 to battery.

Following the seizure of the register sender 19 and the resulting operation of the relays R300, R250, R360, R340 and R410 in the manner just explained, the link circuit equipment occupies a setting such that impulses may be transmitted through the link from the calling substation A to the register sender 19 for the purpose of setting up the required digit information in the register sender. Also, an outgoing impulsive circuit is established between the link and the register sender 19 over which the selector switching mechanism of the link may be directly controlled in accordance with the first digit of the directory number transmitted to the register sender from the calling substation. In this regard it will be understood that with the switching relay R300 operated, the dial actuated calling device provided at the calling substation A may be operated to transmit impulses to the line relay R700 of the sender 19 over a circuit which includes the two sides of the line 10 and the trunk conductors 35a and 36a. The manner in which the register sender responds to the received impulses is explained in detail hereinafter. At this point, however, it is noted that shortly after one or two digits are transmitted to the register sender from the calling substation, the register sender functions to energize the pulsing relay R460, whereby operation of the selector switching mechanism is initiated.

Extending the connection from the link 15

The type of pulsing utilized between the register sender 19, the selector portion of the link 15, and those switches which are required to succeed the link 15 in routing the call to its destination, is determined by the numerical value of the first or second digit transmitted to the register sender from the calling substation A in the manner more fully explained below. In this regard it is indicated above that, depending upon the

destination of a given call, any one of the available register senders may be requiring to transmit a train of digits, certain of which are utilized to direct the operation of automatic switches arranged for direct impulse control and others of which are utilized to direct automatic switches which are arranged for revertive control of the register senders. The selector portion of the link 15 is arranged for the latter type of control. 5 More specifically, the pulsing relay R460 of the link 15 is energized in series with the pulse sending relay R1760 of the register sender 19 during the closed circuit period of each impulse of the first digit. When energized in series with the 10 impulse sending relay R1760, the pulsing relay R460 closes its contacts 461 to complete an obvious circuit for energizing the transfer relay R440. At its contacts 461 and 462, the relay R460 also completes an obvious circuit for energizing the rotary magnet 474. When thus energized, the transfer relay R440 opens its contacts 441 to interrupt the operating circuit for the 15 trunk hunting relay R430. 15 The rotary magnet 474, upon operating, steps the wipers 470 to 473, inclusive, one step in the rotary direction and closes its contacts 474a to complete an obvious circuit for energizing the reverting pulse relay R450. The latter relay, upon operating, opens its contacts 451 to deenergize the series connected relays R460 and R1760, thereby to complete the impulse. At its contacts 452, the relay R450 opens a point in the locking circuit for the relay R430 and a point in the path for impressing ground potential upon the private wiper 472. At its contacts 453, the relay R450 opens a point in the operating circuit for the vertical magnet 475. When deenergized in the manner just explained, the impulse sending relay R1760 restores to step the impulse counting relays of the register sender 19 one step, whereby the transmitted impulse is counted in the manner more fully explained hereinafter. The relay R460, upon restoring, opens its contacts 461 to interrupt the operating circuit for 20 the transfer relay R440. At its contacts 462, the relay R460 deenergizes the rotary magnet 474. The rotary magnet, in releasing, opens its contacts 474a to deenergize the reverting pulse relay R450. The latter relay, upon restoring, closes its contacts 451 to reprepare the circuit for energizing the two relays R460 and R1760 in series. During each succeeding pulse transmitted to the selector portion of the link 15 from the register sender 19, the two relays R460 and R450 interact 25 with the rotary magnet 474 in the exact manner explained above, it being noted that each time a current pulse is transmitted to the rotary magnet the wipers 470 to 473, inclusive, are stepped an additional step, and that each time the relay R460 operates a current pulse is transmitted to the transfer relay R440. Due to its slow-to-release characteristic, the latter relay remains operated during impulsive. It will also be understood that at the end of the first digit the wipers 30 470 to 473, inclusive, occupy a position opposite the vertical row of contacts corresponding to the numerical value of the digit. Thus if a first digit comprising ten impulses is dialed into the register sender 19 from the calling substation A and is repeated back to the selector portion of the link 15 by the impulse sending relays of the register sender, the indicated wipers will, at the end of the first digit transmitted by the impulse sending relays of the register sender, occupy a position 35 opposite the tenth vertical row of contacts in the 40 45 50 55 60 65 70 75

associated contact field. Incident to the first rotary step of these wipers, the rotary off-normal springs 480 and 481 are moved into engagement to prepare the operating circuit for the transfer relay R430. At these off-normal springs, multiple locking circuits for the operated group and unit relays R210 and R220 are also completed.

At the end of the first digit and during the interdigit pause between the first and second digits transmitted by the register sender 19, the pulsing relay R460 remains in its restored position to cause the release of the transfer relay R440. Upon restoring, the latter relay closes its contacts 441 to complete the prepared operating circuit for the transfer relay R430, this circuit extending from ground by way of the engaged rotary off-normal springs 480 and 481, the contacts 492 and 441, the vertical off-normal springs 479 and the winding of R430 to battery. When thus energized, the relay R430 locks to ground through the contacts 431 and 452; closes its contacts 432 to energize the relay R420; and closes its contacts 433 to complete a circuit through the contacts 453 for energizing the vertical magnet 475. In operating, the relay R420 opens its contacts 422 to disconnect the wiper 471 from ground, and opens its contacts 421 to disconnect the wiper 470 from the pulsing conductor 35b of the trunk 35. At its contacts 423, the relay R420 opens a point in the operating circuit for the slow-acting release relay R400. At its contacts 424, the relay R420 prepares the operating circuit for the release magnet 476.

The vertical magnet 475, upon operating, steps the wipers 470 to 473, inclusive, one step in the vertical direction and closes its contacts 475a to complete an obvious circuit for energizing the reverting pulse relay R450. This relay, in operating, opens its contacts 453 to deenergize the vertical magnet 475. At its contacts 452, the relay R450 opens a point in the locking circuit for the trunk hunting relay R430. Incident to the vertical movement of the wipers 470 to 473, inclusive, the off-normal springs 477 and 478 are opened to interrupt the circuit for energizing the pulsing relay R460 and to open the multiple locking circuits for the relays R340, R410 and R360. The vertical off-normal springs 479 are also disengaged to open the previously traced operating circuit for the trunk hunting relay R430.

Further operation of the wipers 470 to 473, inclusive, in the vertical direction depends upon the idle or busy condition of the trunk which is selected incident to the first vertical step of these wipers. More specifically, if this trunk is occupied with a call the test conductor thereof is marked with ground potential to provide a locking circuit through the test wiper 472 and the contacts 431 for maintaining the trunk hunting relay R430 energized. On the other hand, if the trunk is idle, the test conductor thereof is not marked with ground potential so that the trunk hunting relay R430 is deenergized and restores when the off-normal springs 479 and the contacts 452 are opened. Assuming that the first trunk of the selected group is busy, such that the trunk hunting relay R430 is held in its operated position, the vertical magnet 475, upon restoring in response to the operation of the reverting pulse relay R450, opens its contacts 475a to deenergize this relay. In releasing, the reverting pulse relay R450 closes its contacts 452 to recomplete the locking circuit for the trunk hunting relay R430 and closes its contacts 453 to again energize the vertical magnet 475. Upon

reoperating, the magnet 475 steps the wipers of the selector switching mechanism a second step in the vertical direction, whereby the back contacts terminating the conductors of the second trunk in the selected group are connected to these wipers, and closes its contacts 475a to again energize the reverting pulse relay R450. It will be understood from the above explanation that the relay R450 and the magnet 475 continue to interact until an idle trunk of the selected group is found. When this occurs, the test wiper 472 is disconnected from ground, in the manner explained above, to cause the deenergization and release of the trunk hunting relay R430. Thereafter, the relay R450 restores and closes its contacts 452 to impress ground potential upon the test wiper 472, whereby the selected trunk is marked as busy. Upon restoring, the relay R430 opens its contacts 431 further to interrupt its own operating circuit. At its contacts 433, the relay R430 opens the operating circuit for the vertical magnet 475 to prevent further operation of this magnet and the reverting pulse relay R450. At its contacts 432, the relay R430 deenergizes the relay R420. In releasing, the relay R420 closes its contacts 422 to connect the negative line wiper 471 to ground. When ground potential is impressed upon the test wiper 472 and the negative line wiper 471, the switch terminating the distant end of the selected trunk is seized in a well-known manner and conditioned to receive the impulses of the second digit registered in the register sender 19. At its contacts 421, the relay R420 prepares a circuit for transmitting the impulses of the second digit, if any, to the automatic switch seized over the selected trunk. At its contacts 423, the relay R420 reprepares the operating circuit for the release relay R400. At its contacts 424, the relay R420 opens the prepared operating circuit for the release magnet 476. Following the release of the relay R420 no further relay operations occur in the selector portion of the link 15 until all of the digits registered in the register sender 19 have been transmitted from this sender to direct the switches succeeding the illustrated link in their operation to forward the call to the desired destination.

50   *Switching through when the register sender releases*

When the register sender 19 clears itself of all digits transmitted thereto from the calling substation A, it is released in the manner fully explained hereinafter. Incident to the release of this sender, the connected trunk conductor 35c and 36c are disconnected from ground to deenergize the switching relay R300 of the link 15 and the line relay R520 of the register selector 18. When thus deenergized, the relay R300 opens its contacts 307 further to interrupt its own locking circuit. At its contacts 306, the relay R300 opens the operating and locking circuits for the two relays R360 and R410. At its contacts 304, the relay R300 again includes the winding of the line relay R330 in the loop circuit extending to the calling substation A. At its contacts 303, the relay R300 opens the locking circuit for the line relay R330. At its contacts 305, the relay R300 opens the above-traced path in shunt with the winding of the impedance coil 335. At its contacts 301, the relay R300 disconnects the pulsing conductor 35a of the trunk 35 from the negative side of the calling line 10.

The relay R410, upon restoring, opens its contacts 411 to interrupt the path for impressing ground potential upon the negative line wiper 471. At its contacts 412, the relay R410 prepares the path for impressing ground potential upon the two trunk conductors 35a and 35d. At its contacts 413, the relay R410 opens a point in the revertive pulsing circuit described below. The relay R360, upon restoring, opens its contacts 363 to deenergize the relay R340 and closes its contacts 361 to extend the talking circuit through the link 15 to the trunk incoming to the next operated switch of the switch train. At its contacts 362, the relay R360 opens another point in the previously traced circuit for energizing the pulsing relay R460 and for revertively controlling the impulse sending relays of the register sender.

The relay R340, upon restoring, opens its contacts 341 and 343 further to interrupt the locking circuit for itself and the two relays R360 and R410. At its contacts 342, the relay R340 prepares the operating circuit for the relay R400. Following the release of the four relays R300, R340, R360 and R410 no further operation of the equipment embodied in the link 15 occurs until the connection is released at the calling end thereof. In this regard it will be noted that following the release of these four relays, talking battery is supplied to the calling substation A through the windings of the impedance element 335 and the line relay R330.

Release of the register selector 18

As indicated above, the line relay R520 is de-energized incident to the release of the register sender 19. This occurs when all of the digits registered in this sender through operation of the calling device provided at the substation A have been cleared from the sender. In releasing, the relay R520 opens its contacts 521 further to interrupt its own locking circuit. At its contacts 522, the relay R520 disconnects the test conductor 36d of the trunk 36 from ground, thereby to render the register sender 19 accessible to the other register selectors. At its contacts 523, the relay R520 opens the operating circuit for the test relay R530. At its contacts 524, the relay R520 completes an obvious path for short-circuiting the winding of the test relay R530 and an obvious circuit for energizing the motor magnet 560. When thus energized, the magnet 560 operates to advance the wipers 556 to 559, inclusive, one step wherein they are positioned to engage the contacts terminating the trunk conductors extending to another of the register senders. In operating, the magnet 560 also opens its contacts 560a to interrupt the path short-circuiting the winding of the test relay R530. When thus deenergized, the test relay R530 opens its contacts 538 to interrupt its locking circuit as described above. At its contacts 537, the relay R530 opens the locking circuit for the relay R510. Shortly following the release of the test relay R530, the magnet 560 restores and closes its contacts 560a to recomplete the path for short-circuiting the winding of the test relay R530. Following the release of the relay R510 the register selector 18 is fully restored to normal. In this regard it will be noted that after the link 15 has been operated to its switch-through setting the trunk conductor 35d is disconnected from ground therein to prevent the reoperation of the line relay R520 provided in the register selector 18.

All-trunks-busy

In the event all of the trunks of the group selected during the rotary movement of the wipers 470 to 473, inclusive, are busy at the time 5 the trunk hunting operation of the selector switching mechanism is initiated, the step by step movement of these wipers is continued until they are operated to the eleventh vertical off-normal position thereof. When operated to this 10 position, the test wiper 472 is disconnected from ground since the test contacts of the eleventh vertical row of contacts are not wired. It will be understood, therefore, that the trunk hunting relay R430 is deenergized incident to the eleventh vertical step of the selector switch wipers. Upon 15 restoring, this relay opens its contacts 432 and 433 to deenergize the relay R420 and to open the operating circuit for the vertical magnet 475. Thus the trunk hunting operation of the 20 selector switching mechanism is arrested.

The relay R420, in releasing, closes its contacts 421 to complete the above-mentioned revertive pulse circuit, this circuit now extending through the positive line wiper 470 and the contacts 413 to the revertive pulse lead 414. The last-mentioned lead extends to a group of relays which are arranged to cooperate with the pulse sending relay R1760 of the register sender 19 in the exact manner that the rotary magnet 474 and the reverting pulse relay R450 cooperated with the pulse sending relay R1760 during the above-described transmission of the first digit from the register sender to the link 15. It will be understood, therefore, that each time the winding of the pulse sending relay R1760 is connected to the revertive pulse lead 414 through the wiper 470 and the engaged contact of the eleventh vertical contact set in the selected vertical row, one of the reverting pulse relays, not shown, is energized over the revertive pulse lead and, in operating, causes this lead to be disconnected from ground to cause the deenergization of the pulse sending relay R1760. The purpose of providing this conventional arrangement is to clear the register sender of all digits set up therein through operation of the calling device provided at the calling substation. In this regard it will be understood that after the register sender 19 has completed its impulse sending operation it is automatically released.

Incident to the release of the register sender 19 the trunk conductor 36c is disconnected from ground to cause the release of the register selector 18 and the release of the four link relays R300, R340, R360 and R410 in the exact manner explained above. In this case, the relay R300, upon restoring, closes a circuit for transmitting the usual busy tone signal over the calling end of the connection, this circuit extending from one terminal of the busy tone signal generator included in the common equipment 32 by way of the busy tone conductor C911, the wiper 471, the contacts 422, the condenser 344, the contacts 304, 60 222 and 212, the negative side of the loop circuit extending to the calling substation A, the receiver provided at this substation, the positive side of the loop circuit, the contacts 211 and 221 and the winding of the impedance coil 335 to the opposite terminal of the busy tone generator. When 65 this signal is received by the calling subscriber the connection may be released in the manner explained below.

Extending the connection to the called substation

75 From the above explanation it will be under-

stood that the destination of the call extended to the link 15 is determined entirely by the directory number designation set up in the register sender 19 under the control of the calling device provided at the calling substation A. In order fully to explain the facilities provided in the register sender 19 for automatically controlling the type of impulsing used in directing the call to its destination in accordance with the numerical value of the first or second digit of the registered directory number, while at the same time utilizing these digits for switch directing purposes and also to inform the register sender as to the number of digits which are to follow, several different destinations for the call extended to the link 15 have been indicated in Fig. 1 of the drawings. For example, if the initiated call is a toll call requiring the assistance of a toll operator for completion, the single digit "0" is dialed into the register sender 19. In this case the numerical value of the digit indicates to the register sender 19 that only one digit is to be received and transmitted thereby. This sender in repeating the digit to the selector portion of the link 15 directs the link in its operation to seize an idle one of the trunks, such, for example, as the trunk 25, extending to the toll operator switchboard 30. The register sender 19 is released and the link 15 is operated to switch the talking circuit through to the conductors of the trunk 25 immediately after the selector portion of the link operates to seize an idle one of the toll switchboard trunks. From the toll switchboard 30 the call may be extended to the desired exchange and substation in the manner conventionally followed in toll practice.

If the call as routed to the link 15 from the substation A is to be forwarded to another substation, such, for example, as the substation B, served by the same exchange, the directory number designation of the desired substation will necessarily comprise five digits. In this case the first digit transmitted to the register sender from the calling substation may comprise from one to four impulses, which indicates to the register sender that five digits are to be received and that during the transmission of the five digits from the register sender the impulse sending relays will be revertively controlled from the automatic switches through which the connection is extended. The first digit transmitted to the register sender 19 is utilized to direct the selector portion of the link 15 in its operation to seize a trunk, such, for example, as the trunk 22, extending to a revertive pulse second selector. The second digit is utilized to direct the seized second selector such, for example, as the selector 16 in its operation to seize an idle local connection to which it has access. The three remaining digits are utilized to direct the seized connector such, for example, as the connector 17, in its operation to select the desired line 11 and to select the particular code or frequency which is to be used in signaling the called substation B. After these operations are completed, the usual line test is performed in the connector 17 to determine the idle or busy condition of the called line 11; the called substation is signaled if the line is idle; and the usual busy signal is transmitted to the calling subscriber if the line tests busy. The desired talking circuit between the calling and the called substations is completed in the connector 17 when the call is answered at the called substation B.

In the case just considered the register sender

19 is revertively controlled from the selector portion of the link 15, the second selector 16 and the connector 17 in its operation to transmit each of the five digits required to forward the call to the desired substation. It may occur, however, that the call as routed to the link 15 is intended for a substation served by a distant exchange which employs automatic switches not equipped for revertive control of the register sender 19 during impulsing. For example, the first two digits transmitted to the register sender 19 may comprise eight and nine impulses, respectively, indicating that the group of interoffice trunks including the trunk 24 is to be selected during the primary movement of the selector switching mechanism in the link 15. As previously stated, the trunks of the group including the trunk 24, may extend to an exchange in which four digit connectors are the only directly controlled switches utilized in gaining access to the lines terminated thereat. Moreover, these connectors are of the direct impulse type, not being equipped for the revertive control of the register senders provided in the originating exchange. In this case and as will be more fully explained herein-after, the first digit "8" as dialed into the register sender 19 indicates that the trunk group including the trunk 24 is to be selected by the selector switching mechanism of the link 15. The second digit "9" indicates that the impulse sending equipment of the register sender cannot rely upon revertive control to clear the register sender during the transmission of the second, third, fourth and fifth digits. The second digit transmitted to the register sender from the calling substation also indicates to the register sender that five digits are to be received by the sender during the dialing operation. It will be understood that in this case the call may be extended over the trunk 24 and through the four digit connector 21, for example, to the desired substation, such, for example, as the substation C, served by the distant exchange.

As a further illustration of the route which the call may take, it is pointed out that the call may be extended from this link over the trunk 23 and through the second selector 20 either to one of the special service trunks 27, 28 and 29 or through the four digit switch train 22' of a second distant exchange to the line 13 and the substation D, for example. The trunk 23 is terminated in the bank contacts of the selector portion of the link 15 in the sixth vertical row of contacts. Accordingly the first digit dialed into the register sender 19 from the calling substation will necessarily comprise six impulses. In this case also, the second digit transmitted to the register sender 19 is utilized to inform the sender as to the type of impulsing which will be used in extending the connection from the link 15. Thus, if a second digit "2," "3" or "8" is dialed into the register sender 19, the sender is informed that it will be revertively controlled throughout its impulse sending operation. These three second digits when preceded by the digit "6" also indicate that one of the three groups of special service trunks will be seized through the second selector 20, and that only three digits are to be dialed into the register sender from the calling substation. On the other hand, if a second digit "4" is dialed in the register sender 19 after the digit "6," an indication is provided that the call is to be extended through the four digit direct pulse switch train 22, the register sender 19 is informed that all digits after the second digit will

be transmitted to automatic switching equipment not provided with facilities for revertively controlling the impulse sending relays, and an indication is provided in the register sender that a total of six digits are to be received during the directory number dialing operation.

Release of the connection

The release of the connection as extended from the substation A through the link 15 to the toll switchboard 39, or to the substation B, C or D, or to a special service operator position terminating one of the three special service trunks 27, 28 and 29, is under the control of the calling party at the substation A. More specifically, when the calling subscriber restores the receiver provided at this substation to its supporting hook or cradle, the calling loop circuit is opened to cause the deenergization and release of the line relay R330. This relay, in restoring, opens its contacts 333 to deenergize the two relays R240 and R350. The relay R240, upon restoring, opens its contacts 241 to deenergize the relay R250. At its contacts 242, the relay R240 opens the circuit over which the relay R320 is energized in series with the cutoff relay of the line circuit 10a causing both of the two last-mentioned relays to restore. The relay R350, in restoring, closes its contacts 352 to complete the operating circuit for the relay R400, this circuit extending from the grounded E. C. wiper 473 of the selector switching mechanism by way of the contacts 423 and 352 and the winding of R400 to battery. In this regard it is noted that when a succeeding switch is seized through the outlet contacts of the selector switching mechanism embodied in the link 15, ground potential is returned over the E. C. conductor of the trunk extending to the seized switch. The relay R320, upon restoring, opens its contacts 322 to deenergize the group and unit relays R210 and R220. At its contacts 324, the relay R320 prepares the operating circuit for the start relay R200. At its contacts 323, the relay R320 opens the path over which the link 15 is marked as busy in the allotter relays of the common equipment 14, thereby to render this link available for use in handling another call.

The relay R400, upon operating, locks to ground through its contacts 401 and the off-normal springs 481 and 480. At its contacts 403 the relay R400 opens a point in the operating circuit for the two relays R410 and R360. At its contacts 405, the relay R400 opens another point in the locking circuits for the group and unit relays R210 and R220. At its contacts 402, the relay R400 opens a point in the operating circuit for the trunk hunting relay R430. At its contacts 404, the relay R400 completes an obvious circuit for energizing the relay R420.

The relay R420, upon operating, closes its contacts 424 to complete the prepared operating circuit for the release magnet 476, this circuit extending from ground by way of the off-normal springs 480 and 481, the contacts 401, 352 and 424 and the winding of the magnet 476 to battery. When thus energized, the magnet 476 attracts its associated holding pawl permitting the wipers 470 to 473, inclusive, to be returned to vertical and rotary normal in the usual manner. Incident to the release of these wipers, the vertical off-normal springs 477, 478 and 479 are respectively moved into engagement, and the rotary off-normal springs 480 and 481 are disengaged to deenergize the relays R400 and R420 and the release magnet 476. Also incident to the release of the

enumerated wipers, ground potential is removed from the test conductor of the trunk extending to the next succeeding switch of the train through which the connection extends, thereby to initiate

5 the release of that portion of the train which follows the illustrated link 15. Following the release of the relay R400, the link 15 is fully restored to normal and may be assigned for further use by the link allotter relays of the common equipment 14.

The manner in which that portion of the switch train following the illustrated link 15 is released is entirely conventional and will be readily understood by those skilled in the art. In this regard 15 it is noted that, when the relay R240 restores in the manner explained above to deenergize the cutoff relay of the line circuit 10a, this cutoff relay restores to release the indicated line circuit, and guarding ground potential is removed 20 from the private conductor 268 of the line 10.

All trunks to register senders busy

When all of the register senders accessible to the register selector 18 become busy, the all-busy relay R500 is deenergized and restores. In this regard it is noted that a circuit for energizing the all-busy relay R500 is normally completed in the register sender 19 through the contacts 603 and 622, this circuit being opened when the 30 register sender is seized. Similar parallel circuits extend to each of the register senders in the group accessible to the register selector 18. It will be understood, therefore, that when all of the register senders in this group become busy, the relay R500 is deenergized and restores. In releasing, this relay closes its contacts 501 to complete an obvious circuit for energizing the relay R540.

The latter relay, upon operating, closes its contacts 541 to complete a path through the contacts 515 for impressing ground potential directly upon the control conductor 35c of the trunk 35. At its contacts 542, 549, etc., the relay R540 closes similar ground marking paths to the control conductors of the trunks extending to each of the other register selectors having access to the register senders of the group in which the all-busy condition prevails. In operating to apply ground potential to the trunk conductor 35c, the relay R540 closes a circuit for energizing the lock-out relay R230 of the link 15, this circuit extending from the grounded conductor 35c by way of the contacts 243 and the winding of R230 to battery. When thus energized, the relay R230 closes its contacts 234 to complete a circuit including the resistor 263 for energizing the relay R320.

The relay R320 now operates and closes its contacts 323 to complete the path for marking the illustrated link 15 as busy in the link allotter relays of the common equipment 14. At its contacts 324, the relay R320 opens a point in the operating circuit for the start relay R200. At its contacts 321, the relay R320 completes an alternative circuit for energizing the relay R400, this circuit extending from ground by way of the off-normal springs 477 and 478, the contacts 321, 342 and 351, and the winding of R400 to battery. The resulting operation of the relay R400 is without effect. So long as the relay R320 remains operated, the link 15 is prevented from being assigned for use by the link allotter relays of the common equipment.

Obviously, when one of the register senders in the group accessible to the register selector 18 is released, the operating circuit for the all-busy relay R500 is again completed. This relay, in op-

erating, causes the sequential release of the relays R540, R230, R320 and R400 in a manner clearly apparent from the preceding explanation. The relay R320, upon restoring, opens its contacts 323 to interrupt the path over which the illustrated link 15 is marked as busy in the allotter relays of the common equipment 14. Thus, this link is rendered available for further use.

Register senders become busy while the register selector 18 is searching for an idle sender

It will be apparent that all of the register senders accessible to the selector 18 may become busy after the link 15 is seized and while the selector 18 is searching for an idle register sender. In such case, the relays R240, R350, R210, R220, R320 and R330 are operated in the link 15 and the line relay R520 is operated in the register selector 18 at the time the all-busy condition of the register senders occurs. When the all-busy relay R500 restores to indicate the all-busy condition of the register senders accessible to the selector 18, the relay R540 closes its contacts 541 to complete an obvious locking circuit for the line relay R520 and an alternative circuit for energizing the two relays R300 and R230 in parallel. The latter circuit extends from ground by way of the contacts 515 and 541, the conductor 35c and the contacts 244 to the contacts 254 where it divides, one branch extending through the winding of R300 to battery and the other branch extending through the resistor 264, the contacts 236 and the winding of R230 to battery. When thus energized over a circuit in which the conductor 35c is directly connected to ground, the two relays R230 and R300 both operate.

The relay R300, upon operating, locks to the grounded conductor 35c and causes the operation of the relays R250, R360, R410 and R340 in the exact manner explained above. At its contacts 303, the relay R300 establishes the previously traced locking circuit for the line relay R330. The lockout relay R230, upon operating, locks to ground through its preliminary make contacts 231 and the contacts 241, and then opens its operating circuit at the contacts 236. At its contacts 234 and 235 the relay R230 closes a circuit through the resistor 263 for maintaining the relay R320 energized and then disconnects the control conductor 268 from ground to cause the de-energization and partial release of the cutoff relay embodied in the line circuit 10a. The line circuit 10a is thus operated to its line lockout setting. At its contacts 232, the relay R230 opens the path for impressing ground potential upon the negative line wiper 471. At its contacts 233, the relay R230 prepares a path for impressing resistance battery potential upon the indicated line wiper. At its contacts 237, the relay R230 opens the locking circuit for the unit relay R220. The latter relay, in releasing, opens its contacts 221, 222 and 223 to disconnect the talking conductors of the calling line from the talking conductors of the link and to open another point in the initially traced circuit for energizing the relay R320 in series with the cut-off relay of the line circuit 10a. At its contacts 224, the relay R220 opens another point in its own locking circuit. Following the operation of the six relays R230, R250, R300, R340, R360 and R410 and the release of the unit relay R220, no further relay operations occur in the link 15 until the all-busy condition of the register senders accessible to the selector 18 is terminated. In this regard it will be noted that, with the relay R320 operated and

the relay R310 restored, the above-traced path is completed through the contacts 323 and 312 for marking the link as busy in the allotter relays of the common equipment 14, thereby to prevent this link from being assigned to the use of another calling line. It will also be noted that with the relays R250 and R410 operated in the link, the operating circuit for the line relay R520 of the register selector is held open at the contacts 255 and 412.

When the all-busy condition of the register senders accessible to the register selector 18 is cleared, the all-busy relay R500 and the lockout relay R540 restore in the order named. The latter relay, in releasing, opens its contacts 541 to disconnect the trunk conductor 35c from ground and thus cause the release of the switching relay R300 in the link 15 and the line relay R520 in the selector 18. When the line relay R520 restores, the register selector 18 is released in a manner clearly apparent from the above explanation. In releasing, the relay R300 opens its contacts 306 to deenergize the two relays R360 and R410. At its contacts 303, the relay R300 opens the only available circuit for energizing the line relay R330. Thus the three relays R330, R360 and R410 are caused to restore. The relay R360, upon restoring, opens its contacts 363 to interrupt the operating circuit for the relay R340. The relay R410, upon restoring, closes its contacts 412 to complete the previously traced circuit for energizing the permanent signal lamp 265.

The line relay R330, upon restoring, opens its contacts 333 to deenergize the two relays R240 and R350. At its contacts 331, the relay R330 opens a multiple point in the circuit for energizing the permanent signal lamp 265. The relay R350, upon restoring, closes its contacts 351 to prepare the operating circuit for the release relay R430. The relay R240, upon restoring, opens its contacts 241 to deenergize the two relays R230 and R250. At its contacts 245, the relay R240 de-energizes the permanent signal lamp 265. The two relays R230 and R250 now restore and the first thereof opens its contacts 234 to deenergize the relay R320. When the latter relay restores it opens its contacts 321 to deenergize the relay R340. At its contacts 322, the relay R320 opens the locking circuit for the group relay R210, causing the latter relay to restore. At its contacts 323, the relay R320 opens the path for marking the illustrated link 15 as busy in the allotter relays of the common equipment 14. Following the release of the two relays R340 and R210, the link 15 is fully restored to normal and may be assigned to the use of another calling line.

Reverting calls

If the above-described call initiated at the substation A and extended to the link 15 is intended for another substation served by the line 10, the connection may be extended from the link 15 through the second selector 16 and the connector 17 back to the line 10 in a manner clearly apparent from the above explanation. In this regard it will be understood that the connector 17 and the other similar connectors are equipped with facilities for revertively signaling over a calling line in setting up a reverting call connection. In order to initiate the reverting signaling operation, the calling subscriber at the substation A restores the receiver provided at this substation to its supporting hook or cradle to open the loop circuit extending over the line 10 to the register sender 19. At the time the

loop circuit is opened at the calling substation, the switching relay R300 is operated so that the loop circuit is extended through the register selector 18 to the register sender 19 to include the winding of the line relay R700. Accordingly, the line relay R700 is deenergized to initiate certain relay operations which result in the application of ground potential directly to the connected trunk conductors 36c and 35c. The resulting increased energization of the marginal relay R230 causes this relay to operate. Upon operating, the relay R230 locks to ground through the contacts 231 and 241, and then opens its operating circuit at the contacts 236. At its contacts 234 and 235, the relay R230 closes the above-traced locking circuit for the relay R320 and then disconnects the incoming control conductor 268 from ground in the link 15, thereby to deenergize the cut-off relay of the line circuit 10a. At its contacts 237, the relay R230 opens the locking circuit for the unit relay R220 causing the latter relay to restore. At its contacts 233, the relay R230 completes a path including the resistor 263 and the contacts 411 and 422 for impressing negative battery potential upon the negative line wiper 471. The unit relay R220, upon restoring, opens its contacts 221 and 222 to disconnect the talking conductors of the line 10 from the talking conductors of the link 15. At its contacts 223, the relay R220 further interrupts the previously traced circuit for energizing the cut-off relay of the line circuit 10a in series with the relay R320 of the link. Following the operations just described, the connector 17 is conditioned to transmit ringing current over the line 10 for the purpose of energizing the ringer provided at the called substation E. During the ringing period and for a short period after the call is answered, the register sender 19 is held operated. More specifically, this register sender is, in the case under consideration, released under the control of a reverting call timing device incorporated in the timing equipment 31 a predetermined time interval after the call is answered at the called substation E. Incident to the release of the register sender 19 under the control of the reverting call timing device, the connected trunk conductors 36c and 35c are disconnected from ground in this sender to deenergize the switching relay R300 of the link 15 and to initiate the release of the register selector 18. When the switching relay R300 restores, it initiates the release of the link 15 in the exact manner explained above. The register selector 18 is also released in the manner previously explained when the connected trunk conductors 35c and 36c are disconnected from ground in the register sender 19. After a reverting call connection is set up between the two substations A and E, the line circuit 10a occupies a setting such that it is guarded against seizure on incoming calls to the line 10, and talking battery is supplied to the conductors of this line through the windings of the line relay conventionally embodied in the line circuit. This line circuit is restored to normal when the reverting call connection is released at both the calling and called substations.

Permanent lines

It will be understood from the preceding explanation that the link 15 may be seized over a line having a permanent calling condition thereon. This permanent calling condition may be due to a fault, such, for example, as a short circuit between the conductors of the line 10, or

may be due to carelessness on the part of one of the subscribers served by this line. Regardless of the cause, the link 15 may be seized over a line characterized by a permanent calling condition in the exact manner explained above with reference to the call originating at the substation A. Incident to the seizure of the link, the associated register selector 18 operates to seize an idle one of the register senders to which it has access, such, for example, as the register sender 19. Under the conditions stated, no dial pulse will be transmitted to the register sender 19 over the calling line. Accordingly, the sender is forcibly released under the control of the associated permanent timing device included in the timing equipment 31. Incident to the release of the register sender, the connected trunk conductors 36c and 35c are disconnected from ground to deenergize the line relay R520 of the register selector 18 and the switching relay R300 of the link 15. When the line relay R520 restores, it initiates the release of the register selector 18 in the exact manner explained above. The relay R300, upon restoring, closes its contacts 304 to again include the winding of the line relay R330 in the loop circuit established by way of the line having the calling condition thereon, and then opens its contacts 303 to interrupt the previously traced locking circuit for the relay R330. At its contacts 301 and 302, the relay R300 disconnects the trunk conductor 35a from the negative side of the calling loop circuit and reprepares the path for impressing ground potential upon this trunk conductor. Since at this time the relay R250 is operated in the link 15, the paths for impressing ground potential upon the trunk conductors 36a and 35d are held open at the contacts 257 and 255, thereby to insure that the line relays R700 and R520 will not be energized and reoperated after the register sender 19 and the register selector 18 are released. At its contacts 305, the relay R300 opens the operating circuit for the relay R260. At its contacts 306, the relay R300 deenergizes the two relays R360 and R410. The relay R410, upon restoring, closes its contacts 412 to complete the previously traced circuit for energizing the permanent signal lamp 265. The relay R360, upon restoring, opens its contacts 363 to interrupt the operating circuit for the relay R340. Following the release of the three relays R300, R360 and R410 no further operation of the relays embodied in the link 15 occurs until the permanent calling condition is cleared from the line to which the link is connected. In this regard it will be noted that the energization of the permanent signal lamp 265 serves to inform the exchange maintenance staff that the link 15 is being held over a line having a permanent calling condition thereon. When this condition is cleared, the loop circuit extending through the winding of the line relay R330 is opened and this relay restores to initiate the release of the link 15 in a manner which will be clearly apparent from the foregoing explanation.

Operation of the register sender 19

As indicated above, when the register selector 18 operates to seize the register sender 19, the calling loop circuit as extended to the link 15 from the line 10 is extended to the register sender 19 and the line relay R700 is energized therein. In operating, this relay closes its contacts 702 to complete an obvious circuit for energizing a slow-acting hold relay R710. At its con-

tacts 701, the relay R700 opens an incomplete circuit for energizing the pulsing relay R740.

The relay R710, upon operating, closes its contacts 711 further to prepare the operating circuit for the relay R740 and closes its contacts 712 to complete an obvious circuit for energizing the hold slave relay R600. At its contacts 713, the relay R710 opens a point in one of the operating circuits for the timing relay R620. At its contacts 714, the relay R710 opens a point in the paths over which ground potential may be impressed upon the sixth and ninth contacts of the contact set 953.

The hold slave relay R600, upon operating, closes its contacts 602 to complete an obvious multiple path for impressing ground potential upon the test conductor 36d of the trunk 36 in order to maintain the register sender 19 marked as busy in the bank contacts of the register selectors to which it is accessible. At its contacts 603, the relay R600 opens the circuit, individual to the illustrated register sender 19, over which the all-busy relay R580 is controlled from this sender. At its contacts 604, the relay R600 prepares the operating circuit for the timing relay R630. At its contacts 606, the relay R600 opens a point in another of the circuits for energizing the timing relay R620. At its contacts 607, the relay R600 completes a path including the resistor 635 and the contacts 627 for impressing ground potential upon the trunk conductor 36c, thereby to establish a locking circuit for the line relay R520 and to complete the operating circuit for the switching relay R300 in the manner previously explained. At its contacts 608, the relay R600 completes an obvious path for impressing ground potential upon the release conductor 605 thereby to prepare certain operating and locking circuits described with particularity hereinafter. At its contacts 609, the relay R600 completes an obvious path for impressing ground potential upon the start lead 600, thereby to initiate the operation of the timing devices included in the timing equipment 31 and the tone generating devices collectively and schematically illustrated at 32. At its contacts 601, the relay R600 connects the conductor 666 to ground, thereby to prepare additional operating and locking circuits which are fully described below. At its contacts 605, the relay R600 prepares a locking circuit for the timing relay R620 and completes a circuit for energizing the operating magnet 1107 of the digit counting switch 1100. The latter circuit extends from ground by way of the contacts 605 and 625, C661, the contacts 753 and 808, C872, and the winding of the magnet 1107 to battery.

When thus energized the magnet 1107 advances the wipers 1105 and 1106 one step from the illustrated normal positions thereof and closes its contacts 1107a to complete a circuit for energizing the lower winding of the control relay R800, this circuit extending from ground by way of the contacts 605 and 625, C661, the contacts 1107a, C871 and the lower winding of R800 to battery. A branch of this circuit extends through the resistor 749 and the winding of R750 to battery, but the current flow thereover is insufficient to cause the relay R750 to operate. At its contacts 1107b, the magnet 1107 opens a point in the operating circuit for the digit relay R150. When the wipers 1105 and 1106 are moved to engage their respective associated first contacts, a dial tone signaling circuit is prepared by the wiper 1106. The wiper 1106, when operated to engage

its associated first contacts, also functions to complete the prepared operating circuit for the control relay R820, this circuit extending from ground through the dial tone current generator and by way of the dial tone lead C1081, the wiper 1106 and its engaged first contacts, C875 and the upper winding of R820 to battery. The wiper 1105, in operating to engage its associated first contacts, prepares the operating circuits for the impulse storing relays of group No. 1, illustrated in Fig. 13 of the drawings. Incident to the off-normal movement of the wipers 1105 and 1106, the off-normal springs 1109 of the switching mechanism are moved into engagement to prepare one of the operating circuits for the timing relay R620.

The relay R800, upon operating, closes its contacts 801 to prepare the operating circuit for the first sequence relay R610. At its contacts 803, the relay R800 prepares the operating circuit for the second sequence relay R720. At its contacts 804, the relay R800 prepares the operating circuit for the third sequence relay R810. At its contacts 802, the relay R800 further prepares the above-mentioned dial tone signaling circuit. At its contacts 805, the relay R800 opens the path normally short-circuiting its upper winding, thereby to render itself fast to release. At its contacts 806, the relay R800 opens a point in the circuit for energizing the lower winding of the relay R820. At its contacts 807, the relay R800 completes a locking circuit for itself, this circuit extending from ground by way of the contacts 605 and 625, C661, the contacts 753 and 807 and the lower winding of R800 to battery. After completing this locking circuit, the relay R800 opens its contacts 808 to interrupt its operating circuit as traced above. At its contacts 808, the relay R800 also interrupts the above-traced circuit for energizing the operating magnet 1107 of the counting switch 1100. This magnet, in releasing, opens its contacts 1107a further to interrupt the operating circuit for the relay R800 and closes its contacts 1107b to reprepare the operating circuit for the digit relay R150.

The control relay R820, upon operating, opens its contacts 821 to interrupt the available but incomplete circuits for transmitting ring-back tone and busy signaling currents over the calling end 50 of the connection. At its contacts 823, the relay R820 opens a point in the operating circuit for the send alarm relay R830. At its contacts 824, the relay R820 short-circuits the contacts of the send alarm key 705. At its contacts 825, the relay R820 prepares another point in the operating circuit for the digit relay R150. At its contacts 826, the relay R820 prepares a locking circuit for itself. At its contacts 827, the relay R820 prepares a circuit for transmitting current 60 pulses to the impulse storing relays illustrated in Figs. 13, 14 and 15 of the drawings. At its contacts 828, the relay R820 opens a point in one of the operating circuits for the timing relay R620 and one of the holding circuits for the hold slave relay R600. At its contacts 829, the relay R820 opens a point in the path for connecting the control conductor 36c of the trunk 36 directly to ground.

At its contacts 822, the relay R820 also completes the above-mentioned dial tone signaling circuit, this circuit extending from the ungrounded terminal of the dial tone generator provided in the tone generating equipment 32 by way of the dial tone lead C1081, the wiper 1106 and its engaged first contacts, C875, the contacts 75 and the upper winding of R820 to battery.

892 and 822, the condenser 747, the contacts 621, the negative trunk conductor 36a, the wiper 557, the contacts 532, the negative trunk conductor 35a, the contacts 301 and the negative side of the loop circuit extending to the calling substation. From this point the dial tone signaling current is passed through the receiver provided at the calling substation and is returned to the grounded terminal of the dial tone generator over the positive side of the calling loop circuit. The resulting signal produced by the receiver provided at the calling substation, indicates to the calling subscriber that the dialing operation may be started.

Pulse receiving and storing

During the dialing operation, the line relay R700 operates to control the two lock pulsing relays R730 and R740 and these two relays function to repeat the received impulses to the storing relays illustrated in Figs. 13, 14 and 15 of the drawings. It is generally noted that the No. 1 group of storing relays, illustrated in Fig. 12 of the drawings, is operative to register the numerical values of the first, fourth and seventh digits transmitted to the register sender during a directory number dialing operation; the No. 2 group of storing relays, illustrated in Fig. 13 of the drawings, is operative to register the numerical values of the second, fifth and eighth digits transmitted to the register sender during a directory number dialing operation; and the No. 3 group of storing relays, shown in Fig. 15 of the drawings, is operative to register the numerical values of the third, sixth and ninth digits transmitted to the register sender during a directory number dialing operation. It is also noted that the digit counting switch 1100 has the function of directing the impulses of the different digits into the appropriate storing relay groups.

More specifically considered, when the line relay R700 releases during the open-circuit period of the first impulse transmitted to the register sender from the calling substation, it opens its contacts 702 to interrupt the operating circuit for the slow-acting hold relay R710 and closes its contacts 701 to complete the prepared operating circuit for the pulsing relay R740. The latter circuit extends from ground by way of the contacts 701, 711 and 734, and the winding of R740 to battery. In operating, the relay R740 locks to ground over a path including the contacts 734, 711 and 742. At its contacts 743, the relay R740 completes an obvious operating circuit for the pulsing relay R730. At its contacts 744, the relay R740 completes an obvious locking circuit for the hold relay R710. At its contacts 745, the relay R740 opens the path normally short-circuiting the condenser 748. At its contacts 746, the relay R740 completes the prepared circuit for charging the condenser 748 in series with the upper winding of the first relay R1300 in the No. 1 group of storing relays. This charging circuit extends from the grounded conductor 666 by way of the chain-connected contacts 1341, 1331, 1321, 1311 and 1301, the upper winding of R1300, the SP1 lead, the wiper 1105 and its engaged first contacts, C876, the contacts 827, 736 and 746 and the condenser 748 to the negative terminal of the exchange battery. The magnitude of the charging current traversing this circuit is such that the relay R1300 closes its preliminary make contacts 1303 to complete a locking circuit for itself. This locking circuit extends from the grounded conductor 666 by way

- of the contacts 1612, 1315 and 1303, and the lower winding of R1300 to battery. When thus fully energized, the relay R1300 opens its contacts 1301 to interrupt the charging circuit as initially completed through its own upper winding, and closes its contacts 1302 to include the upper winding of the second storing relay R1310 in this circuit. It is noted, however, that by the time the contacts 1302 are closed to include the upper winding of the second storing relay R1310 in the charging circuit, the condenser 748 is substantially fully charged so that the current flow through the upper winding of the second storing relay R1310 is negligible. Thus the second storing relay R1310 is prevented from operating during the condenser charging interval which is utilized to produce the operation of the first storing relay R1300. In operating, the relay R1300 also opens its contacts 1305 to interrupt the available but incomplete locking circuit for the fifth storing relay R1340. At its contacts 1304, the relay R1300 completes a path for impressing ground potential upon the SH1 lead, thereby to prepare circuits for energizing the first register sequence relay R610 and the operating magnet 957 of the outgoing digit counting switch 950.
- The pulsing relay R740, upon operating at the beginning of the open-circuit period of the first impulse transmitted to the register sender, also closes its contacts 741 to complete the prepared operating circuit for the slow-acting digit relay R750, this circuit extending from ground by way of the contacts 605 and 625, C661, the contacts 1107b, C762, the contacts 741 and 825, and the winding of R750 to battery. It will be noted that a parallel circuit extending through the resistor 749 is completed at the contacts 741 for energizing the lower winding of the control relay R800. The resistance value of the resistor 749 is such, however, that the relay R800 is not prevented from releasing when its principal holding circuit is broken. The digit relay R750, upon operating, opens its contacts 751 to interrupt the prepared circuit for energizing the operating magnet 957 of the counting switch 950. At its contacts 752, the relay R750 opens a point in one of the available locking circuits for the timing relay R630. At its contacts 753, the relay R750 interrupts the previously traced locking circuit for the control relay R800, and opens a point in the previously traced circuit for energizing the operating magnet 1107 of the counting switch 1100. The relay R800 now restores. At its contacts 801, this relay opens the prepared operating circuit for the sequence relay R610, thereby to prevent the latter relay from operating in response to the operation of the storing relay R1300 in the manner pointed out above. At its contacts 803, the relay R800 opens the prepared operating circuit for the second sequence relay R720. At its contacts 804, the relay R800 opens the prepared operating circuit for the third sequence relay R810. At its contacts 802, the relay R800 interrupts the previously traced dial tone signaling circuit, whereby the dial tone signal being reproduced at the calling substation is terminated. At its contacts 805, the relay R800 re-completes the path for short-circuiting its upper winding, thereby to render itself slow-to-operate. At its contacts 806, the relay R800 completes the prepared holding circuit for the control relay R820, this circuit extending from the grounded release conductor 665 by way of the contacts 826 and 806, and the lower winding of R820 to battery. At its contacts 807, the relay R800 opens

another point in its own locking circuit. At its contacts 808, the relay R800 reprepares its own operating circuit and the circuit for energizing the operating magnet 1107 of the counting switch 1100.

While the digit relay R750 is operating to perform the functions just described, the pulsing relay R730 operates and locks to ground over a path including the contacts 733, 711 and 742. A branch of this locking circuit also extends to ground through the contacts 701 of the line relay R700. At its contacts 734, the relay R730 opens the operating and locking circuits for the relay R740. At its contacts 736, the relay R730 interrupts the above-traced circuit for charging the condenser 748 in series with the operating winding of the storing relays. At its contacts 735, the relay R730 completes a path including the resistor 738 and the contacts 746 for dissipating the accumulated charge on the condenser 748. At its contacts 732, the relay R730 completes an obvious multiple circuit for energizing the digit relay R750. At its contacts 731, the relay R730 completes a priming circuit for the line relay R700, this circuit extending from ground by way of the resistor 731, the contacts 731 and the winding of R700 to battery. The current flow over this circuit is insufficient to cause the reoperation of the relay R700, but serves to render this relay exceedingly fast to operate when the loop circuit is recompleted at the calling substation at the end of the open-circuit period of the impulse.

When deenergized in response to the operation of the relay R730, the pulsing relay R740 restores. At its contacts 741, the relay R740 opens the operating circuit for the digit relay R750. At its contacts 742, the relay R740 opens another point in its own locking circuit and interrupts one of the locking circuits for the pulsing relay R730. At its contacts 743, the relay R740 opens the operating circuit for the relay R730. At its contacts 744, the relay R740 opens the locking circuit for the hold relay R710. At its contacts 745, the relay R740 completes an obvious alternative path for discharging the condenser 748 through the resistor 738. At its contacts 746, the relay R740 opens another point in the condenser charging circuit and interrupts the initially completed condenser discharge path.

As indicated above, the line relay R700 reoperates when the loop circuit is completed at the end of the open-circuit period of the impulse. In reoperating, this relay opens its contacts 701 to deenergize the pulsing relay R730, and recloses its contacts 702 to again complete the operating circuit for the hold relay R710. When thus deenergized, the relay R730 opens its contacts 731 to interrupt the priming circuit for the line relay R700 and, at its contacts 732, interrupts the circuit for energizing the digit relay R750. At its contacts 733, the relay R730 opens another point in the common portion of its two available locking circuits. At its contacts 734, the relay R730 reprepares the operating and locking circuits for the relay R740. At its contacts 735, the relay R730 opens another point in the initially completed path for discharging the condenser 748. At its contacts 736, the relay R730 reprepares the circuit for charging the condenser 748 in series with the operating windings of the impulse storing relays. Following the release of the relay R730, one cycle of operation of this relay and the two relays R740 and R700 to repeat a received impulse to the storing relays, is completed. During

the transmission of each additional impulse to the register sender 19 these three relays interact in the exact manner just explained. From this explanation it will be noted that a current pulse is transmitted to the digit relay R750 during that portion of each impulse when either the relay R730 or the relay R740 is operated. It will also be noted that the circuit for energizing the hold relay R710 is opened only during that period which separates the release of the pulsing relay R740 from the reoperation of the line relay R700. Due to the slow-to-release characteristics thereof, the hold relay R710 remains operated throughout impulsion and the digit relay R750 remains operated throughout each series of impulses transmitted to the register sender from the calling substation.

From the foregoing explanation, it will be understood that the condenser 748 is charged in series with the upper winding of the second storing relay R1310 in the No. 1 group during the transmission of the second impulse to the register sender from the calling substation. In operating, the relay R1310 locks to the grounded conductor 666 over a path including its preliminary make contacts 1313 and the contacts 1325 and 1312. At its contacts 1311 and 1312, the relay R1310 rearranges the condenser charging circuit to include the upper winding of the third storing relay R1320 instead of its own upper winding. At its contacts 1314, the relay R1310 completes an obvious multiple path for impressing ground potential upon the SH1 lead. At its contacts 1315, the relay R1310 opens the established locking circuit for the first storing relay R1300, causing the latter relay to restore.

The third, fourth and fifth impulses transmitted to the register sender 19 from the calling substation cause the operation of the third, fourth and fifth storing relays R1320, R1330 and R1340, in a manner which will be clearly apparent from the above explanation. It will be understood that each of these relays, in operating, releases the preceding storing relay, rearranges the condenser charging circuit to include the operating winding of the next succeeding storing relay, and closes a multiple path for impressing ground potential upon the SH1 lead. The fifth storing relay R1340, upon operating, also closes its contacts 1347 to prepare the operating circuit for the relay R1350. At its contacts 1342, the relay R1340 also rearranges the condenser charging circuit to include the upper winding of the first storing relay R1300.

If the first digit transmitted to the register sender 19 from the calling substation comprises less than five impulses, the relay R1350 is not operated and that storing relay which corresponds to the numerical value of the digit is left operated at the end of the digit. For example, if the digit comprises three impulses, the third storing relay R1320 remains in its operated position at the end of the digit. On the other hand, if the first digit transmitted to the register sender 19 comprises more than five impulses the relay R1350 and one of the five storing relays of the No. 1 group are operated at the end of the digit. Thus during the transmission of the sixth impulse of a first digit, the first storing relay R1300 reoperates and locks to the grounded conductor 666 through its contacts 1303. In this case the upper winding of the relay R1300 is energized in series with the condenser 748 over a circuit which extends from the grounded conductor 666 by way of the contacts 1342 and 1352.

to the SP1 pulsing lead. At its contacts 1303, the relay R1300 also completes the prepared operating circuit for the relay R1350, this circuit extending from the grounded conductor 666 by way of the contacts 1612, 1315, 1303, 1347 and 1351, and the winding of R1350 to battery. In operating, the relay R1350 locks to the grounded lead 666 through its preliminary make contacts 1353 and the contacts 1612. After this locking circuit is completed, the relay R1350 opens its contacts 1351 to interrupt its operating circuit, and opens its contacts 1352 to interrupt the condenser charging circuit as extended through the upper winding of the relay R1200. From this point on, the remaining impulses of the digit are counted by the second to fifth storing relays of the No. 1 group in the exact manner explained above. It will be recalled that if the digit comprises less than five impulses, only one of the five storing relays is operated at the end of the digit. Accordingly, the operating circuit for the first digit connect relay R1220 is prepared at the contacts 1355 of the relay R1350 at the end of the digit. On the other hand, if the digit comprises more than five impulses, the relay R1350 and one of the five storing relays are operated at the end of the digit. With the relay R1350 in its operated position, the operating circuit for the connect relay R1220 is held open at the contacts 1355, and the operating circuit for the connect relay R1230 is prepared at the contacts 1354.

At the end of the first digit, the operating circuit for the digit relay R750 is held open at the contacts 732 and 741 for an interval sufficient to permit this relay to release. Upon restoring, the relay R750 closes its contacts 752 to reprepare the locking circuit for the relay R630. At its contacts 753, the relay R750 completes the previously traced circuit for energizing the operating magnet 1107 of the counting switch 1100. At its contacts 751, the relay R750 completes the prepared circuit for energizing the operating magnet 957 of the counting switch 950, this circuit extending from the SH1 lead, which is now connected to ground through the make contacts of the operated storing relay in the No. 1 group, by way of the contacts 611, 902, 844, 751, 904 and 845, and the winding of the magnet 957 to battery.

The magnet 1107, upon operating, steps the wipers 1105 and 1106 into engagement with their respective associated second contacts. At its contacts 1107b, the magnet 1107 opens another point in the operating circuit for the digit relay R750. At its contacts 1107a, the magnet 1107 reprepares the previously traced operating circuit for the control relay R800. When the wiper 1105 is stepped out of engagement with its associated first contacts, the previously traced circuit for charging the condenser 748 in series with the operating windings of the storing relays in the No. 1 group is broken. When this wiper is operated to engage its associated second contacts, a circuit including the SP2 lead is prepared for charging the condenser 748 in series with the operating windings of the storing relays R1400, R1410, etc., forming the No. 2 storing relay group. As the wiper 1106 is moved out of engagement with its associated first contacts, another point is opened in the previously traced dial tone signaling circuit and in the operating circuit for the control relay R820. As this wiper is moved into engagement with its associated second contacts, an alternative circuit for ener-

gizing the upper winding of the control relay R820 is completed, this circuit extending from the grounded release conductor 665 by way of the contacts 826, C873, the contacts 1063, the marking lead 1071, the wiper 1106 and its engaged second contacts, C875, and the upper winding of R820 to battery. Thus the control relay R820 is prevented from releasing in response to the reoperation of the control relay R800.

10 The magnet 957, upon operating, steps the wipers 955 and 956 from the illustrated normal positions thereof into engagement with their respective associated first contacts. At its contacts 957b, the magnet 957 opens a point in the locking circuit for the timing relay R630. At its contacts 957a, the magnet 957 closes a path through the contacts 841 for impressing ground potential upon the SM1 lead, thereby to complete the prepared operating circuit for one of the two first digit connect relays R1220 and R1230. More specifically, if the first digit transmitted to the register sender 19 comprises less than five impulses, such that the relay R1350 is not operated, the operating circuit for the relay R1220 is completed, this circuit extending from the grounded SM1 lead by way of the contacts 1355 and the winding of R1220 to battery. On the other hand, if the first digit transmitted to the register sender 19 comprises more than five impulses, the operating circuit for the first digit connect relay R1230 is completed, this circuit extending from the grounded SM1 lead by way of the contacts 1354 and the winding of R1230 to battery. The operations resulting from the energization of one of the two connect relays R1220 and R1230 are described below. When the wiper 955 is operated to engage its associated first contacts a circuit is prepared for energizing the impulse sending relays R1730 and R1740. When the wiper 956 is operated to engage its associated first contacts, a circuit is prepared for energizing the connect relay R1610. Incident to the off-normal movement of the wipers 955 and 956, the off-normal springs 959 are moved into engagement to prepare the operating circuit for the timing relay R620.

50 The relay R800, upon reoperating, closes its contacts 801 to complete the prepared circuit for energizing the sequence relay R610, this circuit extending from the grounded conductor 666 by way of the contacts 1612, the operated make contacts 1304, 1314, etc., of the storing relay which is operated in the No. 1 group, the SH1 lead, the contacts 801, and the winding of R610 to battery. At its contacts 802, the relay R800 reprepares the above-traced dial tone signaling circuit. At its contacts 803 and 804, the relay R800 reprepares the operating circuits for the two sequence relays R720 and R810. At its contacts 805, the relay R800 opens the path short-circuiting its upper winding. At its contacts 806, the relay R800 opens one of the established locking circuits for the control relay R820. At its contacts 807, the relay R800 completes the previously traced locking circuit for itself. At its contacts 808, the relay R800 deenergizes the operating magnet 1107 of the digit counting switch 1100. The magnet 1107 now restores and opens its contacts 1107a to interrupt the operating circuit for the control relay R800. At its contacts 1107b, the magnet 1107 reprepares the operating circuit for the digit relay R750.

55 Following the operations just described, the register sender is conditioned to receive and store the impulses of the second digit dialed at

60

65

70

75

the calling substation. In this regard it is pointed out above that with the wipers of the counting switch 1100 operated to engage their associated second contacts, the impulse storing relays of the No. 2 group illustrated in Fig. 14 of the drawings are connected to be controlled by the pulsing relays R730 and R740. The manner in which these two relays interact with the line relay R700 in response to the impulses of the second digit is exactly the same as set forth above, it being noted in this regard that the operating circuit for the digit relay R750 is completed at the contacts 741 at the beginning of the open-circuit period of the first impulse of the second digit transmitted to the register sender. In this case the charging circuit for the condenser 748 is successively extended to include the operating windings of the five impulse storing relays R1400, R1410, R1420, R1430 and R1440 as the impulses are received. More specifically, this circuit as initially completed by the pulsing relay R740, extends from the grounded conductor 666 by way of the chain-connected break contacts 1441, 1441, 1401, etc., of the five storing relays, the upper winding of R1400, the SP2 lead, the wiper 1105 and its engaged second contacts, C876, the contacts 827, 736 and 746, and the condenser 748 to the negative terminal of the exchange battery. When thus energized, the relay R1400 locks to the grounded conductor 666 over a path including its preliminary make contacts 1403, and the additional contacts 1415 and 1622. After this locking circuit is completed, the relay R1400 opens its contacts 1401 to interrupt the condenser charging circuit, and closes its contacts 1402 to extend the charging circuit through the operating winding of the second storing relay R1410. At its contacts 1404, the relay R1400 completes a path including the contacts 1622 for impressing ground potential upon the SH2 lead. Since the six relays of the No. 2 storing group, illustrated in Fig. 14 of the drawings, are identical in arrangement with the relays forming the No. 1 storing group, the manner in which these relays are successively operated in response to the received second and succeeding impulses of the second digit will be clearly apparent from the above explanation with reference to the operation of the relays forming the No. 1 group. In this regard it will be understood that if the second digit comprises less than five impulses, that storing relay which corresponds to the numerical value of the digit will remain operated at the end of the digit. On the other hand, if the received second digit comprises more than five impulses the relay R1450 and one of the five storing relays will be operated at the end of the digit.

The digit relay R750, upon operating at the beginning of the second digit, opens its contacts 751 to interrupt the previously traced operating circuit for the magnet 857. At its contacts 152, the relay R750 opens a point in the locking circuit for the timing relay R630. At its contacts 753, the relay R750 deenergizes the control relay R800. The relay R800, upon restoring, opens its contacts 801 to interrupt the operating circuit for the sequence relay R610. At its contacts 803 and 804, the relay R800 opens the prepared operating circuits for the two other sequence relays R720 and R810. At its contacts 806, the relay R800 completes an obvious multiple locking circuit for the control relay R820. At its contacts 807, the relay R800 opens another point in its own locking

circuit. At its contacts 808, the relay R800 reprepares the circuit for energizing the operating magnet 1107 of the counting switch 1100.

At the end of the second digit, the two pulsing relays R730 and R740 are held deenergized for a time interval sufficient to cause the release of the digit relay R750. This relay, in restoring, closes its contacts 153 to recomplete the circuit for energizing the operating magnet 1107 of the counting switch 1100. Upon operating, the magnet 1107 steps the wipers 1105 and 1106 out of engagement with their respective associated second contacts and into engagement with their respective associated third contacts. At its contacts 1107b, the magnet 1107 opens another point in the incomplete operating circuit for the digit relay R750. At its contacts 1107a, the magnet 1107 recloses the operating circuit for the control relay R800. When the wiper 1105 is stepped out of engagement with its associated second contacts the above-traced circuit for charging the condenser 748 in series with the operating windings of the storing relays in the No. 2 group is broken. Incident to the movement of this wiper to engage its associated third contacts, a circuit including the SP2 lead is prepared for charging the condenser 748 in series with the operating windings of the storing relays in the No. 3 group. When the wiper 1106 is operated out of engagement with its associated second contacts and into engagement with its associated third contacts, the locking circuit for the control relay R820 is rearranged to include the contacts 1053 and the marking lead 1072 rather than the contacts 1063 and the marking lead 1071.

The control relay R800, upon operating in response to the operation of the magnet 1107 at the end of the second digit, closes its contacts 803 to complete the prepared operating circuit 40 for the second sequence relay R720, this circuit extending from the grounded conductor 666 by way of the contacts 1622, the operated make contacts 1404, 1414, etc. of the storing relay which is operated in the No. 2 group, the SH2 lead, the contacts 803, and the winding of R720 to battery. When thus energized the relay R720 operates to perform the functions described below. In reoperating, the control relay R800 also locks to ground through its contacts 807, and opens its contacts 808 to deenergize the magnet 1107. This magnet, upon restoring, opens its contacts 1107a to interrupt the operating circuit for the relay R800, and closes its contacts 1107b to reprepare the operating circuit for the digit relay R750.

55 The impulses of the third digit transmitted to the register sender are repeated by the pulsing relays R730 and R740 to the storing relays of the No. 3 group, illustrated in Fig. 15 of the drawings. In this case the charging circuit for the condenser 748, as initially completed, extends from the grounded conductor 666 through the chain-connected upper break contacts of the five storing relays R1500, R1510, R1520, R1530 and R1540, the upper winding of R1500, the SP3 lead, the wiper 1105 and its engaged third contacts, C876, the contacts 827, 736 and 746, and the condenser 748 to the negative terminal of the exchange battery. This charging circuit is obviously rearranged successively to include the operating windings of the succeeding storing relays of the No. 3 group, as the impulses of the third digit are received. Each of these relays, in operating, locks to the grounded lead 666 through the contacts 1632, opens the locking circuit for the preceding storing relay, and closes its lower make

contacts to complete a circuit through the contacts 1602 for impressing ground potential upon the SH3 lead, thereby to prepare the operating circuit for the third sequence relay R810. As explained above with reference to the operation of the No. 1 storing relay group, if the third digit comprises less than five impulses, that storing relay which corresponds to the numerical value of the digit is left operated at the end of the digit. On the other hand, if the digit comprises more than five impulses, one of the storing relays and the relay R1550 will be energized at the end of the digit.

As will be apparent from the preceding explanation, the digit relay R750 operates at the beginning of the third digit and opens its contacts 753 to deenergize the control relay R800. The latter relay, in releasing, closes its contacts 803 to reprepare the circuit for energizing the operating magnet 1107 of the digit counting switch 1100. This circuit is completed at the contacts 753 when the digit relay R750 restores at the end of the third digit. Incident to the operation of the magnet 1107, the wipers 1105 and 1106 are stepped to engage their respective associated fourth contacts, and the contacts 1107a are closed to recomplete the operating circuit for the control relay R800. In this case the relay R800, upon operating, closes its contacts 804 to complete the prepared operating circuit for the third sequence relay R810, this circuit extending from the grounded SH3 lead by way of the contacts 804 and the winding of R810 to battery. In operating, the relay R810 performs the functions described below.

From the preceding explanation it will be understood that the counting switch 1100 is operated one step at the end of each digit transmitted to the register sender from the calling substation. It will also be apparent from a consideration of the wiring of the three SP leads to the upper, outer row of contacts 1101, that the charging circuit for the condenser 748 is rearranged at the end of each digit so that the impulses of the next succeeding digit are directed to the next group of storing relays. As the wiper 1106 is successively stepped to different positions, the holding circuit for the control relay R820 is rearranged to include different sets of the break contacts 1063, 1053, 1043, etc., respectively controlled by the digit marking relays illustrated in Figs. 9 and 10 of the drawings.

Impulse transmission from the register sender 19 with revertive control of the sending relays

In considering the manner in which the register sender functions to retransmit the digits registered in the storing relay groups, it may first be assumed that the destination of the call under consideration is the substation B, such that the impulse sending relays of the register sender will be revertively controlled at all times during the extension of the connection, and further that this substation is designated by the directory number "45678." In this case, the fourth storing relay R1330 is left operated in the No. 1 storing relay group at the end of the first digit, the fifth relay R1440 is left operated in the No. 2 storing relay group at the end of the second digit, the relays R1500 and R1550 are left operated in the No. 3 storing relay group at the end of the third digit, the relays R1310 and R1350 are left operated in the No. 1 storing relay group at the end of the fourth digit, and the relays R1420 and R1450 are left operated in the No. 2

storing relay group at the end of the fifth digit. In this regard it will be apparent from the following explanation that the first digit is transmitted from the register sender 19 and the No. 5 1 group of storing relays is conditioned to receive and store the impulses of the fourth digit, prior to the actual transmission of the fourth digit from the calling substation. In the case assumed, the first digit is also utilized to indicate to the register sender the number of digits which are to be received during the directory number dialing operation. To this end, the terminal 4 of terminal row 3 is cross-connected to terminal 5 of terminal row 1 at the cross-connecting frame 11 illustrated in Fig. 12 of the drawings.

The actual transmission of the first digit to the selector portion of the link 15 is started immediately after the impulses of this digit have been transmitted to the register sender. Thus, 20 when the operating magnet 957 operates at the end of the first digit to complete the operating circuit for the connect relay R1220 in the manner explained above, the latter relay closes its contacts 1224 to complete the prepared operating circuit for the digit marking relay R1020, this circuit extending from the grounded conductor 666 by way of the contacts 1336 of the operated storing relay R1330, the contacts 1224, the strap between the terminal 4 of terminal row 3 and terminal 5 of terminal row 1, the digit marking lead 5D, the contacts 1021, and the winding of R1020 to battery. When thus energized, the relay R1020 first locks to the grounded release conductor 665 through its preliminary make contacts 30 1025, and then opens its contacts 1021 to interrupt its operating circuit. At its contacts 1023, the relay R1020 opens the path, including the contacts 813 and the conductor C814, over which ground potential is normally impressed upon the 40 fifth marking lead 1075, thereby to condition the control relay R820 to be released after the five digits of the directory number have been received and stored in the three storing relay groups. At its contacts 1022, the relay R1020 connects the 45 marking lead 965 to ground over a path including the contacts 1025 and the release conductor 665, thereby to set up a circuit for releasing the register sender after the five digits of the directory number have been transmitted therefrom. At its contacts 1024, the relay R1020 completes a circuit including the grounded release conductor 665 for energizing the relay R840.

In operating, the relay R840 locks to the grounded release conductor 665 through its contacts 849'. At its contacts 849 and 849', the relay R840 completes an obvious path for impressing ground potential upon the tenth contact of the contact set 951. At its contacts 841, the relay R840 opens the previously traced operating circuit for the operated connect relay R1220, causing the latter relay to restore. At its contacts 842, the relay R840 prepares the operating circuit for the release relay R1720. At its contacts 843, the relay R840 prepares the previously mentioned circuit for energizing the pulsing relay R460 of the finder-selector-link 15 and the pulsing relays of switches succeeding this link in the switch train, in series with the relay R1760. At its contacts 844 and 845, the relay R840 opens the 65 previously traced operating circuit for the magnet 957. At its contacts 846, the relay R840 prepares an alternative circuit for energizing the operating magnet 957 of the digit counting switch 950. At its contacts 847, the relay R840 prepares 70 a point in the common portion of the ring-back

and busy signaling circuits. At its contacts 840, the relay R840 opens an available alternative operating circuit for itself.

Shortly before the relay R840 operates, the first sequence relay R610 is energized in the manner explained above. In operating, this relay locks to the grounded SH1 lead through its contacts 612. At its contacts 611, the relay R610 opens the circuit for energizing the operating magnet 957 of the counting switch 950. At its contacts 614, the relay R610 interrupts the path including the conductor 663, over which ground potential is normally impressed upon the marking leads 1073 and 1076 extending to the fourth and seventh contacts of the contact set 1103 in the digit counting switch 1100. At its contacts 613, the relay R610 completes the prepared operating circuit for the connect relay R1610, this circuit extending from ground by way of the contacts 608 and 613, the wiper 956 and its associated first contacts, the OS1 lead, the contacts 1711, and the winding of R1610 to battery.

The relay R1610, upon operating, first closes its preliminary make contacts 1611 and then opens its contacts 1612, thereby to include the break contacts 1718' in the locking circuit for the operated storing relay R1330 of the No. 1 storing group and in the path over which ground potential is impressed upon the SH1 lead. The two relays R1330 and R610 are thus rendered releasable under the control of the relay R1710.

At its contacts 1616 to 1619, inclusive, the relay R1610 connects the four lowermost marking leads of the No. 1 group to the terminals of the four counting relays R1630, R1640, R1650 and R1660, over the conductors 1691, 1692, 1693 and 1694, respectively, and in so doing completes a circuit for energizing the lower winding of the relay R1630. This circuit extends from the grounded conductor 666 by way of the contacts 1336 and 1616, the conductor 1691 and the lower winding of R1630 to battery. Since the storing relay R1330 is the only operated relay of the No. 1 group, it will be understood that only the first counting relay R1630 is operated. In operating, the relay R1610 also closes its contacts 1614 to complete the prepared operating circuit for the relay R1680, this circuit extending from the grounded conductor 666 by way of the contacts 1356, 1614 and 1716, and the winding of R1680 to battery. At its contacts 1613, the relay R1610 opens the out-pulsing circuit over which battery pulses are first transmitted to the pulsing relay R460 of the link 15 and later to the pulsing relays of the succeeding switches in the train.

The impulse counting relay R1630, upon operating, locks to ground over a path including its preliminary make contacts 1633, the contacts 1645 and 1723, and the grounded conductor 666. After completing this circuit, the relay R1630 opens its contacts 1631 to interrupt the available circuit for energizing its own upper winding, and closes its contacts 1632 to prepare a circuit for energizing the upper winding of the succeeding counting relay R1640. At its contacts 1635, the relay R1630 opens a point in the locking circuit for the fifth counting relay R1670. At its contacts 1634, the relay R1630 completes the prepared operating circuit for the start sending relay R1710, this circuit extending from the grounded conductor 666 by way of the contacts 1723, 1634, 1742 and 1714, and the winding of R1710 to battery.

The relay R1680, upon operating, locks to ground over a path including its preliminary make

contacts 1684, the contacts 1723, and the grounded conductor 666. At its contacts 1682, the relay R1680 opens a point in one of the available circuits for energizing the upper winding of the counting relay R1630. At its contacts 1681, the relay R1680 opens a point in an incomplete alternative operating circuit for itself. At its contacts 1683, the relay R1680 prepares the operating circuit for the relays R1730 and R1740.

The start sending relay R1710, upon operating, locks to ground through its preliminary make contacts 1713, the contacts 1722, and the grounded conductor 666, and then opens its contacts 1714 to interrupt its operating circuit. At its contacts 1712, the relay R1710 prepares locking circuits for the two relays R1720 and R1740. At its contacts 1711, the relay R1710 prepares one of the operating circuits for the relays R1730 and R1740. At its contacts 1715, the relay R1710 prepares the previously mentioned alternative circuit for energizing the operating magnet 957 of the digit counting switch 950. At its contacts 1716, the relay R1710 interrupts the operating circuit for the relay R1680. At its contacts 1717, the relay R1700 deenergizes the connect relay R1710. At its contacts 1716' and 1718, the relay R1710 opens points in the respective operating circuits for the two connect relays R1600 and R1620. At its contacts 1718', the relay R1710 opens the previously traced locking circuits for the operated storing relay R1330 and the first sequence relay R610, causing both of these relays to restore. At its contacts 1719, the relay R1710 further prepares the out-pulsing circuit over which the relay R1760 is controlled in series with the pulsing relay R460 of the link 15.

It will be noted from the above explanation that following the operation of the relay R1710 the digit information stored in the No. 1 relay group is transferred to the impulse counting relays illustrated in Fig. 16 of the drawings, and that after this transfer operation is effected the three relays R1610, R1330 and R610 are deenergized and restore. It will also be noted that the first digit connect relay R1220 is deenergized and releases in response to the operation of the start sending relay R840. The release of the two relays R1220 and R1330 is without effect. The relay R610, upon restoring, opens its contacts 612 further to interrupt its own locking circuit, and closes its contacts 611 to reprepare the initially traced circuit for energizing the operating magnet 957 of the counting switch 950. At its contacts 613, the relay R610 opens another point in the previously traced operating circuit for the connect relay R1610. At its contacts 614, the relay R610 recompletes the path for impressing ground potential upon the fourth and seventh contacts of the contact set 1103 in the counting switch 1100.

The relay R1610, upon restoring, closes its contacts 1612 to reprepare the path for impressing ground potential upon the SH1 lead and the previously traced locking circuits for the storing relays of the No. 1 group. At its contacts 1614, the relay R1610 opens another point in the operating circuit for the relay R1680. At its contacts 1615, the relay R1610 opens another point in the operating circuit for the relay R1710. At its contacts 1616 to 1619, inclusive, the relay R1610 disconnects the marking leads of the No. 1 group from the terminals of the four storing relays R1630, R1640, R1650 and R1660. At its contacts 1613, the relay R1610 completes the previously mentioned circuit for energizing the pulsing relay

R1760 in series with the pulsing relay R460 of the link 15, this circuit extending from ground through the off-normal springs 471 and 478 by way of the winding of R460, the contacts 451 and 362, the trunk conductor 35b, the contacts 531, the wiper 556, the conductor 36b, the contacts 843 and 851, the out-pulsing lead OP, the contacts 1702, 1719, 1623, 1613, 1609, 1724, 1733 and 1754, and the winding of R1760 to battery. When thus energized, the relay R1760 locks through its contacts 1762 to the grounded out-pulsing lead OP over a path from which the contacts 1733 and 1754 are excluded. At its contacts 1761, the relay R1760 completes an obvious circuit for energizing the relay R1750.

The relay R1750, upon operating, opens its contacts 1754 to interrupt the operating circuit for the relay R1760. At its contacts 1755, the relay R1750 opens a path for directly transmitting impulses over the out-pulsing lead OP. At its contacts 1753, the relay R1750 opens a point in the operating circuit for the relay R1740. At its contacts 1751, the relay R1750 opens the normally closed low resistance discharge path for the condenser 1756. At its contacts 1752, the relay R1750 completes the prepared circuit for charging the condenser 1756 in series with the upper or operating winding of the second impulse counting relay R1640. This circuit extends from the grounded conductor 666 by way of the chain-connected contacts 1671, 1661, 1651, 1641 and 1632, the upper winding of R1640, the contacts 1731 and 1752, and the condenser 1756 to the negative terminal of the exchange battery. The charging current initially traversing this circuit is sufficient to cause the operation of the relay R1640. This relay, in operating, first locks to ground over a path including its preliminary make contacts 1643, the contacts 1655 and 1723, and the conductor 666. After this locking circuit is completed, the relay R1640 opens its contacts 1641 to exclude its upper winding from the condenser charging circuit, and closes its contacts 1642 to include the upper winding of the relay R1650 in the condenser charging circuit. It is noted, however, that by the time the relay R1640 is fully operated the condenser 1756 is substantially fully charged so that the current flow through the upper winding of the third counting relay R1650 is negligible. Accordingly, this counting relay R1650 is prevented from operating during the condenser charging interval under consideration. At its contacts 1645, the relay R1640 interrupts the above-traced locking circuit for the relay R1730, causing the latter relay to restore. At its contacts 1644, the relay R1640 prepares a multiple circuit for energizing the relay R1710.

The pulsing relay R1760 remains operated until the reverting pulse relay R450 of the link operates in the manner previously described. When the latter relay operates, the holding circuit for the relay R1760 is opened at the contacts 451. In releasing, the relay R1760 opens its contacts 1762 further to interrupt its locking circuit, and, at its contacts 1761, opens the operating circuit for the relay R1750. The latter relay, upon restoring, closes its contacts 1754 to reprepare the out-pulsing circuit; closes its contacts 1755 to reprepare the path for directly transmitting ground pulses over the out-pulsing lead OP; closes its contacts 1753 to reprepare the operating circuit for the relay R1740; opens its contacts 1752 to interrupt the above-traced circuit for charging the condenser 1756; and closes its

contacts 1751 to discharge the condenser 1756 through the resistor 1725.

The manner in which the pulsing relay R1760 is repeatedly energized under the control of the two relays R460 and R450 of the link 15 will be clearly apparent in view of the preceding explanation. Each time the relay R1760 operates it locks to the grounded out-pulsing lead OP through its contacts 1762, and closes its contacts 1761 to energize the relay R1750. Each time the latter relay operates it closes its contacts 1752 to complete the circuit for charging the condenser 1756. This circuit is transferred successively to include the operating windings of the relays R1650, R1660 and R1670, in the order named. Thus the second time the relay R1750 operates the condenser 1756 is charged in a circuit which extends from the grounded conductor 666 by way of the contacts 1671, 1661, 1651 and 1642, the upper winding of R1650, the contacts 1731 and 1752, and the condenser 1756 to battery. When thus energized the relay R1650 locks to the grounded conductor 666 through its preliminary make contacts 1653, transfers the condenser charging circuit to the upper winding of the fourth counting relay R1660, opens the locking circuit for the relay R1640, and prepares a multiple circuit for energizing the relay R1710. Each time the relay R1750 restores it obviously discharges the condenser 1756 through the resistor 1725.

After four impulses have been counted by the impulse counting relays, the pulse transmission is arrested. More specifically, when the fifth counting relay R1670 operates in response to the fourth operation of the relay R1750, it closes its contacts 1672 to complete the prepared operating circuit for the stop sending relay R1730, this circuit extending from the grounded conductor 666 by way of the contacts 1672 and 1683, and the winding of R1730 to battery. The relay R1730, upon operating, opens its contacts 1733 to interrupt the previously traced operating circuit for the relay R1760. At its contacts 1731, the relay R1730 opens a point in the above-traced circuit for charging the condenser 1756 in series with the operating windings of the counting relays. At its contacts 1732, the relay R1730 completes a path for discharging the condenser 1756 through the resistor 1725. Shortly following the operation of the relay R1730, the two relays R1760 and R1750 are sequentially released under the control of the reverting pulse relay R450 of the link 15. The relay R1750, upon restoring, closes its contacts 1753 to complete the prepared operating circuit for the relay R1740, this circuit extending from the grounded conductor 666 by way of the contacts 1672, 1683 and 1753, and the winding of R1740 to battery.

It will be noted that with the relay R1730 operated and the pulsing relay R1760 released, no circuit is available for energizing the pulsing relay R460 in series with the pulsing relay R1760 when the reverting pulse relay R450 restores. Accordingly, the impulsive transmission to the pulsing relay R460 of the link 15 is arrested after four impulses have been transmitted to this relay. The relay R1740, upon operating, locks to ground over a path including the contacts 1741 and 1742, and the conductor 666. At its contacts 1742, the relay R1740 opens another point in the operating circuit for the relay R1710. At its contacts 1743, the relay R1740 completes the previously mentioned alternative circuit for energizing

the operating magnet 957 of the outgoing digit counting switch 950, this circuit extending from the grounded conductor 666 by way of the contacts 1715 and 1743, the lead MO, the contacts 846, and the winding of the magnet 957 to battery. In operating, the magnet 957 steps the wipers 955 and 956 out of engagement with their respective associated first contacts and into engagement with their respective associated second contacts. At its contacts 957b, the magnet 957 opens a point in the locking circuits for the two relays R630 and R850. At its contacts 957a, the magnet 957 completes the prepared operating circuit for the relay R1720, this circuit extending from the grounded release conductor 665 by way of the contacts 957a and 842, the LO lead, and the winding of R1720 to battery. When thus energized the relay R1720 locks to the grounded conductor 666 through the contacts 1721 and 1712. At its contacts 1723, the relay R1720 opens a point in the common portion of the locking circuits for the six impulse counting relays, thereby to cause the deenergization and release of the two relays R1670 and R1680. At its contacts 1724, the relay R1720 opens another point in the previously traced outpulsing circuit over which the relay R1760 is controlled during each impulse sending operation. At its contacts 1722, the relay R1720 opens the locking circuit for the relay R1710.

The relay R1710 now restores and opens contacts 1713 further to interrupt its own locking circuit. At its contacts 1714, the relay R1710 reprepares its own operating circuit. At its contacts 1711, the relay R1710 opens a point in the previously mentioned alternative circuit for energizing the relays R1730 and R1740. At its contacts 1715, the relay R1710 opens the above-traced circuit including the MO lead for energizing the operating magnet 957 of the counting switch 950, causing this magnet to release. At its contacts 1716, the relay R1710 reprepares the above-traced operating circuit for the relay R1680. At its contacts 1716', 1717 and 1718, the relay R1710 reprepares the respective operating circuits for the three connect relays R1680, R1610 and R1620. At its contacts 1718', the relay R1710 reprepares the alternative locking circuits for the three sequence relays and the relays of the three storing relay groups. At its contacts 1719, the relay R1710 opens another point in the out-pulsing circuit over which the pulsing relay R1760 is controlled during each impulse sending operation. At its contacts 1712, the relay R1710 interrupts the locking circuits for the relays R1720 and R1740.

The relays R1670 and R1680, upon restoring, open their contacts 1672 and 1683, respectively, to interrupt the operating circuit for the relay R1730. The latter relay, in restoring, closes its contacts 1733 to reprepare the out-pulsing circuit over which the pulsing relay R1760 is controlled during each impulse sending operation. At its contacts 1731, the relay R1730 reprepares the above-described circuit for charging the condenser 1756 in series with the operating windings of the five counting relays. At the contacts 1672 and 1683, the two relays R1670 and R1680 also interrupt the previously traced operating circuit for the relay R1740. In releasing, the latter relay closes its contacts 1742 to reprepare the operating circuit for the relay R1710, and opens its contacts 1741 further to interrupt its own locking circuit.

The magnet 957, upon restoring in response to the release of the relay R1710, opens its contacts 957a to interrupt the above-traced operating circuit for the relay R1720. At its contacts 957b, the magnet 957 reprepares the locking circuits for the two relays R630 and R850. The relay R1720, upon restoring in response to the release of the magnet 957 and the relay R1710, opens its contacts 1721 further to interrupt its own locking circuit; closes its contacts 1722 to reprepare the locking circuit for the relay R1710; closes its contacts 1723 to reprepare the locking circuits for the impulse counting relays; and closes its contacts 1724 further to prepare the out-pulsing circuit over which the pulsing relay R1760 is controlled during each impulse sending operation. Following the release of the relay R1720, the first digit as stored in the No. 1 storing relay group and later transferred to the impulse counting relays, has been transmitted to the selector portion of the link 15 to direct the selector switching mechanism of this link in its operation to select the fourth group of trunks accessible thereto. Moreover, after this relay releases, the impulse sending equipment as shown in Figs. 16 and 17 of the drawings is conditioned to transmit the second digit, i. e., that registered in the No. 2 group of the storing relays, to the selector which is seized through the outlet contacts of the selector switching mechanism of the link 15 during the trunk hunting operation of this mechanism.

In this regard it is pointed out above that after the impulses of the second digit are received and stored in the No. 2 group of impulse storing relays, the second sequence relay R720 is energized and operates. More specifically, this sequence relay is energized over a circuit including the SH2 lead in response to the operation of the control relay R800 during the inter-digit pause between the second and third digits. In operating, this relay locks to the grounded SH2 lead through its contacts 722, and opens its contacts 721 to interrupt an incomplete circuit for energizing the operating magnet 957 of the counting switch 950. At its contacts 724, the relay R720 disconnects the two marking leads 1074 and 1077 from the grounded release conductor 665. At its contacts 723, the relay R720 completes the prepared operating circuit for the connect relay R1620 associated with the No. 2 group of impulse storing relays, this circuit extending from the grounded release conductor 665 by way of the contacts 723, the wiper 956 and its engaged second contacts, the lead OS2, the contacts 1716', and the winding of R1620 to battery.

In operating, the relay R1620 first closes its preliminary make contacts 1621 and then opens its contacts 1622, thereby to include the break contacts 1718' of the relay R1710 in the locking circuits for the operated relay R1440 of the No. 2 storing relay group and the second sequence relay R720. At its contacts 1623, the relay R1620 opens a point in the out-pulsing circuit over which the pulsing relay R1760 is controlled during each impulse sending operation. At its contacts 1626 to 1629, inclusive, the relay R1620 connects the four marking leads of the No. 2 group by way of the conductors 1691 to 1694, inclusive, to the lower winding terminals of the four counting relays R1630, R1640, R1650 and R1660. Since, however, in the case under consideration the fifth storing relay R1440 is operated in the No. 2 group of storing relays, none of the four enumerated counting relays is operated. At its contacts 1624, the relay R1620 completes the prepared operating circuit for the relay R1680, this

circuit now extending from the grounded conductor 666 by way of the contacts 1456, 1624 and 1716, and the winding of R1680 to battery. At its contacts 1625, the relay R1620 completes the operating circuit for the relay R1710, this circuit now extending from the grounded conductor 666 by way of the contacts 1446, 1625, 1742 and 1714, and the winding of R1710 to battery.

The relay R1680, upon operating, locks to the grounded conductor 666 through its contacts 1684, opens its contacts 1681 to interrupt one of its own operating circuits, opens its contacts 1682 to interrupt one of the available circuits for energizing the upper winding of the relay R1630, and closes its contacts 1683 to prepare the operating circuits for the relays R1730 and R1740. The relay R1710, in operating, locks to the grounded conductor 666, opens its contacts 1716' to deenergize the second connect relay R1620, opens its contacts 1718' to deenergize the second sequence relay R1720 and the operated relay R1440 of the No. 2 storing relay group, and closes its contacts 1719 to prepare the out-pulsing circuit. This circuit is completed at the contacts 1723 incident to the release of the connect relay R1620. From this point on, the manner in which the impulse sending relays illustrated in Fig. 17 of the drawings cooperate to transmit five impulses to the second selector, such, for example, as the selector 16 seized through the outlet contacts of the selector portion of the link 15, is exactly the same as explained above with reference to the transmission of the impulses of the first digit.

After the five impulses of the second digit have been transmitted to the seized second selector, the relays R1670, R1730 and R1740 are sequentially operated in the manner previously described. The last of these relays, in operating, closes its contacts 1743 to recomplete the circuit for energizing the operating magnet 957 of the outgoing digit counting switch 950. When thus energized the wipers 955 and 956 are stepped out of engagement with their respective associated second contacts and into engagement with their respective associated third contacts. In operating, the magnet 957 also closes its contacts 957a to recomplete the above-traced operating circuit for the release relay R1720. This relay, in operating, causes the deenergization of the magnet 957, the release of the impulse counting relays R1670 and R1680, and the release of the relays R1710, R1730 and R1740 in the exact manner explained above. When the relay R1710 and the magnet 957 restore, the relay R1720 is deenergized and releases. Following the restoration of this relay the impulse counting relays are conditioned to receive the digit information set up in the No. 3 impulse storing relay group, and the impulse sending relays are conditioned to repeat the required number of impulses over the previously described out-pulsing circuit.

The transmission of the impulses constituting the third digit from the register sender 19 is started when the third register sequence relay R810 operates during the inter-digit pause separating the end of the received third digit from the beginning of the fourth digit. More specifically, this relay, in operating, locks to the grounded SH3 lead through its contacts 811, and opens its contacts 813 to disconnect the eighth marking lead 1078 from ground. At its contacts 812, the relay R810 completes the prepared operating circuit for the third connect relay R1600, this circuit extending from the grounded release

conductor 665 by way of the contacts 812, the wiper 956 and its engaged third contacts, the OS3 lead, the contacts 1718 and the winding of R1600 to battery.

- 5 In operating, the relay R1600 closes its contacts 1601 and then opens its contacts 1602, thereby to include the break contacts 1718' of the relay R1710 in the locking circuits for the operated relays R1500 and R1550 of the No. 3 storing relay group and the locking circuit for the third register sequence relay R810. At its contacts 1605 to 1608, inclusive, the relay R1600 connects the four marking leads of the No. 3 group by way of the conductors 1691 to 1694, inclusive, to the lower winding terminals of the relays R1630, R1640, R1650 and R1660, thereby to complete the prepared operating circuit for the fourth counting relay R1660. This circuit extends from the grounded conductor 666 by way of the contacts 1506 and 1608, the conductor 1694, and the lower winding of R1660 to battery. At its contacts 1603, the relay R1600 prepares one of the operating circuits for the relay R1680, this circuit being held open at the open break contacts 1556 of the operated relay R1550 in the No. 3 storing relay group. At its contacts 1604, the relay R1600 prepares one of the operating circuits for the relay R1710. At its contacts 1609, the relay R1600 opens a point in the incomplete out-pulsing circuit, which circuit has now been extended to the No. 3 switch, such, for example, as the connector 17, of the switch train through which the connection is being progressively extended to the desired line.

The relay R1660, in operating, locks to the grounded conductor 666 through its preliminary make contacts 1663 and the additional contacts 1674 and 1723. At its contacts 1662, the relay R1660 includes the upper or operating winding of the fifth counting relay R1670 in the previously traced circuit for charging the condenser 1756. At its contacts 1665, the relay R1660 opens a point in the locking circuit for the relay R1650. At its contacts 1664, the relay R1660 completes the prepared operating circuit for the relay R1710. 45 In this case the last-mentioned circuit extends from the grounded conductor 666 by way of the contacts 1723, 1664, 1742 and 1714, and the winding of R1710 to battery.

In operating, the relay R1710 opens its contacts 1718 and 1718', thereby to deenergize the third connect relay R1600, the operated relays R1500 and R1550 of the No. 3 storing relay group, and the operated sequence relay R810. The latter relay, upon restoring, opens its contacts 811 further to interrupt its locking circuit; opens its contacts 812 further to interrupt the operating circuit for the connect relay R1600; and closes its contacts 813 to again impress ground potential by way of the conductor C874 upon the marking lead 1078.

In operating, the relay R1710 also closes its contacts 1719 further to prepare the out-pulsing circuit. This circuit is completed at the contacts 1609 to initiate the impulse sending operation incident to the release of the third connect relay R1600. The manner in which the current pulses are transmitted to the pulsing relay of the third switch in the switch train and the pulsing relay R1760 is revertively controlled from this switch, 65 is exactly the same as explained above with reference to the transmission of the impulses constituting the first digit. In this regard it will be understood that the transmitted impulses are counted through operation of the impulse counting relays, and that since the relay R1660 is op-

erated at the start of the impulse transmitting operation, a total of six impulses will be transmitted before the impulse sending equipment is released. Thus, when the relay R1670 operates to count the first transmitted impulse, it locks to ground over a path including the contacts 1673, 1635 and 1723, and closes its contacts 1672 to prepare the previously mentioned alternative circuit for charging the condenser 1756 through the operating winding of the first counting relay R1630. In operating, the relay R1670 also closes its contacts 1675 to prepare the previously mentioned alternative operating circuit for the relay R1680. Thereafter, and when the relay R1750 operates incident to the transmission of the second impulse of the digit, the condenser 1756 is charged in series with the upper winding of the relay R1630 over a circuit which extends from the grounded conductor 666 by way of the contacts 1672 and 1682, the upper winding of R630, the contacts 1731 and 1752, and the condenser 1756 to the negative terminal of the exchange battery. When its upper winding is thus energized the relay R1630 locks to the grounded conductor 666 through its preliminary make contacts 1633, and completes the prepared alternative operating circuit for the relay R1680. The latter circuit extends from the grounded conductor 666 by way of the contacts 1723, 1645, 1633, 1675 and 1681, and the winding of R1680 to battery. In operating, the relay R1680 first locks to ground through its preliminary make contacts 1684, and then interrupts its operating circuit at the contacts 1681. At its contacts 1682, the relay R1680 opens the established circuit for charging the condenser 1756 in series with the operating winding of the relay R1630. At its contacts 1683, the relay R1680 prepares the previously traced operating circuits for the two relays R1730 and R1740.

With the relay R1680 operated, it will be understood that after the four additional impulses of the third digit have been transmitted, the relay R1670 is operated and closes its contacts 1672 to energize the relays R1730 and R1740, and thus initiate the release of the impulse sending equipment in the exact manner explained above. Incident to the release of this equipment a current pulse is transmitted to the operating magnet 957 of the outgoing digit counting switch 950, whereby the wipers of this switch are stepped to engage their respective associated fourth contacts.

With the wipers of the counting switch 950 operated to the fourth off-normal position thereof, it will be understood that when the first register sequence relay R610 operates following the storing of the impulses of the fourth digit in the No. 1 storing relay group, a circuit is completed by way of the wiper 956 and the OS1 lead for energizing the first connect relay R1610. This relay, in operating, causes the impulses of the fourth digit to be transmitted to the third switch in the automatic switch train through which the connection is being routed to the called line. It will be apparent from the above explanation and an examination of the wiring of the three OS leads to the inner contact set 954 of the counting switch 950 that the connect relays R1610, R1620 and R1680 are sequentially operated under the control of this counting switch. Each of these relays, in operating, connects the associated group of storing relays with the impulse counting relays shown in Fig. 16 of the drawings, and initiates the operation of the impulse sending relays to transmit the digit to the associated switch train.

In the present case, wherein five digits are

transmitted to the register sender and are repeated by this register sender to the automatic switches forming the train through which the connection is extended to the desired line 11, the 5 register sender 19 is automatically released after these digits have been received therein and retransmitted therefrom. In this regard it will be recalled that the wipers of the incoming digit counting switch 1100 are stepped to engage their 10 respective associated sixth contacts at the end of the received fifth digit. With the wipers of the switch 1100 standing in this position, one of the locking circuits for the relay R820 is held open at the contacts 1023 of the operated digit marking relay R1020. Incident to the operation of these wipers to engage their associated sixth contacts, the magnet 1107 closes its contacts 1107a to complete the operating circuit for the control relay R800. In this case the relay R800, upon 20 opening its contacts 806, deenergizes the control relay R820 in addition to performing its other functions as described above. The relay R820 now restores and opens its contacts 826 to interrupt one of the branches of its own locking circuit. At its contacts 827, the relay R820 opens the previously traced circuit for charging the condenser 748 in series with the operating windings of the relays in the three storing relay groups, thereby to prevent these relays from responding 25 to further inadvertent operation of the two pulsing relays R730 and R740. At its contacts 828, the relay R820 prepares one of the operating circuits for the timing relay R620. At its contacts 829, the relay R820 prepares the path for connecting the trunk conductor 36c directly to ground. At its contacts 825, the relay R820 opens a point in the incomplete operating circuit for the digit relay R750. At its contacts 824, the relay R820 opens the path short-circuiting the contacts 30 of the send alarm key 705. At its contacts 823, the relay R820 prepares the operating circuit for the send alarm relay R830. At its contacts 822, the relay R820 opens a point in the previously traced dial tone signaling circuit. At its contacts 821, the relay R820 completes the previously 35 mentioned ring-back tone signaling circuit. The last-mentioned signaling circuit extends from one terminal of the ringing current generator provided in the common equipment 32, by way of the conductor C912, the contacts 862, the condenser 859, the contacts 847 and 821, the condenser 747, the contacts 621, the trunk conductor 36a, the wiper 557, the contacts 532, the trunk conductor 35a, the contacts 301 and the negative side of the loop circuit extending to the calling substation. From this point, the current for producing the 40 ring-back tone signal at the calling substation is transmitted through the receiver provided at this substation and over the positive side of the calling loop circuit to the opposite terminal of the ringing current generator from which the current is derived.

Release of the register sender 19

45 As indicated above, the register sender is held operated until the five digits have been transmitted therefrom. In this regard it will be understood that after the fifth digit is transmitted, the wipers of the outgoing digit counting switch 50 950 are operated to engage their respective associated sixth contacts. When the wiper 955 is moved into engagement with its associated sixth contacts a circuit is completed for energizing the release relay R850, this circuit extending from the grounded release conductor 665 by way of the

contacts 1025 and 1022, the marking lead 965, the wiper 955 and its engaged sixth contacts, and the winding of R850 to battery. In operating, the relay R850 opens its contacts 851 to interrupt the previously traced out-pulsing circuit. At its contacts 852, the relay R850 prepares the operating circuit for the revertive call relay R640. At its contacts 853, the relay R850 opens a point in the locking circuits for the two relays R630 and R830. At its contacts 854, the relay R650 completes a locking circuit for itself, this circuit extending from the grounded release conductor 665 by way of the contacts 957b and 854, and the winding of R850 to battery. At its contacts 856, the relay R850 prepares the operating circuit for the timing relay R650. At its contacts 855, the relay R850 opens a point in the prepared operating circuit for the timing relay R630. At its contacts 857, the relay R850 completes the prepared operating circuit for the timing relay R620, this circuit extending from ground by way of the contacts 828, 865 and 857, the off-normal springs 959 and 1109 in parallel, and the lower winding of R620 to battery.

When thus energized, the relay R620 locks to ground over a circuit which includes its preliminary make contacts 624 and the contacts 605. At its contacts 624, the relay R620 completes another locking circuit for itself, this circuit extending away from ground by way of the contacts 626, the parallel connected off-normal springs 959 and 1109, and the winding of R620 to battery. At its contacts 623, the relay R620 opens a point in the circuit for energizing its upper winding. At its contacts 622, the relay R620 opens another point in the circuit individual to the register sender 19, over which the all-busy relay R500 is energized when this register sender is idle. At its contacts 621, the relay R620 opens a point in the common portion of the above-traced dial and ring-back tone signaling circuits, thereby to terminate the ring-back tone signal being reproduced at the calling substation. At its contacts 625, the relay R620 disconnects the conductor C661 from ground, thereby to deenergize the operated control relay R800. At its contacts 621, the relay R620 also interrupts the calling loop circuit as extended to the register sender 19, thereby to deenergize the line relay R700. At its contacts 627, the relay R620 disconnects the trunk conductor 36c from ground in the register sender 19, thereby to cause the switch-through operation of the link 15 and the release of the register selector 18, in the manner previously described. At its contacts 628, the relay R620 completes the prepared operating circuits for the release magnets 958 and 1108, these circuits extending from ground by way of the contacts 628, C662 and the parallel-connected windings of the two magnets 958 and 1108 to battery.

The line relay R700, upon restoring, opens its contacts 702 to deenergize the hold relay R710, and closes its contacts 701 to complete the prepared operating circuit for the relay R740. The latter relay, upon operating, closes its contacts 743 to energize the relay R730 and, at its contacts 744, completes the locking circuit for the hold relay R710. The relay R730, upon operating, locks to ground through the contacts 733, 711 and 704, and opens its contacts 734 to deenergize the pulsing relay R740. The latter relay, upon restoring, opens its contacts 744 to deenergize the hold relay R710. The relay R710 now restores and opens its contacts 711 to deenergize

the pulsing relay R730. At its contacts 713, the relay R710 prepares an alternative operating circuit for the timing relay R620. At its contacts 714, the relay R710 closes a point in the path for impressing ground potential upon the sixth and ninth contacts of the contact set 953 in the counting switch 950. At its contacts 712, the relay R710 deenergizes the hold slave relay R600. The release of the two relays R730 and R800 is without effect.

The hold slave relay R600, upon restoring, opens its contacts 601 to disconnect the conductor 666 from ground and thus opens a point in the common portion of the operating and locking circuits for all of the relays illustrated in Figs. 12, 13, 14, 15, 16 and 17 of the drawings, with the exception of the pulsing relay R760. It is noted, however, that by the time the conductor 666 is disconnected from ground at the contacts 601, all of the relays in the indicated portion of the register sender are restored to normal. At its contacts 602, the relay R600 disconnects the test conductor 36d of the trunk 36 from ground, thereby to render the register sender 19 available for seizure through another of the register selectors to which it is accessible. At its contacts 603, the relay R600 reprepares the circuit, individual to the register sender 19, over which the all-busy relay R500 is normally energized. At its contacts 604, the relay R600 opens a point in one of the operating circuits for the timing relay R630. At its contacts 605, the relay R600 opens one of the locking circuits for the timing relay R620. At its contacts 606, the relay R600 completes an obvious multiple holding circuit for the timing relay R620. At its contacts 607, the relay R600 opens another point in the path for impressing ground potential upon the trunk conductors 36c and 35c. At its contacts 609, the relay R600 disconnects the common start lead 660 from ground in the register sender 19. At its contacts 608 the relay R600 disconnects the release conductor 665 from ground, thereby to cause the deenergization and release of the relays R1020, R850 and R840. The release of these three relays is without effect.

When the release magnet 958 is energized in response to the operation of the timing relay R620 it attracts its associated holding pawl, thereby to permit the wipers 955 and 956 to be restored to their respective normal positions. Incident to the release of these wipers the off-normal springs 959 are disengaged to open one of the multiple circuits for energizing the timing relay R620. In a similar manner when the release magnet 1108 is energized it attracts its associated holding pawl to permit the spring-biased wipers 1105 and 1106 to be restored to normal, at which time the off-normal springs 1109 are opened to interrupt the other multiple circuit for energizing the timing relay R620. When thus deenergized the timing relay R620 restores and opens its contacts 626 to deenergize the release magnets 958 and 1108. Following the release of these magnets the register sender is fully restored to normal and may be seized for use in the setting up of another connection through any of the register selectors to which it is accessible.

From a consideration of the circuits described above, it will be understood that the two relays R600 and R620 are controllable to release the register sender regardless of the setting of the other relays provided therein, when the register sender is occupied with a line to line call as distinguished from a reverting call. Thus, up until

the time the release relay R850 operates to initiate the normal release of the register sender after a sending operation is completed, an alternative circuit for energizing the timing relay R620 is prepared through the contacts 858 and 867. With this arrangement, if the register sender 19 is seized over a calling line, the directory number dialing operation is partially completed and the call is abandoned, the calling loop circuit is opened to cause the sequential release of the line relay R700 and the hold relay R710 in the manner explained above. In this case the relay R710, in opening its contacts 712, deenergizes the hold slave relay R600. At its contacts 713, the relay R710 completes a circuit through the contacts 867 and 858, and the parallel-connected off-normal springs 959 and 1109 for energizing the timing relay R620. In operating, the relay R620 locks to ground through its contacts 624 and 626, and closes its contacts 628 to energize the two release magnets 958 and 1108 in the manner previously described. At its contacts 627, the relay R620 disconnects the connected trunk conductors 36c and 35c from ground in the register sender, thereby to cause the release of the register selector 18 and the link 15 in the manner previously explained. At its contacts 625, the relay R620 also opens a point in the common portion of the operating and locking circuits for the control relays R800 and R820. The hold slave relay R600, upon restoring, opens its contacts 601 and 603 to disconnect the two conductors 666 and 665 from ground, whereby all the operated relays, with the exception of the timing relay R620, are caused to restore. When the two digit counting switches 950 and 1100 are released their off-normal springs 959 and 1109 are disengaged to deenergize the timing relay R620. This relay, upon restoring, opens its contacts 628 to deenergize the two release magnets 958 and 1108. Following the release of these magnets the register sender is fully restored to normal.

As previously indicated, although not specifically referred to, provisions are made in the register sender for positively preventing impulses from being directed to any one of the three storing relay groups of Figs. 13, 14 and 15 at a time when a digit is already registered therein. In this regard it will be noted from the preceding explanation that each of the three register sequence relays R610, R720 and R810 is operated immediately after a digit is registered in the associated storing relay group and remains operated until the digit thus registered is transferred to the impulsing counting relays and the operated relays of the associated storing relay group are released to condition this group for the registration of another digit. Thus the first register sequence relay R610 is controlled by the relay R800 to operate during the inter-digit pause between the first and second digits of a directory number dialed into the register sender. This relay remains in its operated position until the connect relay R1610 operates to transfer the registration in the No. 1 storing relay group to the impulse counting relays, and the start sending relay R1720 thereafter operates to deenergize the operated relays of the No. 1 storing relay group. During the period when the register sequence relay R610 is operated, the path for impressing ground potential upon the fourth and seventh marking leads 1073 and 1076 is held open at the contacts 614. Accordingly, if the counting switch 1100 is operated so that the wipers thereof engage their respective associated fourth or seventh contacts 75

during an interval when the relay R610 is energized, the circuit for maintaining the upper winding of the control relay R820 energized, is opened by the wiper 1106. This condition will only arise 5 when all three of the storing relay groups have digits registered therein. Should it arise, the relay R800 is energized in response to the operation of the magnet 1107 to step the wipers 1105 and 1106 into engagement with their respective 10 associated fourth contacts. In operating, the relay R800 opens its contacts 806 to deenergize the lower winding of the relay R820, permitting the latter relay to restore. In releasing, the relay R820 opens its contacts 827 to interrupt the previously traced circuit for charging the condenser 748 in series with the operating windings of the storing relays. At its contacts 828, the relay R820 prepares the previously traced operating 15 circuit for the timing relay R620. At its contacts 825, the relay R820 opens the operating circuit for the digit relay R750.

If the digit registration set up in the No. 1 group of storing relays is transferred to the impulse counting relays, and this storing relay group is released before the next digit, i. e., the 20 fourth digit, is dialed into the register sender 19, the control relay R820 is reoperated to permit the impulses of the fourth received digit to be transmitted to the storing relays of the No. 1 25 group in the desired manner. Thus if this group of storing relays is released under the control of the start sending relay R1710 before the fourth digit is received, the register sequence relay R610 is also deenergized. In releasing, this relay closes its contacts 614 to energize the upper winding of the control relay R820 in a circuit which extends from the grounded release conductor 665 by way of the contacts 614, C663, the contacts 1043, the marking lead 1073, the 30 wiper 1106 and its engaged fourth contacts, C875 and the upper winding of R820 to battery. In reoperating, the relay R820 closes its contacts 35 825 to reprepare the operating circuit for the digit relay R750, and closes its contacts 827 to 40 reprepare the circuit for charging the condenser 748 in series with the operating windings of the storing relays. Thus, with the relay R820 reoperated, the subsequently received impulses of the fourth digit dialed at the calling substation 45 may be transmitted to the relays of the No. 1 50 storing relay group.

If the relay R820 is not reoperated before the 55 fourth digit is dialed into the register sender 19 from the calling substation, the call will fail. Under this condition, a portion or all of the received impulses are absorbed and, hence, the 60 call at best can only be directed to the wrong substation. If only a part of the impulses of the fourth digit are absorbed before the relay R820 65 reoperates to direct the remaining impulses of the digit into the No. 1 group of storing relays, the digit is not wholly lost and, accordingly, the operation of the register sender will proceed in the exact manner described above. On the other hand, if the fourth and possibly succeeding digits are wholly absorbed in the register sender during the period when the relay R820 is deenergized, an insufficient number of digits will be counted 70 by the outgoing digit counting switch 950 to cause the operation of the release relay R850 and the consequent automatic release of the register sender after all digits have been transmitted by the impulse sending relays to the associated switch train. Under these circumstances the 75 register sender 19 and the automatic switch train

through which the call is partially forwarded to its destination, are automatically released under the control of the timing equipment 31, in the manner explained below.

The other two sequence relays R720 and R810, in discharging their functions to control the paths for impressing ground potential upon the marking leads 1074, 1071, 1075 and 1078, may also cause the control relay R820 to be released in the manner just explained. If all three of the storing relay groups have digits registered therein at the same time, the one of the three register sequence relays which will effect the release of the relay R820 under the described abnormal conditions depends, of course, upon the particular point in the directory number dialing operation at which all three of the storing relay groups are concurrently occupied with registered digits. The manner in which the release of the relay R820 is effected under such a condition is, however, exactly the same regardless of the particular register sequence relay which is responsible for the release of this relay.

Transmitting the digit "0"

With the illustrated wiring arrangement, the register sender is arranged automatically to be released after the single digit "0" of ten impulses is transmitted thereto from a calling substation and the ten impulses of the digit are retransmitted to the selector portion of the link through which the sender is seized. In this regard it will be recalled from the preceding explanation that the digit "0" is used as the directory number designating the trunks extending to the toll switchboard 30. In order to effect the automatic release of the sender after this digit has been transmitted therefrom, the terminal 10 in the terminal row 3 of the terminal frame shown in Fig. 12 of the drawings is cross-connected to the terminal 1 in terminal row 1. With this arrangement the connect relay R1230, upon momentarily operating in response to the release of the digit relay R750 at the end of the received digit, closes a circuit for energizing the digit marking relay R1060, this circuit extending from the grounded conductor 665 by way of the contacts 1346 of the operated storing relay R1340, the contacts 1235, the strap connecting the terminal 10 of terminal row 3 with the terminal 1 of terminal row 1, the digit conductor 1D, the contacts 1061 and the winding of R1060 to battery. In operating, the relay R1060 first locks to the grounded release conductor 665 through its preliminary make contacts 1065, and then opens its contacts 1061 to interrupt its operating circuit. At its contacts 1065 and 1062, the relay R1060 prepares a circuit including the marking lead 961 for energizing the release relay R850. At its contacts 1063, the relay R1060 opens the path over which ground potential is normally impressed upon the first marking conductor 1071.

With the relay R1060 operated to withhold ground potential from the marking lead 1071, it will be understood that the control relay R820 is deenergized and restores in response to the operation of the switch 1100 to count the single digit transmitted to the register sender 19. More specifically, one branch of the locking circuit for the control relay R820 is opened at the wiper 1106 when this wiper is stepped to engage its associated second contacts. The other branch of this circuit is opened at the contacts 806 in response to the operation of the control relay R800, which results from the operation of the

magnet 1107 to advance the wipers 1105 and 1106 into engagement with their respective associated second contacts. It will be understood from the preceding explanation that the relay R820, upon restoring, prevents further impulses from being transmitted to the impulse storing relays, closes the ring-back tone signaling circuit, and otherwise conditions the register sender to be released when the ten impulses of the digit have been transmitted to the selector portion of the link through which the register sender is seized. It will also be recalled that after the ten impulses of the digit have been transmitted by the impulse sending relays of the register sender, the operating magnet 957 is operated to advance the wipers of the digit counting switch 950 to engage their respective associated second contacts, and the impulse sending relays are released. As the wiper 955 is operated into engagement with its associated second contacts the above-mentioned circuit for energizing the release relay R850 is completed, this circuit now extending from the grounded release conductor 665 by way of the contacts 1065 and 1062, the marking lead 961, the wiper 955 and its engaged second contacts, the contacts 923, and the winding of R850 to battery. The release relay R850, upon operating, initiates the release of the register sender and the register selector through which it is seized in the exact manner explained above.

From an examination of the wiring of the circuits controlled by the digit relays R940, R1000, R1010, R1020, R1030, R1040, R1050 and R1060, it will be understood that by appropriately cross-connecting the terminals forming the terminal row 3 of the terminal block shown in Fig. 12 of the drawings to the terminals forming the terminal row 1 the release of the register sender may be effected after any desired number of digits have been transmitted to the register sender and retransmitted therefrom. It will also be apparent that by selectively strapping the terminals of terminal row 3 to the terminals of terminal row 1, the numerical value of any desired first digit may be used to provide an indication of the total number of digits to be received and transmitted. With the illustrated wiring arrangement, a received first digit of one, two, three or four impulses, indicates that a total of five digits are to be received and retransmitted during the dialing operation. To this end, the terminals 1, 2, 3 and 4 in terminal row 3 are strapped to the terminal 5 in terminal row 1. The nine digit marking relays are directly controlled over the digit leads 1D to 9D, inclusive, and are arranged to set up different circuits through the numerically corresponding contacts of the contact sets 951 and 952 for energizing the release relay R850 after the corresponding numbers of digits have been transmitted from the register sender 19. This release circuit as controlled by the digit marking relays R1040, R1050, R1020, R1010, R1000, R940 and R840, which relays respectively correspond to directory numbers comprising three, four, five, six, seven, eight and nine digits, is arranged to be directly extended to the grounded release conductor 665 from the one of the marking leads 963, 964, 965, 966, 967 and 968 which corresponds to the operated digit marking relay. In case the marking relay R1060 or the marking relay R1050, which respectively corresponds to directory numbers of one and two digits, is operated, the circuit for energizing the release relay is carried from the

marking lead 961 or 962 through one set of the break contacts 923 and 933, thus rendering the circuit controllable by the relays R920 and R930. The purpose of this arrangement is pointed out more fully hereinafter.

Using the second digit to indicate the number of digits to be received

In the event the numerical value of the second digit rather than that of the first digit is to be used to inform the register sender of the total number of digits to be received during a directory number dialing operation, that terminal in terminal row 3 of the terminal frame shown in Fig. 12 of the drawings which corresponds to the numerical value of the first digit is strapped to the terminal 1 in terminal row 2, and the terminal in terminal row 4 corresponding to the numerical value of the second digit is cross-connected to that terminal in terminal row 1 which corresponds to the total number of digits to be received. For example, with the illustrated trunking arrangement it is desirable in the handling of calls which must be extended through the second selectors in the group including the selector 20, to utilize the second digits of the directory numbers designating the desired lines for the purpose of informing the register sender as to the total number of digits in the directory number designations. This group of selectors, it will be recalled, is designated by the transmission of a first digit of six impulses to any one of the first selectors having access thereto. Accordingly, the terminal 6 in terminal row 3 is strapped to terminal 1 in terminal row 2. It will also be recalled that the special service trunks accessible to the second selector 20 are designated by the directory numbers 631, 621 and 681, respectively. Since each of these directory numbers comprises three digits, the terminals 2, 3 and 8 of terminal row 4 are strapped to terminal 3 in terminal row 1.

With this wiring arrangement the relay R1230, upon momentarily operating after a first digit of six impulses has been transmitted to the register sender 19 from a calling substation, completes a circuit through its contacts 1231 for energizing the second digit test relay R900. This circuit extends from the grounded conductor 666 by way of the contacts 1306 and 1231, the strap connecting terminal 6 of terminal row 3 with terminal 1 of terminal row 2, the 2DT lead, the contacts 906, and the winding of R900 to battery. In operating, the relay R900 first locks to the grounded release conductor 665 through its preliminary make contacts 908. After completing this locking circuit, the relay R900 opens its operating circuit at the contacts 906. At its contacts 907, the relay R900 prepares circuits for energizing the start sending and release relays R840 and R850. At its contacts 901, the relay R900 connects the out-pulsing lead OP to the positive trunk conductor 36b in order to provide a circuit over which the impulses of the stored digit may be retransmitted from the register sender to the selector portion of the link occupied with the call. At its contacts 902 and 904, the relay R900 opens the completed circuit for energizing the magnet 957, causing this magnet to restore. In releasing, the magnet 957 opens its contacts 957a to deenergize the operated connect relay R1230, causing this relay to restore. In operating, the relay R900 also closes its contacts 903 and 905, thereby to prepare the operating circuits for the second digit connect relays R1200 and R1210. 70 78

With the second digit test relay R900 operated, if a second digit of eight impulses is dialed into the register sender 19 from the calling substation, the relays R1450 and R1420 are operated in the

- 5 No. 2 storing relay group at the end of the digit. The digit relay, upon restoring at the end of the digit, completes the prepared operating circuit for the second digit connect relay R1210, this circuit extending from the grounded conductor 666 by way of the contacts 1622 and 1424, the SH2 lead, the contacts 721, 903, 844, 751 and 905, the SM2 lead, the contacts 1454, and the winding of R1210 to battery. It will be noted that in the event the second digit transmitted to the register sender comprises less than five impulses, such that the relay R1450 is not operated at the end of the digit, the second digit connect relay R1200 is energized through the contacts 1455 over the above-traced circuit in lieu of the second digit connect relay R1210. In operating, the relay R1210 closes its contacts 1213 to complete the prepared operating circuit for the digit marking relay R1040, this circuit extending from the grounded conductor 666 by way of the contacts 1426 and 1213, the strap connecting the terminal 8 of terminal row 4 with the terminal 3 of terminal row 1, the 3D lead, the contacts 1041, and the winding of R1040 to battery. In operating, the relay R1040 locks to the grounded release conductor 665 through its preliminary make contacts 1045. At its contacts 1043, the relay R1040 disconnects the marking lead 1073 from ground to indicate to the digit counting switch 1100 that three digits are to be received. At its contacts 1041, the relay R1040 opens its own operating circuit. At its contacts 1042 and 1045, the relay R1040 completes a path for impressing ground potential upon the marking lead 963, thereby to indicate to the outgoing digit counting switch 950 that three digits are to be transmitted. At its contacts 1044, the relay R1040 completes the operating circuit for the start sending relay R840.

- 45 In operating, the relay R840 locks to ground through its contacts 849', and then closes its contacts 849 to complete obvious multiple locking circuits for itself and the second digit test relay R900. At its contacts 841, the relay R840 opens another point in the common portion of the previously traced operating circuits for the two connect relays R1220 and R1230. At its contacts 843, the relay R840 establishes a multiple connection between the out-pulsing lead OP and the positive trunk conductor 36b. At its contacts 844, the relay R840 deenergizes the operated second digit connect relay R1210, causing this relay to release. At its contacts 846, the relay R840 connects the operating magnet 957 of the switch 950 to be controlled over the MO lead by the impulse sending relays illustrated in Fig. 17 of the drawings. At its contacts 842, the relay R840 connects the release relay R1720 to be controlled over the LO lead by the operating magnet 957 of the counting switch 950.

60 It will be noted that the transmission of the received first digit "6" is started immediately this digit is stored in the No. 1 storing relay group, and that the digit may be completely transmitted before the second digit is stored in the No. 2 storing relay group. More specifically, the transmission of the first digit is started in response to the sequential operation of the two relays R800 and R610 which occurs during the inter-digit pause separating the received first and second digits. In the event the transmission

of the impulses of the first digit from the register sender is completed before all of the impulses of the second digit are received in the sender, the relays R1710, R1730 and R1740 are operated when the start sending relay R840 is energized at the end of the second digit, in the manner just explained. Accordingly, the circuit for energizing the operating magnet 957 of the counting switch 950 is completed at the contacts 846 incident to the operation of the start sending relay R840. The magnet 957, upon operating, advances the wipers 955 and 956 to engage their associated second contacts, and closes its contacts 957b to complete the operating circuit for the release relay R1720. The latter relay, upon operating, initiates the release of the impulse counting relays and the three relays R1710, R1730 and R1740, in the manner previously described. Incident to the release of the three latter relays the circuit for energizing the operating magnet 957 is opened at the contacts 1715 and 1743. The magnet 957 accordingly releases and opens its contacts 957a to deenergize the release relay R1720. From this point on the manner in which the impulses of the remaining digit are received and stored, the impulses of the second and third digit are transmitted from the register sender 19, and the sender is released at the end of the impulse transmitting operation, is exactly the same as explained above. In this regard it will be noted that the second digit test relay R900 is deenergized and restores when the hold slave relay R600 is released to disconnect the release conductor 665 from ground.

Combined revertive and direct pulsing

As indicated previously, provisions are made in the register sender 19 whereby the impulsing relay R1760 may be revertively controlled during the transmission of the first digit or the first and second digits, and the remaining digits of a given directory number designation will be directly transmitted from the register sender without revertively controlling the pulsing relay R1760 from the switch train through which the connection is extended. One case in which the two different types of pulsing are required is exemplified in the illustrated trunking arrangement in the extension of a connection from the link 15 through the revertive pulse second selector 20 and the four digit, direct pulse switch train 22' to the substation D. In this particular case the pulsing relay R1760 of the register sender must be revertively controlled by the impulsing relays of the selector portion of the link 15 during the transmission of the first digit and by the impulsing relays of the second selector 20 during the transmission of the second digit. The remaining four digits, however, are transmitted directly from the register sender without any control being exercised on the impulsing relay R1760 from the switch train 22' through which the connection is extended. In order to provide the necessary circuits for effecting the change from one type of pulsing to the other after the impulses of the second digit have been transmitted from the register sender 19, the terminal 6 in terminal row 3 of the terminal block shown in Fig. 12 of the drawings is strapped to the terminal 1 in terminal row 2; the terminal 4 in terminal row 4 is strapped to the terminal 2 in terminal row 2; and the terminal 6 in terminal row 2 is strapped to the terminal 6 in terminal row 1. The first of these straps, i. e., that connecting the terminal 6 in terminal row 3

with the terminal 1 in terminal row 2, provides a marking path over which the second digit test relay R900 is controlled to indicate that the numerical value of the second digit will determine the total number of digits to be received by the register sender during the directory number dialing operation in progress. The second strap, i. e., that connecting the terminal 4 in terminal row 4 with the terminal 2 in terminal row 2, is utilized in a circuit over which the two digit revertive relay R930 may be controlled to provide an indication to the impulse sending relays that the impulses of all digits following the second are to be directly transmitted without revertive control of the impulsing relay R1760. The third strap, i. e., that connecting the terminal 4 in terminal row 2 with the terminal 6 in terminal row 1, is utilized to provide a marking path over which the digit marking relay R1010 may be controlled to indicate to the outgoing digit counting switch 950 and the incoming digit counting switch 1100 that a total of six digits will be received and retransmitted during the directory number dialing operation in progress.

From the preceding explanation it will be recalled that in utilizing the register sender 19 to extend a connection through the second selector 20 and the switch train 22' to the substation D the first two digits dialed into the register sender 19 from the calling substation are the digits "6" and "4," respectively. It will be understood, therefore, that at the end of the first digit the relays R1300 and R1350 are operated in the No. 1 storing relay group and that at the end of the second digit the relay R1430 is operated in the No. 2 storing relay group. It will also be understood that the second digit test relay R900 is energized and operates to perform its assigned functions at the end of the first digit. When the digit relay R150 thereafter releases at the end of the second digit it closes its contacts 751 to complete the previously described circuit for energizing the second digit connect relay R1200. This relay, in operating, closes the prepared operating circuit for the two digit revertive relay R930, this circuit extending from the grounded conductor 666 by way of the contacts 1436 and 1204, the strap connecting the terminal 4 of terminal row 4 with the terminal 2 of terminal row 2, the lead 2DP, the contacts 931, and the winding of R930 to battery. In operating, the relay R930 first locks to the grounded release conductor 665 through its preliminary make contacts 936, and then opens its operating circuit at the contacts 931. At its contacts 932 and 936, the relay R930 completes an obvious path for impressing ground potential upon the marking lead 962. At its contacts 933, the relay R930 opens a point in one of the previously traced operating circuits for the release relay R850. At its contacts 934, the relay R930 prepares the operating circuit for the change pulse relay R1100. At its contacts 935, the relay R930 completes a circuit for energizing the digit marking relay R1010, this circuit extending from the grounded release conductor 665 by way of the contacts 935, the lead 2DPM, the strap connecting the terminal 4 in terminal row 2 with the terminal 6 in terminal row 1, the 6D lead, the contacts 1011, and the winding of R1010 to battery. In operating, the relay R1010 first locks to the grounded release conductor 665 through its preliminary make contacts 1015, and then interrupts

its operating circuit at the contacts 1011. At its contacts 1012 and 1015, the relay R1010 connects the marking lead 966 to the grounded release conductor 665, thereby to indicate to the outgoing digit counting switch 950 that six digits are to be transmitted from the register sender 19. At its contacts 1013, the relay R1010 disconnects the marking lead 1076 from ground, thereby to indicate to the incoming digit counting switch 1100 that six digits are to be received by the register sender 19 from the calling substation. At its contacts 1014, the relay R1010 completes the previously traced operating circuit for the start sending relay R840. The relay R840, upon operating, locks to the grounded release conductor 665 through its contacts 849' and performs the other functions described above. From this point on, the storing of the impulses of the third and succeeding digits, and the transmission of the second and succeeding digits from the register sender 19 proceeds in the exact manner previously explained. It will be understood from this explanation that after the second digit is transmitted by the register sender to the second selector 20, for example, the wipers of the counting switch 950 are operated to engage their respective associated third contacts. Incident to this operation, the previously mentioned operating circuit for the change pulse relay R1700 is completed, this circuit extending from the grounded release conductor 665 by way of the contacts 936 and 932, the marking lead 962, the wiper 955 and its associated third contacts, the contacts 934, the GP lead, and the winding of R1700 to battery.

In operating, the relay R1700 locks to the grounded conductor 666 through its contacts 1704, and at its contacts 1702 interrupts the above-traced out-pulsing circuit over which the pulsing relay R1760 is revertively controlled by the impulsive relays of the first and second selectors during the transmission of the first two digits. At its contacts 1703, the relay R1700 connects the out-pulsing lead OP to ground through the contacts 1755 to complete a circuit for directly transmitting impulses successively to the different switches of the switch train 22'. At its contacts 1705, the relay R1700 completes an obvious circuit for connecting the start lead 1706 to ground, thereby to initiate the operation of the pulse generator 33, providing this generator is not already operated. At its contacts 1701, the relay R1700 connects the pulsing relay R1760 to be controlled directly by the pulse generator 33 over the pulsing lead 1707 during those intervals when the relay R1710 is operated and the relays R1600, R1610, R1620, R1720 and R1730 are deenergized. More specifically, with the relays R1700 and R1710 operated, the two relays R1760 and R1750 are operative to repeat the ground pulses applied to the pulsing lead 1707 by the pulse generator 33 over the out-pulsing lead OP. Thus each time the lead 1707 is connected to ground in the pulse generator 33 the relay R1760 is energized in a circuit which includes the contacts 1701, 1719, 1623, 1613, 1609, 1724, 1733 and 1754. In operating, the relay R1760 locks to the grounded pulsing lead 1707 through its contacts 1762, and closes its contacts 1761 to energize the relay R1750. The latter relay, in operating, opens its contacts 1755 to disconnect the out-pulsing lead OP from ground and thus repeat the pulse to the switch which has been seized through the outlet contacts of the second selector 20, for example. In operating, the relay R1750 also causes the impulse counting relays of Fig. 16 to count the impulse in the manner

previously explained, and opens its contacts 1754 to interrupt the operating circuit for the relay R1760. When thereafter the pulse generator 33 operates to disconnect the pulsing lead 1707 from ground, the relays R1760 and R1750 are sequentially deenergized and restore. The latter relay, in releasing, closes its contacts 1755 to again connect the out-pulsing lead OP to ground and thus complete the impulse. From an inspection of the circuits over which the pulsing relay R1760 is controlled, it will be understood that after all of the impulses of a specific digit have been transmitted over the out-pulsing lead OP and counted by the impulse counting relays, the relay R1730 is operated and opens its contacts 1733 to prevent the two relays R1760 and R1750 from responding to further ground pulses transmitted over the pulsing lead 1707. It will also be understood that during the inter-digit pause separating the digits, the circuit for transmitting ground pulses to the pulsing relay R1760 is held open at the contacts 1724, 1719, 1623, 1613 or 1609. Thus the two relays R1760 and R1750 are controlled to transmit over the out-pulsing lead OP numbers of impulses which correspond precisely to the digits that are stored in the three storing relay groups and are successively transferred to the impulse counting relay shown in Fig. 16 of the drawings. The manner in which the third, fourth, fifth and sixth digits of the directory number designating the desired line 13 as received in the register sender 19 are stored and then retransmitted as direct impulses under the control of the impulse sending relays shown in Figs. 16 and 17 of the drawings will be clearly apparent from this preceding explanation. After the six digits have been received and counted by the incoming digit counting switch 1100, the control relay R820 is deenergized and releases to indicate that no further digits are to be received. After the six digits have been transmitted by the register sender 19, the wipers of the outgoing digit counting switch 950 are operated to engage their respective associated seventh contacts, wherein the prepared circuit for energizing the release relay R850 is completed. In the present case, this circuit extends from the grounded release conductor 665 by way of the contacts 1015 and 1012, the marking lead 966, the wiper 955 and its engaged seventh contacts, and the winding of R850 to battery. Upon operating, the relay R850 initiates the release of the register sender 19 and the register selector through which this sender was initially seized, in the exact manner explained above. In this regard it will be understood that the two digit revertive relay R930 and the operated digit marking relay R1010 are deenergized and restore when the hold slave relay R600 releases to disconnect the release conductor 665 from ground. In the event the trunking arrangement of the system is such that under certain circumstances, the impulsive relay R1760 of the register sender 19 is to be revertively controlled only during the transmission of the first digit and all succeeding digits are to be directly transmitted from the register sender, provisions are made in the register sender for effecting the operation of the one digit revertive relay R920 after the impulses of the second digit are received and stored therein but before they are retransmitted by the impulse sending relays to the automatic switch train through which the call is to be forwarded. To illustrate the utility of this arrangement, the link 15 is shown as having access to a four digit direct pulse connector 21 through which connections

may be extended to a number of substations including the substation C. This connector is shown as being accessible to the selector portion of the link 15 through the eighth vertical row of contacts of the selector switching mechanism and is arranged to absorb the impulses of a received first digit of nine impulses. It will be understood, therefore, that in utilizing the register sender 19 to extend a connection through the link 15 and the connector 21 to the substation C, for example, five digits including a first digit of eight impulses and a second digit of nine impulses must be dialed into the register sender. During the transmission of the first of these digits from the register sender 19 to the selector portion of the link 15, the impulsive relay R1760 is revertively controlled by the revertive pulse relay R450 of the link. The second, third, fourth and fifth digits, however, must be directly transmitted to the seized connector 21. In order to provide the necessary circuits for effecting the required change in the type of pulsing before the impulses of the second digit are transmitted from the register sender 19, the terminal 8 in terminal row 3 of the terminal block shown in Fig. 12 of the drawings is strapped to the terminal 1 in terminal row 2; the terminal 9 of terminal row 4 which corresponds to the numerical value of the second digit is strapped to the terminal 3 in terminal row 2; the terminal 5 in terminal row 2 is strapped to the terminal of terminal row 1 which corresponds to the total number of digits to be received, i. e., terminal 5.

With the wiring arrangement just described, it will be understood that after the first digit of eight impulses is dialed into the register sender 19 from a calling substation, the second digit test relay R990 is operated to prepare, at its contacts 903 and 905, two points in the common portion of the operating circuits for the two second digit connect relays R1200 and R1210. It will also be recalled that after this digit is received it is immediately transmitted to the selector portion of the link occupied with the call. The second digit "9" as transmitted to the register sender from the calling substation is stored in the No. 2 storing relay group so that at the end of the digit the relays R1430 and R1450 are operated in this group. When the digit relay R750 restores at the end of the second digit, it closes the previously traced operating circuit for the second digit connect relay R1210. In this case the relay R1210, upon operating, completes a circuit for energizing the one digit revertive relay R920, this circuit extending from the grounded conductor 666 by way of the contacts 1436 and 1214, the strap connecting the terminal 9 in terminal row 4 with the terminal 3 in terminal row 2, the 1DP lead, the contacts 921, and the winding of R920 to battery. In operating, the relay R920 locks to the grounded release conductor 665 through its preliminary make contacts 926, and then opens its contacts 921 to interrupt its operating circuit. At its contacts 922 and 926, the relay R920 connects the marking lead 961 to the grounded release conductor 665, thereby to prepare the operating circuit for the change pulse relay R1700. At its contacts 925, the relay R920 completes a circuit for energizing the digit marking relay R1020, this circuit extending from the grounded release conductor 665 by way of the contacts 925, the lead 1DPM, the strap connecting the terminal 5 in terminal row 2 with the terminal 5 in terminal row 1, the lead 5D, the contacts 1021, and the winding of R1020 to battery. At its contacts

924, the relay R920 further prepares the operating circuit for the change pulse relay R1700. At its contacts 923, the relay R920 opens a point in one of the previously traced operating circuits for the release relay R850.

The digit marking relay R1020, in operating, locks to the grounded release conductor 665, closes a marking path through its contacts 1022 and 1025 for indicating to the counting switch 950 that five digits are to be transmitted, opens the marking path through its contacts 1023 to indicate to the digit counting switch 1100 that five digits are to be received, and closes its contacts 1024 to energize the start sending relay R340. The relay R340, in operating, causes the wipers of the switch 950 to be stepped into engagement with their associated second contacts in the manner previously explained. As the wiper 955 is operated to engage its associated second contacts the relay R1700 is energized. In the present case, the operating circuit for the change pulse relay R1700 extends from the grounded marking lead 961 by way of the wiper 955 and its associated second contacts, the contacts 924, the change pulse lead GP, and the winding of R1700 to battery. Upon operating, the relay R1700 rearranges the pulsing circuits in the manner previously explained so that revertive control of the relay R1760 is not required during the transmission of the second, third, fourth and fifth digits, and the impulses of these digits are directly transmitted to the connector 21. From this point on the manner in which the impulses of the three remaining digits are stored in the register sender, the impulses of the second, third, fourth and fifth digits are transmitted from this sender, and the impulse sender is released at the end of the transmission of the fifth digit, is exactly the same as explained above.

From the above explanation it will be understood that the directory number 89XXX is used to designate the called substation and that the second digit "9" as dialed into the register sender 19 is used to indicate the number of digits which are to be received and the type of pulsing to be used. This second digit cannot be used in any other directory number wherein the second digit is to provide corresponding indications. For example, in the illustrated arrangement, it cannot be used in directory numbers having the first digit "6," since in such case it would cause the operation of one digit revertive relay R920 in addition to the two digit revertive relay R930 and thus cause a premature transfer to direct pulsing. This second digit, as transmitted to the connector 21, for example, is absorbed therein and the remaining three digits are utilized in the selection of the desired line and the desired ringing code or frequency.

60 Reverting calls

In utilizing the register sender 19 to direct the automatic switching operations required in the setting up of reverting call connections, the first 65 digit dialed into the register sender from the calling substation is utilized to inform the register sender that the call in progress is of the revertive type. This digit is prefixed to those directory numbers which designate substations connected to multiparty subscriber lines and is not utilized to direct the operation of any of the automatic switches used in performing the revertive signaling operation. With the illustrated wiring arrangement a prefix digit "9" is 70 arbitrarily selected as the digit for indicating to

the register sender that the sender is to be used in handling a reverting call. To this end the terminal 9 in terminal row 3 of the terminal block shown in Fig. 12 of the drawings, is strapped to the terminal 10 of terminal row 1.

More specifically to consider the manner in which a reverting signaling operation is performed, it may be assumed that a call intended for the substation E is originated at the substation A and that the link 15, the selector 16, the connector 17, the register selector 18, and the register sender 19 are utilized in handling the call. In this regard it will be understood that after the register sender 19 is seized and the prefix digit "9" is dialed at the calling substation A, the relays R1330 and R1350 are operated in the No. 1 storing relay group. It will also be recalled that when the digit relay R750 releases at the end of the prefix digit to energize the operating magnet 957 of the counting switch 950, the operating circuit for the first digit connect relay R1230 is completed at the contacts 957a. In operating, this relay closes the prepared operating circuit for the reverting call relay R910, this circuit extending from the grounded conductor 666 by way of the contacts 1336 and 1234, the strap connecting the terminal 9 in terminal row 3 with the terminal 10 in terminal row 1, the lead RC, the contacts 911, and the winding of R910 to battery.

In operating, the relay R910 locks to ground over a path including its preliminary make contacts 915, C661, and the contacts 625 and 605. After completing this locking circuit the relay R910 opens its operating circuit at the contacts 911. At its contacts 912 and 915, the relay R910 completes an alternative circuit for energizing the digit marking relay R1010, this circuit extending from ground by way of the contacts 605 and 625, C661, the contacts 915, 912 and 1011, and the winding of R1010 to battery. At its contacts 913, the relay R910 prepares an alternative circuit for energizing the relays R1730 and R1740. At its contacts 914, the relay R910 completes an obvious circuit for energizing the reverting call slave relay R860.

The digit marking relay R1010, upon operating, locks to the grounded release conductor 665 through its preliminary make contacts 1015, and then opens its operating circuit at the contacts 1011. At its contacts 1012 and 1015, the relay R1010 connects the marking lead 966 to the grounded release conductor 665, thereby to indicate to the counting switch 950 that six digits are to be counted by this switch during the transmission of impulses from the register sender 19. At its contacts 1013, the relay R1010 disconnects the marking lead 1076 from ground, thereby to indicate to the counting switch 1100 that six digits are to be counted by this switch during the transmission of impulses to the register sender 19 from the calling substation. At its contacts 1014, the relay R1010 completes the operating circuit for the start sending relay R840.

The reverting call slave relay R860, upon operating, closes its contacts 861 to prepare the operating circuit for the reverting call relay R640. At its contacts 862, the relay R860 opens a point in the previously traced ring-back tone signaling circuit. At its contacts 863, the relay R860 prepares a circuit for transmitting busy tone signaling current over the calling end of the connection. At its contacts 864, the relay R860 prepares a multiple locking circuit for the hold slave relay R600. At its contacts 865, the relay R860

opens a point in the previously traced operating and locking circuits for the timing relay R620. At its contacts 866, the relay R860 prepares a path for impressing ground potential directly upon the trunk conductor 36c. At its contacts 867, the relay R860 opens a point in another of the circuits for energizing the timing relay R620. At its contacts 868, the relay R860 opens a point in the path over which ground potential may be impressed upon the sixth contact of the contact set 973.

The start sending relay R840, upon operating, locks to the grounded release conductor 665; closes its contacts 847 further to prepare the busy signaling circuit referred to above; opens its contacts 844 and 845 to deenergize the operating magnet 957 of the digit counting switch 950; closes its contacts 846 to render the magnet 957 controllable by the relay R1740; closes its contacts 843 to prepare the previously traced out-pulsing circuit; opens its contacts 841 to deenergize the connect relay R1230; and closes its contacts 842 to render the release relay R1720 controllable by the operating magnet 957 of the counting switch 950.

Incident to the energization and deenergization of the magnet 957, the wipers of the counting switch 950 are stepped to engage their respective associated first contacts, whereby the previously traced circuit is prepared through the wiper 956 for energizing the connect relay R1610. This circuit is completed at the contacts 613 in response to the sequential operation of the relays R800 and R610 which occurs shortly after the wipers 955 and 956 are stepped to the first off-normal positions thereof. In operating, the connect relay R1610 performs the functions explained above. From this explanation it will be apparent that the relays R1680 and R1630 are operated in response to the operation of the relay R1610. The counting relay R1630, upon operating, closes the previously traced operating circuit for the relay R1710. The latter relay, in operating, opens its contacts 1718' to deenergize the sequence relay R610 and the operated relays R1330 and R1350 of the No. 1 storing relay group. At its contacts 1717, the relay R1710 deenergizes the connect relay R1610. At its contacts 1711, the relay R1710 completes the previously mentioned alternative circuit for energizing the two relays R1730 and R1740, this circuit extending from ground by way of the contacts 913, the wiper 955 and its engaged first contacts, the lead BS, the contacts 1711, and the parallel-connected windings of the relays R1730 and R1740 to battery. When thus energized the relay R1730 opens its contacts 1733 to interrupt the out-pulsing circuit and thus prevent this circuit from being completed in response to the release of the connect relay R1610.

The relay R1740, upon operating, locks to the grounded conductor 666 through its contacts 1741; opens another point in the operating circuit for the relay R1710 at its contacts 1742; and closes its contacts 1743 to complete the previously traced circuit for energizing the operating magnet 957 of the counting switch 950. At its contacts 1741, the relay R1740 also completes a holding circuit for the relay R1730, this circuit extending from the grounded conductor 666 by way of the contacts 1712, 1741 and 1753, and the winding of R1730 to battery. The magnet 957, in operating, steps the wipers 955 and 956 out of engagement with their associated first contacts and into engagement with their associated sec-

ond contacts. Incident to this operation the above-traced alternative circuit for energizing the two relays R1730 and R1740 is interrupted by the wiper 955. In operating, the magnet 957 also closes its contacts 957a to complete the previously traced operating circuit for the release relay R1720. This relay, upon operating, locks to the grounded conductor 666 through its contacts 1721, and opens its contacts 1722 to deenergize the relay R1710. At its contacts 1723, the relay R1720 deenergizes the two impulse counting relays R1630 and R1680. At its contacts 1724, the relay R1720 opens another point in the previously traced out-pulsing circuit. The relay R1710, upon restoring, opens its contacts 1715 to deenergize the magnet 957. At its contacts 1712, the relay R1710 deenergizes the two relays R1730 and R1740. When the magnet 957 releases it opens its contacts 957a to deenergize the release relay R1720. Following the release of this relay the impulse sending relays shown in Figs. 16 and 17 of the drawings are fully restored to normal.

From the above explanation it will be apparent that with the reverting call relay R910 operated the impulse sending relays shown in Figs. 16 and 17 of the drawings are so controlled that the prefix digit dialed into the register sender 19 is absorbed therein. In other words, this digit, while utilized to effect the operation of the reverting call relays R910 and R860 and to cause the operation of the switch 950 to count the digit, is not retransmitted from the register sender 19 as a switch control digit. From this point on the manner in which the succeeding five digits are stored in the register sender 19 and the first four thereof are then transmitted to direct the operation of the selector portion of the link 15, the second selector 16 and the connector 17, is exactly the same as explained previously. In this regard it is noted that with the relay R860 operated the previously traced path for impressing ground potential upon the sixth contact of the contact set 953 is held open at the contacts 868. Accordingly, this path cannot be completed at the contacts 812 by the third sequence relay R810 when this relay operates in response to the storing of the impulses of the sixth digit in the No. 3 storing relay group. With this path open, no circuit is provided for energizing the third connect relay R1600 to initiate the transmission of the sixth digit to the connector 21. Thus the impulse transmission from the register sender 19 is momentarily arrested after four digits have been transmitted therefrom.

After all six of the digits have been dialed into the register sender 19 from the calling substation, the control relay R820 is deenergized and restores in the manner previously explained. In releasing, this relay closes its contacts 821 to complete the prepared busy signaling circuit, this circuit extending from one terminal of the busy tone generator provided in the tone generating equipment 32 by way of the busy tone lead C971, the contacts 863, the condenser 859, the contacts 847 and 821, the condenser 747, the contacts 621, the negative trunk conductor 36a, the wiper 557, the contacts 532, the negative trunk conductor 35a, the contacts 301, 222 and 212, the negative side of the loop circuit extending to the calling substation, the receiver provided at this substation, the positive side of the loop circuit, the contacts 211 and 221, and the winding of the impedance element 335 to the opposite terminal of the busy tone generator. When this circuit is

completed the usual busy signal is reproduced by the receiver provided at the calling substation.

In releasing, the relay R820 also opens its contacts 822 further to interrupt the previously traced dial tone signaling circuit. At its contacts 823, the relay R820 prepares the operating circuit for the send alarm relay R830. At its contacts 824, the relay R820 opens the path short-circuiting the contacts of the send alarm key 705. At its contacts 825, the relay R820 opens a point in the previously traced operating circuit for the digit relay R750. At its contacts 826, the relay R820 further interrupts one of the branches of its own locking circuit. At its contacts 827, the relay R820 opens a point in the circuit for charging the condenser 748 in series with the operating windings of the storing relays. At its contacts 828, the relay R820 closes the prepared multiple circuit for energizing the hold slave relay R600, this circuit extending from ground by way of the contacts 829 and 864, and the winding of R600 to battery. At its contacts 829, the relay R820 further prepares the above-mentioned path for impressing ground potential directly upon the trunk conductor 36c.

When the busy signal is received at the calling substation the calling subscriber is informed that he must restore the receiver at this substation to its supporting hook or cradle before the call can be completed. Incident to this operation the calling loop circuit is interrupted to cause the release of the line relay R700, the sequential operation of the relays R1740 and R1730, the release of the relay R740, the release of the hold relay R710, and finally the release of the relay R730, in a manner which will be clearly apparent from the preceding explanation. It is noted that the reoperation and release of the two relays R730 and R740 is without effect. The relay R710, upon restoring, opens its contacts 712 to interrupt the operating circuit for the hold slave relay R600, and closes its contacts 713 to complete the above-mentioned path for impressing ground potential directly upon the connected trunk conductors 36c and 35c. This path extends from ground by way of the contacts 713, 866, 829, 607 and 627 to the trunk conductor 36c, and when completed serves to increase the energization of the marginal relay R230 in the link 15. As previously explained, when thus fully energized the relay R230 deenergizes the unit relay R220, locks itself operated, closes a locking circuit for the relay R320, and closes a path for impressing resistance battery potential upon the negative line 55 wiper 471.

In releasing, the relay R710 also closes its contacts 714 to complete a path for impressing ground potential upon the sixth contact of the contact set 953, thereby to energize the third connect relay R1600. More specifically, the operating circuit for this relay extends from the grounded release conductor 665 by way of the contacts 812 of the operated sequence relay R810, the contacts 714, the wiper 956 and its engaged sixth contacts, the lead OS3, the contacts 1718, and the winding of R1600 to battery. When thus energized the relay R1600 operates to initiate the transmission of the sixth digit to the connector 17, in a manner which will be clearly apparent from the preceding explanation. This digit is utilized in the connector 17 for the purpose of setting the code or frequency selecting switch of the connector to select the particular code or frequency designating the desired substation E. At the end 70 of this digit the control equipment of the con-

ector 17 is shifted to its ringing setting to project ringing current of the selected code or frequency over the line 10, thereby to signal the called substation E in an entirely conventional manner. After the sixth or code selecting digit has been transmitted from the register sender 19 to the connector 17 in the manner just explained, the impulse sending relays shown in Fig. 17 of the drawings function to transmit a current pulse to the operating magnet 957 of the counting switch 950. This magnet, in operating, advances the wipers 955 and 956 into engagement with their respective associated seventh contacts, and closes its contacts 957a to energize the release relay R1720 and thus effect the release of the impulse sending relays in the manner previously explained. Incident to the release of these relays the circuit for energizing the magnet 957 is opened at the contacts 1715 and 1743. When the magnet 957 restores it opens its contacts 957a to deenergize the release relay R1720. Incident to the operation of the wiper 955 into engagement with its associated seventh contacts the previously traced operating circuit for the release relay R850 is completed.

In operating, the relay R850 locks to ground through the contacts 854 and 957b. At its contacts 851, the relay R850 further interrupts the out-pulsing circuit. At its contacts 852, the relay R850 further prepares the operating circuit for the reverting call relay R640. At its contacts 855, the relay R850 opens the prepared operating circuit for the timing relay R630. At its contacts 856, the relay R850 prepares the operating circuit for the timing relay R650. At its contacts 858, the relay R850 opens a point in one of the previously traced locking circuits for the timing relay R620. At its contacts 857, the relay R850 prepares an alternative circuit for energizing the timing relay R620. Following the operation of the release relay R850 no further operation of the relays provided in the register sender 19 occurs until the call is answered at the called substation E.

When the call is answered at the substation E or at another of the substations served by the multiparty line 10, the control equipment of the connector 17 is automatically shifted to its call answered setting. Incident to this operation the transmission of ringing current over the line 10 is arrested and the battery reversing relay of the connector is operated to connect the positive trunk conductor 22b to the negative terminal of the exchange battery, thereby to complete the above-mentioned circuit for energizing the reverting call relay R640. More specifically, this circuit may be traced as extending from the grounded release conductor 665 by way of the winding of R640, the contacts 641, 861, 852 and 843, the positive trunk conductor 36b, the wiper 556, the contacts 531, the trunk conductor 35b, the contacts 421, the wiper 470, the trunk conductor 22b, the positive line wiper of the selector 16, the positive conductor of the trunk extending to the connector 17, and the winding of the line relay conventionally embodied in the connector 17 to battery. When thus energized the relay R640 first closes its preliminary make contacts 649 to complete an obvious locking circuit for itself. After this circuit is completed the relay R640 opens its contacts 641 to interrupt its operating circuit as traced above. At its contacts 649', the relay R640 completes an obvious path for impressing ground potential upon the reverting call tone start lead 664, thereby to initiate the opera-

tion of the reverting call tone generator in the event this generator is not already in operation. At its contacts 642, the relay R640 completes a circuit for transmitting a distinctive signal

5 through the link 15, the selector 16, and the connector 17 to the line 10 and the substation E to inform the answering party that the answered call is of the reverting type. This circuit may 10 partially be traced as extending from one terminal of the reverting call tone generator by way of C761, the condenser 703, the contacts 642, 861, 852 and 843, the trunk conductor 35b, the wiper 556, the contacts 531, the trunk conductor 35b, and the contacts 421 to the positive line wiper 470 15 of the selector switching mechanism embodied in the link 15. From this point the signaling current is transmitted through the selector 16 and the connector 17 and over the line 10 to energize the receiver provided at the answering substation E.

In considering the reason for transmitting the special tone signal over the multiparty line in response to the answering of the call, it will be understood that the ringers respectively pro-

25 vided at the calling and called substations associated with this line may possibly be arranged for energization over different sides of the line. Accordingly, the ringer provided at the calling substation is not energized during the ringing operation and the calling subscriber is not signaled as to when the call is answered. In such case the calling subscriber, after hanging up to initiate the ringing operation in the manner just explained, waits a reasonable time interval and 30 then picks up his receiver to again establish a connection with the line. If during this interval the call is answered at the called substation, the special signal transmitted to this substation serves to inform the answering party that the 35 call is of the reverting type. On the other hand, if the subscriber at the calling substation removes the receiver provided at this substation from its supporting hook or cradle before the call is answered, the current transmitted through the 40 receiver provided at this substation from the special tone generator serves to signal the calling subscriber that the call has not been answered. In such case the calling subscriber may either abandon the call or may hold the connection until the call is answered.

The reverting call relay R640, upon operating in the manner explained above, also closes its contacts 644 and 645 to render the two timing relays R620 and R630 controllable by the timing 55 equipment 31. At its contacts 646 and 648, the relay R640 opens the incomplete operating and locking circuits for the timing relay R650. At its contacts 647, the relay R640 prepares a locking circuit for the timing relay R630.

60 In considering the manner in which the two timing relays R620 and R630 are controlled, it is pointed out that the timing equipment 31 is provided with means for alternately transmitting ground pulses over the TA-1 and TA-2 leads 65 at spaced intervals. The first ground pulse transmitted over the TA-1 lead following the operation of the reverting call relay R640, serves to energize the upper winding of the timing relay R630 in a circuit which includes the contacts 644, 632 and 604. In operating, the relay R630 first closes its preliminary make contacts 631 to complete the prepared locking circuit for itself, this circuit extending from the grounded release conductor 665 by way of the contacts 647 and 631, 70 and the lower winding of R630 to battery. After

this locking circuit is completed, the relay R630 opens its contacts 632 to interrupt its operating circuit. At its contacts 634, the relay R630 further prepares the operating circuit for the timing relay R620.

Approximately two minutes following the operation of the relay R630, the timing equipment 31 functions to transmit a ground pulse over the TA-2 lead, thereby to energize the upper winding of the timing relay R620 in a circuit including the contacts 645, 634 and 623. In operating, the relay R620 first locks to ground through its preliminary make contacts 624 and the contacts 605, and then opens its contacts 623 to interrupt its operating circuit. At its contacts 622, the relay R620 opens another point in the circuit, individual to the register sender 19, over which the all-busy relay R580 is normally energized. At its contacts 626, the relay R620 completes the previously traced multiple locking circuit for itself. At its contacts 627, the relay R620 disconnects the connected trunk conductors 33c and 35c from ground in the register sender 19, thereby to initiate the release of the register selector 18 in the manner previously explained. At its contacts 628, the relay R620 completes the previously traced operating circuits for the release magnets 958 and 1108, whereby the release of the counting switches 950 and 1100 is effected in the manner previously described. At its contacts 625, the relay R620 interrupts the previously traced operating and locking circuits for the relays R800 and R910, causing both of these relays to restore. The relay R910, in releasing, opens its contacts 914 to deenergize the relay R660. The latter relay, upon restoring, opens its contacts 864 to deenergize the hold slave relay R600. When the relay R800 releases, the remaining operated relays of the register sender 19 are restored to normal in the exact manner previously explained.

In the event the reverting call is not answered, no circuit is provided for energizing the reverting call relay R640. With this relay restored the timing relay R650 is controllable by the timing equipment 31 to effect the forced release of the register sender 19. In this regard it is pointed out that in this equipment provisions are made for alternately transmitting ground pulses over the TR-1 and TR-2 leads at spaced intervals. When the first ground pulse is transmitted over the TR-1 lead by the timing equipment 31 following the operation of the release relay R850, the lower winding of the timing relay R650 is energized in a circuit which includes this lead and the contacts 859, 654 and 643. In operating, the relay R650 first locks to the grounded release conductor through its preliminary make contacts 653 and the contacts 646, and then opens its contacts 654 to interrupt its operating circuit. At its contacts 652, the relay R650 opens one of the available locking circuits for the timing relay R630. At its contacts 651, the relay R650 prepares the operating circuit for the timing relay R620.

In the event the reverting call is answered to cause the operation of the reverting call relay R640 during the interval separating the operation of the timing relay R650 from the transmission of a ground pulse over the TR-2 lead by the timing equipment 31, the timing relay R650 is released and the normal timing operation is initiated in the manner explained above. In this regard it is noted above that the reverting call relay R640, upon operating, opens its contacts 646 and

648 to interrupt the operating and locking circuits for the timing relay R650. Thus if the latter relay is operated at the time the relay R640 is energized, it releases, and the timed release of the register sender 19 is transferred to the two timing relays R620 and R630.

If, on the other hand, the call is not answered to cause the operation of the relay R640, the upper winding of the timing relay R620 is energized in a circuit including the contacts 623, 633 and 651 when the timing equipment next operates to transmit a ground pulse over the lead TR-2. In operating, the relay R620 initiates the release of the register sender 19 and the register selector 18 in the exact manner explained above.

Forced release on permanents

As previously indicated, if the register sender 19 is seized over a line characterized by a permanent calling condition, it is forcibly released under the control of the timing equipment 31. This release operation is effected by the two timing relays R630 and R620 under the control of ground pulses transmitted over the TP-1 and TP-2 leads by the timing equipment 31. In this regard it is pointed out that provisions are made in this timing equipment for transmitting ground pulses alternately over the leads TP-1 and TP-2 at spaced intervals. It is also pointed out that following the seizure of the register sender 19, the relays R700, R710, R600, R800 and R820 are operated therein. The upper winding of the timing relay R630 is energized in a circuit including the contacts 604, 632, 643 and 855 in response to the operation of the timing equipment 31 to transmit a ground pulse over the TP-1 lead following the seizure of the register sender 19. In operating, this relay first locks to ground over a path including its preliminary make contacts 631 and the contacts 652, 752, 853 and 957b. After completing this locking circuit, the relay R630 opens its operating circuit at the contacts 632, and closes its contacts 634 to prepare a circuit including the TP-2 lead for energizing the timing relay R620. When, thereafter, the timing equipment 31 operates to transmit a ground pulse over the TP-2 lead, the upper winding of the timing relay R620 is energized in a circuit including this lead and the contacts 705a, 645, 634 and 623. The relay R620, in operating, locks to ground through its contacts 624 and 626, and opens its contacts 625 to deenergize the control relay R800. At its contacts 621, the relay R620 opens the calling loop circuit, thereby to cause the sequential deenergization and release of the line relay R700 and the hold relay R710. The latter relay, in restoring, opens its contacts 712 to deenergize the hold slave relay R600. When the relay R800 restores all of the other operated relays of the register sender 19 and the register selector 18 are released in a manner which will be clearly apparent from the above explanation.

65 Forced release when the dialing operation is delayed or abandoned

As indicated in the above explanation, a circuit including the TP-1 lead is provided for energizing the upper winding of the timing relay R630 at all times during the interval separating the sequence of the register sender 19 and the operation of the release relay R850 to indicate that the impulse sending operation has been completed by the sender. It will be understood,

therefore, that the timing relay R630 may be energized and locked up one or more times while the dialing of the directory number designating the desired substation is in progress and the impulses of the dialed digits are being retransmitted from the register sender 19. Since, however, the locking circuit for this timing relay is at this time extended to include the break contacts 752 and 957b, it will be understood that this relay and the relay R620 are prevented from releasing the register sender if the dialing operation proceeds at a normal rate. Thus each time the digit relay operates to mark the beginning of a new digit incoming to the register sender 19 it opens its contacts 752 to deenergize the relay R630, if operated. Similarly, each time the magnet 957 operates after a digit has been transmitted by the impulse sending relays of the register sender, it opens its contacts 957b to deenergize the timing relay R630.

In the event the dialing operation is delayed or is abandoned at the calling substation after one or more digits have been dialed, and the connection is held from the calling substation, the timing relay R630 is permitted to remain in its operated position for an interval exceeding that separating its operation from the transmission of the next ground pulse over the TP-2 lead by the timing equipment 31. Under these circumstances the timing relay R620 is energized by the ground pulse transmitted over the TP-2 lead and operates forcibly to release the register sender 19, the register selector 18 and the link 15, in the manner explained above.

The send alarm key 705

The key 705 is provided for the purpose of enabling an exchange attendant to check the speed with which the impulse sending relays illustrated in Figs. 16 and 17 of the drawings function to clear the register sender of the digits stored therein. To this end, the key may be operated to its off-normal position wherein the contacts 705a are disengaged and the contacts 705b are engaged. With the key 705 operated, and an impulse sending operation in progress, the magnet 957 in its operation to register each transmitted digit normally prevents the timing relay R630 from remaining operated for any substantial time interval. In case there should be an excessive delay in sending the digits set up in the three groups of storing relays, however, or the impulse sending equipment should fail, the timing relay R630 may be permitted to remain in its operated position. Thereafter and when the timing equipment 31 functions to transmit a ground pulse over the TP-2 lead, the send alarm relay R830 is energized in a circuit which extends from this lead by way of the contacts 705b, 823 and 832, the resistor 834, the upper winding of R830, the contacts 645, 634 and 623, and the upper winding of R620 to battery. It will be noted that this circuit is held open at the contacts 823, and a circuit for directly energizing the upper winding of the timing relay R620 is prepared at the contacts 824, until the control relay R820 is deenergized to indicate that all of the digits of the directory number designating the desired substation have been dialed into the register sender. Thus the send alarm relay is prevented from operating to produce an alarm signal in the manner explained below, in case the operation of the timing relay R630 is caused by a delay in the dialing operation.

Due to the relatively high resistance of the above-traced circuit for energizing the respective upper windings of the two relays R620 and R830 in series, the relay R620 is insufficiently energized to operate when this circuit is completed. The relay R830, however, operates and closes its preliminary make contacts 833 to complete a locking circuit for itself, this locking circuit extending from the grounded release conductor 665 by way of the contacts 957b, 853 and 833, and the lower winding of R830 to battery. After completing this locking circuit, the relay R830 opens its contacts 832 to interrupt the circuit for energizing its upper winding in series with the upper winding of the relay R620. At its contacts 831, the relay R830 completes an obvious circuit for energizing the alarm signal lamp 834, thereby to provide a visual indication that the register sender 19 is not in proper working order. It will be noted that the locking circuit for the send alarm relay R830 is also extended through the break contacts 957b of the magnet 957. Accordingly, if the transmission of the stored digits proceeds after the relay R830 is operated, this relay and the timing relay R630 are concurrently deenergized when the magnet 957 next operates. On the other hand, if the relay R830 remains in its operated position, the operated switches including the register sender 19 can only be released under the control of the calling subscriber or an attendant who restores the send alarm key 705 to its normal position. If the call is abandoned by the calling subscriber the release of the register sender and the other operated switches is effected in the manner previously described. On the other hand, if an exchange attendant observes the energized condition of the signal lamp 834 and restores the send alarm key 705 to normal, the operated switches are released under the control of the timing equipment 31. More specifically, when this key is restored to normal the contacts 705a are closed to reprepare the previously traced circuit including the TP-2 lead for directly energizing the timing relay R620. Accordingly, when the timing equipment 31 next operates to transmit a ground pulse over the TP-2 lead, the timing relay R620 is energized and operates to initiate the release of the register sender 19 and the other operated switches through which the connection extends, in the manner explained above.

While one embodiment of the invention has been disclosed, it will be understood that various modifications may be made therein which are within the true spirit and scope of the invention.

What is claimed is:

1. In combination with directly controllable automatic switches of two different types which require different types of directive control in extending connections therethrough; a register sender including means for directly controlling certain of said switches of said different types to extend a connection therethrough, and means for automatically controlling said last-named means to change the type of directive control exercised thereby as said connection is extended through a switch of one type to a switch of the other type.
2. In combination with directly controllable automatic switches of two different types which require different types of directive control in extending connections therethrough; a register sender including means for directly controlling certain of said switches which may be of the same or different types to extend a connection

therethrough, and means for automatically controlling said last-named means to change the type of directive control exercised thereby each time said connection is extended through a switch of one type to a switch of the other type.

3. In combination with directly controllable automatic switches of two different types which require different types of directive control in extending connections therethrough; a register sender including means for directly controlling certain of said switches to set up a switch train wherein a switch or switches of one type are followed at a predetermined switching stage by a switch or switches of the other type, and means for automatically controlling said last-named means to change the type of control exercised thereby as the connection is extended beyond said predetermined switching stage.

4. In combination with directly controllable automatic switches of different types which require different types of directive control in the setting up of connections between the lines of a telephone system; a register sender including means for directly controlling certain of said switches of said different types to extend a connection from a calling line to a called line, and means controlled over said calling line for automatically controlling said last-named means to change the type of directive control exercised thereby as said connection is extended through a switch of one type to a switch of the other type.

5. In combination with directly controllable automatic switches of different types which require different types of directive control in the setting up of connections between the lines of a telephone system; a register sender including means for directly controlling certain of said switches which may be of the same or different types to extend a connection from a calling line to a called line, and means controlled over said calling line for automatically controlling said last-named means to change the type of directive control exercised thereby each time said connection is extended through a switch of one type to a switch of the other type.

6. In combination with directly controllable automatic switches of different types which require different types of directive control in the setting up of connections between the lines of a telephone system; a register sender including means directly controlled over a calling line for directly controlling certain of said switches to set up a switch train wherein a switch or switches of one type are followed at a predetermined switching stage by a switch or switches of the other type, and means also controlled over said calling line for automatically controlling said last-named means to change the type of directive control exercised thereby as the connection is extended beyond said predetermined switching stage.

7. In combination with directly controllable automatic switches of different types which require different types of directive control in extending connections therethrough; a register sender including means controlled in accordance with the digits of a received plural digit directory number for directly controlling certain of said switches of said different types to extend a connection therethrough, and means controlled in accordance with the numerical value of at least one of said received digits for automatically controlling said last-named means to change the type of directive control exercised thereby as

said connection is extended through a switch of one type to a switch of the other type.

8. In combination with directly controllable automatic switches of different types which require different types of directive control in extending connections therethrough; a register sender including means controlled in accordance with the digits of a received plural digit directory number for directly controlling certain of said switches which may be of the same or different types to extend a connection therethrough, and means controlled in accordance with the numerical value of at least one of said received digits for automatically controlling said last-named means to change the type of directive control exercised thereby each time said connection is extended through a switch of one type to a switch of the other type.

9. In combination with directly controllable automatic switches of different types which require different types of directive control in extending connections therethrough; a register sender including means controlled in accordance with the digits of a received plural digit directory number for directly controlling certain of said switches of said different types to extend a connection therethrough, and means at least partially controlled in accordance with the numerical value of the first of said received digits for automatically controlling said last-named means to change the type of directive control exercised thereby as said connection is extended through a switch of the one type to a switch of the other type.

10. In combination with directly controllable automatic switches of different types which require different types of directive control in extending connections therethrough; a register sender including means controlled in accordance with the digits of a received plural digit directory number for directly controlling certain of said switches which may be of the same or different types to extend a connection therethrough, and means at least partially controlled in accordance with the numerical value of the first of said received digits for automatically controlling said last-named means to change the type of directive control exercised thereby each time said connection is extended through a switch of one type to a switch of the other type.

11. In combination with directly controllable automatic switches of different types which require different types of directive control in extending connections therethrough; a register sender including means controlled in accordance with the digits of a received plural digit directory number for directly controlling certain of said switches to extend a connection therethrough, means controlled in accordance with the numerical value of one of said received digits for automatically controlling said last-named means to make the type of directive control exercised thereby conform to the requirements of the switches through which the connection is extended, and means controlled in accordance with the numerical value of a received digit preceding said one digit for controlling said last-named means.

12. In combination with directly controllable automatic switches of different types which require different types of directive control in extending connections therethrough; a register sender including means controlled in accordance with the digits of a received plural digit directory number for directly controlling certain

of said switches of said different types to extend a connection therethrough, means controlled in accordance with the numerical value of one of said received digits for automatically controlling said last-named means to change the type of directive control exercised thereby as said connection is extended through a switch of one type to a switch of the other type, and means controlled in accordance with the numerical value of a received digit preceding said one digit for controlling said last-named means.

13. In combination with directly controllable automatic switches of different types which require different types of directive control in extending connections therethrough; a register sender including means controlled in accordance with the digits of a received plural digit directory number for directly controlling certain of said switches which may be of the same or different types to extend a connection therethrough, means controlled in accordance with the numerical value of one of said received digits for automatically controlling said last-named means to change the type of directive control exercised thereby each time said connection is extended through a switch of one type to a switch of the other type, and means controlled in accordance with the numerical value of a digit preceding said one digit for controlling said last-named means.

14. In combination with pulse controlled automatic switches of different types which require different types of pulse control in extending connections therethrough; a register sender including directly controllable means for transmitting pulses in digit form to certain of said switches to extend a connection therethrough, means for counting the digits transmitted to said switches from said sender, and means controlled by said last-named means for automatically controlling said pulse transmitting means to make the type of pulse control exercised thereby conform to the requirements of the switches through which said connection is extended.

15. In combination with pulse controlled automatic switches of different types which require different types of pulse control in extending connections therethrough; a register sender including a plurality of groups of impulse storing relays, means controlled in accordance with the settings of said relays for transmitting pulses in digit form to certain of said switches in order to extend a connection therethrough, means for counting the digits transmitted from said sender, and means jointly controlled by said last-named means and at least one of said groups of storing relays for controlling said pulse transmitting means to make the type of pulse control exercised thereby conform to the requirements of the switches through which said connection is extended.

16. A register sender including directly controllable means for exercising either of two different types of directive control over the switches of an associated switch train, and directly controllable means for controlling said last-named means to exercise first one and the other type of directive control over the switches of said train.

17. A register sender including a plurality of 70 digit registers, means controlled in accordance with the settings of said registers for directly controlling the switches of an automatic switch train, and means controlled by at least one of said registers for causing said last-named means 75

to exercise one type of directive control over certain of the switches of said train and a different type of directive control over the remaining switches of said train.

5 18. A register sender including directly controllable means for exercising either of two different types of directive control over the switches of an associated switch train, and means for controlling said last-named means to automatically 10 shift from one type of directive control to the other after a predetermined number of said switches have been included in said train.

19. A register sender including directly controllable means for exercising either of two different types of directive control over the switches of an associated switch train, means for controlling said last-named means to automatically shift from one type of directive control to the other after a predetermined number of said switches have been included in said train, and directly controlled means for selectively controlling said last-named means to direct the shift from one type of directive control to the other after different numbers of switches have been controlled by said first-named means.

20. In combination with directly controllable automatic switching apparatus for forwarding a call from one point of a telephone system over different routes which require a change in the type of directive control exercised over said switching apparatus at different predetermined switching stages of said different routes; a register sender including means for directly controlling said apparatus, and means controlled in accordance with the indicated route of a given call for automatically controlling said last-named means to shift from one type of directive control to the other after the call has been forwarded to any one of said predetermined switching stages.

21. In combination with pulse controlled automatic switching apparatus for forwarding a call from one point of a telephone system over different routes which require a change in the type of pulsing utilized in controlling said apparatus at different predetermined switching stages of said different routes; a register sender including means for transmitting pulses in digit form to said automatic switching apparatus, and means for selectively controlling said last-named means to effect a shift from one type of pulsing after a variable number of digits have been transmitted to said apparatus.

22. In combination with pulse controlled automatic switching apparatus for forwarding a call from any calling lines of a telephone system over different routes which require a change in the type of pulsing utilized in controlling said apparatus at different predetermined switching stages of said different routes; a register sender including means directly controllable over a calling line to transmit pulses in digit form to said apparatus, and means directly controllable over said calling line for effecting a shift from one type of pulsing to the other after a variable number of digits have been transmitted to said apparatus.

23. In combination with automatic switching apparatus; a register sender including means for exercising either of two types of directive control over said apparatus, means directly controlled in accordance with the digits of a received plural digit directory number for controlling said first-named means, means for controlling said first-named means to change from one type of direc-

tive control to the other, and means operative in the event said received directory number includes one predetermined digit for operating said last-named means after the control directed by the digit or digits preceding said one digit have been exercised on said apparatus by said first-named means.

24. In combination with automatic switching apparatus; a register sender including means for exercising either of two types of directive control over said apparatus, means directly controlled in accordance with the digits of a received plural digit directory number for controlling said first-named means, means for controlling said first-named means to change from one type of directive control to the other, and means selectively controlled in accordance with the numerical values of the first and second digits for selectively controlling said last-named means to effect the operation thereof only after the control directed by one or both of the first and second digits have been exercised on said apparatus by said first-named means.

25. In combination with automatic switching apparatus; a register sender including means for exercising either of two types of directive control over said apparatus, means directly controlled in accordance with the digits of a received plural digit directory number for controlling said first-named means, means for controlling said first-named means to change from one type of directive control to the other, means for operating said last-named means in the event said received directory number includes one predetermined digit, and means for preventing said first-named means from exercising the control directed by said one digit until said last-named means completes its operation.

26. In combination with automatic switching apparatus; a register sender including means for exercising either of two types of directive control over said apparatus, means directly controlled in accordance with the digits of a received plural digit directory number for controlling said first-named means, means for controlling said first-named means to change from one type of directive control to the other, means for operating said last-named means in the event the second digit of said directory number is of a predetermined numerical value, and means for preventing said first-named means from exercising the control directed by said second digit until said last-named means completes its operation.

27. In combination with automatic switching apparatus; a register sender including means for exercising either of two types of directive control over said switches, means directly controlled in accordance with the digits of a received plural digit directory number for controlling said first-named means, means for controlling said first-named means to change from one type of directive control to the other, means selectively controlled in accordance with the numerical values of the first and second digits of a received directory number for selectively controlling said last-named means to effect the operation thereof after the control directed by one or both of said first and second digits have been exercised on said apparatus by said first-named means, and means for preventing said first-named means from exercising the control directed by said second digit until said last-named means completes its operation.

28. In combination with directly control-

lable automatic switching apparatus for setting up connections between the lines of a telephone system; a register sender controllable over a calling line and including means for directing the operation of said apparatus to extend a connection from the calling line to a called line, means for releasing said sender after the operation thereof to control said apparatus is completed, and means controlled over said calling line for controlling said release means.

29. In combination with directly controllable automatic switching apparatus for setting up connections between the lines of a telephone system; a register sender including means directly controlled by the digits of a plural digit directory number transmitted thereto over a calling line for directing the operation of said apparatus to extend a connection from the calling line to a called line, means for releasing said sender after the operation thereof to direct said apparatus is completed, and means controlled in accordance with the numerical value of one of said digits for controlling said release means.

30. In combination with a plurality of directly controllable automatic switches for setting up connections between the lines of a telephone system; a register sender including means directly controlled by the digits of a plural digit directory number transmitted thereto over a calling line for directing the operation of said automatic switches to extend a connection from the calling line to a called line, means selectively controlled in accordance with the numerical value of one of said digits for indicating the number of switch directing operations that are to be performed by said first-named means, and means controlled by said last-named means for automatically releasing said register sender.

31. In combination with a plurality of directly controllable automatic switches for setting up connections between the lines of a telephone system; a register sender including means directly controlled by the digits of a plural digit directory number transmitted thereto over a calling line for directing the operation of said automatic switches to extend a connection from the calling line to a called line, means selectively controlled in accordance with the numerical value of one of said digits for indicating the number of switch directing operations that are to be performed by said first-named means, means for counting said switch directing operations as they are performed by said first-named means, and means jointly controlled by said two last-named means for automatically releasing said register sender after the indicated number of switch directing operations have been performed by said first-named means.

32. In combination with directly controllable automatic switching apparatus for setting up connections between the lines of a telephone system; a register sender including means directly controlled by the digits of a plural digit directory number transmitted thereto over a calling line for repeating said digits to said apparatus, thereby to direct said apparatus in the setting up of a connection between two of said lines, a group of digit marking relays selectively controlled in accordance with the numerical value of one of the digits to indicate the number of digits that are to be transmitted by said first-named means to said apparatus, a digit counting device controlled by said first-named means to count the digits transmitted thereby to said apparatus, and means jointly controlled by said

counting device and said relays for automatically releasing said register sender after the indicated number of digits have been transmitted to said apparatus.

33. In combination with directively controlled automatic switching apparatus for setting up connections between the lines of a telephone system; a register sender including a plurality of registers, means controlled by the impulses of a plural digit directory number transmitted to said sender over a calling line for registering the digits of said number in said registers, means controlled by said registers for directively controlling said apparatus to extend a connection from the calling line to a called line, means for rendering said first-named means inoperative to control said registers, and means controlled in accordance with the numerical value of one of said digits for operating said last-named means after the digits of said directory number have been registered in said registers.

34. In combination with directively controlled automatic switching apparatus for setting up connections between the lines of a telephone system; a register sender including a plurality of registers, means controlled by the impulses of a plural digit directory number transmitted to said sender over a calling line for registering the digits of said number in said registers, means controlled by said registers for directively controlling said apparatus to extend a connection from the calling line to a called line, means selectively controlled in accordance with the numerical value of one of said digits for indicating the number of digits in said directory number, and means controlled by said last-named means for rendering said first-named means inoperative to control said registers after the digits of said directory number have been registered in said registers.

35. In combination with directively controlled automatic switching apparatus for setting up connections between the lines of a telephone system; a register sender including a plurality of registers, means controlled by the impulses of a plural digit directory number transmitted to said sender over a calling line for registering the digits of said number in said registers, means controlled by said registers for directively controlling said apparatus to extend a connection from the calling line to a called line, means selectively controlled in accordance with the numerical value of one of said digits for indicating the number of digits in said directory number, means for counting said digits as they are registered by said registers, and means jointly controlled by said two last-named means for rendering said first-named means inoperative to control said registers after the digits of said directory number have been registered in said registers.

36. In combination with directively controlled automatic switching apparatus for setting up connections between the lines of a telephone system; a register sender including a plurality of registers, means controlled by the received impulses of a plural digit directory number for registering the digits of said number in said registers, means controlled by said registers for directively controlling said registers to set up a connection between two of said lines, a group of digit marking relays selectively controlled in accordance with the numerical value of one of said digits to indicate the number of digits in said directory number, a digit counting device

controlled by said first-named means to count said digits, and means jointly controlled by said counting device and said relays for rendering said first-named means inoperative to control said registers after the indicated number of digits have been registered by said registers.

37. In combination with directively controlled automatic switching apparatus for setting up connections between the lines of a telephone system; a register sender including a plurality of registers, means controlled by the received impulses of a plural digit directory number for registering the digits of said directory number in said registers, means controlled by said registers for repeating said digits to said automatic switching apparatus, thereby to direct said apparatus in the setting up of a connection between two of said lines, a group of digit marking relays selectively controlled in accordance with the numerical value of one of the received digits to indicate the number of digits that are to be received and transmitted, means controlled by said relays for rendering said first-named means inoperative to control said registers after the indicated number of digits have been received, and means controlled by said relays for automatically releasing said register sender after the indicated number of digits have been transmitted to said automatic switching apparatus.

38. In combination with directively controlled automatic switching apparatus for setting up connections between the lines of a telephone system; a register sender including a plurality of registers, means controlled by the received impulses of a plural digit directory number for registering the digits of said directory number in said registers, means controlled by said registers for repeating said digits to said automatic switching apparatus, thereby to direct said apparatus in the setting up of a connection between two of said lines, a group of digit marking relays selectively controlled in accordance with the numerical value of one of the received digits to indicate the number of digits that are to be received and transmitted, a first counting device operative to count the digits registered in said registers, a second counting device operative to count the digits transmitted to said automatic switching apparatus, means jointly controlled by said relays and said first counting device for rendering said first-named means inoperative to control said registers after the indicated number of digits have been received, and means jointly controlled by said relays and said second counting device for automatically releasing said register sender after the indicated number of digits have been transmitted to said automatic switching apparatus.

39. In a register sender, an impulse sender, a group of counting relays adapted to have registered therein the number of impulses to be transmitted by said impulse sender during a given digit, to count the impulses as they are transmitted and to arrest the operation of said impulse sender when the number of impulses transmitted by said impulse sender corresponds to the number registered therein, a plurality of digit registers, means for counting the digits transmitted by said impulse sender, and means controlled by said last-named means for successively transferring the registrations of said digit registers to said group of counting relays.

40. In a register sender, an impulse sender, a group of counting relays adapted to have registered therein the number of impulses to be

transmitted by said impulse sender during a given digit, to count the impulses as they are transmitted and to arrest the operation of said impulse sender when the number of impulses transmitted by said impulse sender corresponds to the number registered therein, a plurality of digit registers, a device for counting the digits transmitted by said impulse sender, means controlled by said counting relays for operating said device each time a digit is transmitted by said impulse sender, and means controlled by said device for successively transferring the registrations of said digit registers to said group of counting relays.

41. In a register sender, an impulse sender, a group of counting relays adapted to have registered therein the number of impulses to be transmitted by said impulse sender during a given digit, to count the impulses as they are transmitted and to arrest the operation of said impulse sender when the number of impulses transmitted by said impulse sender corresponds to the number registered therein, a plurality of digit registers, a device for counting the digits transmitted by said impulse sender, means controlled by said counting relays for operating said device each time a digit is transmitted by said impulse sender, means controlled by said device for successively transferring the registrations of said digit registers to said group of counting relays, and means controlled by said device for automatically releasing said register sender.

42. In a telephone system which includes a multiparty subscriber line and directly controlled automatic switching apparatus for selectively signaling the substations served by said line in setting up reverting call connections between said substations; a register sender including means for directly controlling said apparatus in its operation to signal one of said substations, and means for transmitting a distinctive signal over said line to the party answering a reverting call, whereby the answering party is informed that the answered call is a reverting call if the call is answered at the called substation and is informed that the call has not been answered if the call answering operation is performed at the calling substation.

43. In a telephone system which includes a multiparty subscriber line and directly controlled automatic switching apparatus for selectively signaling the substations served by said line in setting up reverting call connections between said substations; a register sender including means controllable over said line for directly controlling said apparatus in its operation to signal one of said substations, and means for transmitting a distinctive signal over said line to the party answering a reverting call, whereby the answering party is informed that the answered call is a reverting call if the call is answered at the called substation and is informed that the call has not been answered if the call answering operation is performed at the calling substation.

44. In a telephone system which includes a multiparty subscriber line and directly controlled automatic switching apparatus for selectively signaling the substations served by said line in setting up reverting call connections between said substations; a register sender including means for directly controlling said apparatus in its operation to signal one of said substations, and means controlled over said line by the party answering a reverting call for trans-

mitting a distinctive signal to the answering party, whereby the answering party is informed that the answered call is a reverting call if the call is answered at the called substation and is informed that the call has not been answered if the call answering operation is performed at the calling substation.

45. In a telephone system which includes a multiparty subscriber line and directly controlled automatic switching apparatus for selectively signaling the substations served by said line in setting up reverting call connections between said substations; a register sender including means controllable over said line for directly controlling said apparatus in its operation selectively to signal one of said substations, and means controlled over said line by the party answering a reverting call for transmitting a distinctive signal to the answering party, whereby the answering party is informed that the answered call is a reverting call if the call is answered at the called substation and is informed that the call has not been answered if the call answering operation is performed at the calling substation.

46. In a telephone system which includes a multiparty subscriber line and directly controlled automatic switching apparatus for selectively signaling the substations associated with said line in setting up reverting call connections between said substations; a register sender including means for directly controlling said apparatus in its operation to signal said substations, and means operative in response to the answering of a reverting call at one of said substations for transmitting a signal of limited duration to the answering substation and for then automatically releasing said register sender.

47. In a telephone system which includes a multiparty subscriber line and directly controlled automatic switching apparatus for selectively signaling the substations associated with said line in setting up reverting call connections between said substations; a register sender including means controllable over said line for directly controlling said apparatus in its operation selectively to signal said substations, and means operative in response to the answering of a reverting call at one of said substations for transmitting a signal of limited duration to the answering substation and for then automatically releasing said register sender.

48. In a telephone system which includes a multiparty subscriber line and directly controlled automatic switching apparatus for selectively signaling the substations associated with said line in setting up reverting call connections between said substations; a register sender including means for directly controlling said apparatus in its operation selectively to signal said substations, and means controllable over said line and operative in response to the answering of a reverting call at one of said substations for transmitting a signal of limited duration to the answering substation and for then automatically releasing said register sender.

49. In a telephone system which includes a multiparty subscriber line and directly controlled automatic switching apparatus for selectively signaling the substations associated with said line in setting up reverting call connections between said substations; a register sender including means controllable over said line for directly controlling said apparatus in its operation selectively to signal said substations, and

means controllable over said line and operative in response to the answering of a reverting call at one of said substations for transmitting a signal of limited duration to the answering substation and for then automatically releasing said register sender.

50. In a telephone system which comprises a plurality of lines including a multiparty subscriber line having a plurality of substations associated therewith and automatic switching apparatus operative to select said multiparty line in response to the line selecting digits of a plural digit directory number and including means controlled by the signal selecting digit or digits of said directory number for signaling one of said substations; a register sender including means controllable over said line from another of said substations for transmitting only said line selecting digits to said automatic switching apparatus, and means responsive to a switch release operation performed at said other substation for transmitting the signal selecting digit or digits to said automatic switching apparatus.

51. In a telephone system which comprises a plurality of lines including a multiparty line having a plurality of substations associated therewith and automatic switching apparatus operative to select said multiparty line in response to the line selecting digits of a plural digit directory number and including means controlled by the last digit of said directory number for signaling one of said substations; a register sender controllable over said line from another of said substations to transmit all but the last digit of said directory number to said automatic switching apparatus, and means responsive to a switch release operation performed at said other substation for transmitting the last digit of said directory number to said automatic switching apparatus.

52. In a telephone system which comprises a plurality of lines including a multiparty line having a plurality of substations associated therewith and directly controllable automatic switching apparatus operative to select said line and including means responsive to a predetermined digit to signal one of said substations; a register sender including means directly controllable over said line from another of said substations to direct said automatic switching apparatus in its operation to select said one line, and means operative in response to a switch release operation performed at said other substation for transmitting said predetermined digit to said automatic switching apparatus.

53. In a telephone system which comprises a plurality of lines including a multiparty subscriber line having a plurality of substations associated therewith and automatic switching apparatus operative to select said multiparty line in response to the line selecting digits of a plural digit directory number and including means controlled by the signal selecting digit or digits of said directory number for signaling one of said substations; a register sender including means controllable over said line from another of said substations for transmitting only said line selecting digits to said automatic switching apparatus, means responsive to a switch release operation performed at said other substation for transmitting the signal selecting digit or digits to said automatic switching apparatus, and means operative in response to the answering of the call at said one substation for transmitting a signal over

said line which indicates that the answered call is a reverting call.

54. In a telephone system which comprises a plurality of lines including a multiparty line having a plurality of substations associated therewith and automatic switching apparatus operative to select said multiparty line in response to the line selecting digits of a plural digit directory number and including means controlled by the last digit of said directory number for signaling one of said substations; a register sender controllable over said line from another of said substations to transmit all but the last digit of said directory number to said automatic switching apparatus, means responsive to a switch release operation performed at said other substation for transmitting the last digit of said directory number to said automatic switching apparatus, and means operative in response to the answering of the call at said one substation for transmitting a signal over said line which indicates that the answered call is a reverting call.

55. In a telephone system which comprises a plurality of lines including a multiparty line having a plurality of substations associated therewith and directly controllable automatic switching apparatus operative to select said line and including means controlled by a predetermined digit for signaling one of said substations; a register sender including means directly controllable over said line from another of said substations to direct said automatic switching apparatus in its operation to select said one line, means operative in response to a switch release operation performed at said other substation for transmitting said predetermined digit to said automatic switching apparatus, and means operative in response to the answering of the call at said one substation for transmitting a signal over said line which indicates that the answered call is a reverting call.

56. In a telephone system which comprises a plurality of lines including a multiparty line having a plurality of substations associated therewith and automatic switching apparatus operative to select said multiparty line and to signal one of said substations in response to the digits of a predetermined plural digit directory number designating said one substation; a register sender including means responsive to the transmission of the digits of a different directory number to said sender from another of said substations for transmitting a portion of the digits of said predetermined directory number to said automatic switching apparatus, and means controllable over said line from said other substation for causing the remaining digits of said predetermined directory number to be transmitted to said automatic switching apparatus.

60. 57. In a telephone system which comprises a plurality of lines including a multiparty line having a plurality of substations associated therewith and automatic switching apparatus operative to select said multiparty line and to signal one of said substations in response to the digits of a predetermined plural digit directory number designating said one substation; a register sender including means responsive to the transmission of a predetermined prefix digit followed by the digits of said directory number to said sender from another of said substations for transmitting a portion of the digits of said directory number to said automatic switching apparatus and for storing at least one of the digits of said directory number, and means responsive to a

switch release operation performed at said other substation for transmitting the stored digit or digits to said automatic switching apparatus.

58. In a telephone system which comprises a plurality of lines including a multiparty line having a plurality of substations associated therewith and automatic switching apparatus operative to select said multiparty line and to signal one of said substations in response to the digits of a predetermined plural digit directory number designating said one substation; a register sender including means responsive to the transmission of a predetermined prefix digit followed by the digits of said directory number to said sender from another of said substations for absorbing said prefix digit and for transmitting a portion of the digits of said directory number to said automatic switching apparatus, means responsive to the transmission of said prefix digit to said sender for causing the other digit or digits of said directory number to be stored in said register sender, and means responsive to a switch release operation performed at said other substation for transmitting the stored digit or digits to said automatic switching apparatus.

59. In a telephone system which comprises a plurality of lines including a multiparty line having a plurality of substations associated therewith and automatic switching apparatus operative to select said multiparty line and to signal one of said substations in response to the digits of a predetermined plural digit directory number designating said one substation; a register sender including means responsive to the transmission of a predetermined prefix digit followed by the digits of said directory number to said sender from another of said substations for absorbing said prefix digit and for transmitting all but the last digit of said directory number to said automatic switching apparatus, means responsive to the transmission of said prefix digit to said sender for causing the last digit of said directory number to be stored in said register sender, and means responsive to a switch release operation performed at said other substation for transmitting the last digit of said directory number to said automatic switching apparatus.

60. In a telephone system which comprises a plurality of lines including a multiparty line having a plurality of substations associated therewith and automatic switching apparatus operative to select said multiparty line and to signal one of said substations in response to the digits of a predetermined plural digit directory number designating said one substation; a register sender including means responsive to the transmission of the digits of a different directory number to said sender from another of said substations for transmitting a portion of the digits of said predetermined directory number to said automatic switching apparatus, means controllable over said line from said other substation for causing the remaining digits of said predetermined directory number to be transmitted to said automatic switching apparatus, and means operative in response to the answering of the call at said one substation for transmitting a signal over said line which indicates that the answered call is a reverting call.

61. In a telephone system which comprises a plurality of lines including a multiparty line having a plurality of substations associated therewith and automatic switching apparatus operative to select said multiparty line and to signal one of said substations in response to the digits

75 of a predetermined plural digit directory number designating said one substation; a register sender including means responsive to the transmission of a predetermined prefix digit followed by the digits of said directory number to said sender from another of said substations for transmitting a portion of the digits of said directory number to said automatic switching apparatus and for storing at least one of the digits of said directory number, means responsive to a switch release operation performed at said other substation for transmitting the stored digit or digits to said automatic switching apparatus, and means operative in response to the answering of the call at said one substation for transmitting a signal over said line which indicates that the answered call is a reverting call.

62. In a telephone system which comprises a plurality of lines including a multiparty line having a plurality of substations associated therewith and automatic switching apparatus operative to select said multiparty line and to signal one of said substations in response to the digits of a predetermined plural digit directory number designating said one substation; a register sender including means responsive to the transmission of a predetermined prefix digit followed by the digits of said directory number to said sender from another of said substations for absorbing said prefix digit and for transmitting a portion of the digits of said directory number to said automatic switching apparatus, means responsive to the transmission of said prefix digit to said sender for causing the other digit or digits of said directory number to be stored in said register sender, means responsive to a switch release operation performed at said other substation for transmitting the stored digit or digits to said automatic switching apparatus, and means operative in response to the answering of the call at said one substation for transmitting a signal over said line which indicates that the answered call is a reverting call.

63. In a telephone system which comprises a plurality of lines including a multiparty line having a plurality of substations associated therewith and automatic switching apparatus operative to select said multiparty line and to signal one of said substations in response to the digits of a predetermined plural digit directory number designating said one substation; a register sender including means responsive to the transmission of a predetermined prefix digit followed by the digits of said directory number to said sender from another of said substations for absorbing said prefix digit and for transmitting all but the last digit of said directory number to said automatic switching apparatus, means responsive to the transmission of said prefix digit to said sender for causing the last digit of said directory number to be stored in said register sender, means responsive to a switch release operation performed at said other substation for transmitting the last digit of said directory number to said automatic switching apparatus, and means operative in response to the answering of the call at said one substation for transmitting a signal over said line which indicates that the answered call is a reverting call.

64. In a register sender, a plurality of digit registers, a line relay operative in response to seizure of said sender, means controlled by said relay in its response to the impulses of the digits of a received directory number for successively operating said registers to register the numerical

values of said digits, means controlled in accordance with the settings of said registers for repeating the registered digits to associated automatic switching apparatus, means controlled by one of said registers in its response to one of the digits of a predetermined directory number for absorbing said one digit and for preventing the digit stored in the last operated register from being transmitted to said automatic switching apparatus, and means responsive to the subsequent release of said line relay for transmitting the digit stored in said last operated register to said automatic switching apparatus.

65. In a register sender, a plurality of digit registers, a line relay operative in response to seizure of said sender, means controlled by said relay in its response to the impulses of the digits of a received directory number for successively operating said registers to register the numerical values of said digits, means controlled in accordance with the settings of said registers for repeating the registered digits to associated automatic switching apparatus, means controlled by one of said registers in its response to a predetermined prefix digit for preventing the last digit of a subsequently registered directory number from being transmitted to said automatic switching apparatus, and means responsive to the subsequent release of said line relay for transmitting the last digit of said registered directory number to said automatic switching apparatus.

66. In a register sender, a plurality of digit registers, a line relay operative in response to seizure of said sender, means controlled by said relay in its response to the impulses of the digits of a received directory number for successively operating said registers to register the numerical values of said digits, means controlled in accordance with the settings of said registers for repeating the registered digits to associated automatic switching apparatus, indicating means controlled by one of said registers in its response to the first digit of a received directory number for indicating the number of digits of the directory number, release means normally operative automatically to release said register sender after the number of digits indicated by said last-named means have been transmitted to said automatic switching apparatus, means controlled by said one register in its response to a different first digit of a different directory number for conditioning said indicating means to be controlled by the next operated register, for preventing the subsequent operation of said release means and for preventing the subsequently received last digit of said different directory number from being transmitted to said automatic switching apparatus, and means responsive to the subsequent release of said line relay for transmitting the last digit of said different directory number to said automatic switching apparatus.

67. In a telephone system which comprises a plurality of lines including a multiparty line having a plurality of substations associated therewith and automatic switching apparatus operative to select said multiparty line and to signal one of the substations associated therewith in response to the digits of a predetermined plural digit directory number designating said one substation; a register sender including means directly controllable over said line from another of said substations for transmitting a por-

tion of the digits of said directory number to said automatic switching apparatus, means for transmitting a signal to said other substation after said portion of the digits of said directory number have been transmitted to said automatic switching apparatus, and means responsive to a switch release operation performed at said other substation for causing the remaining digit or digits of said directory number to be transmitted to said automatic switching apparatus.

68. In a telephone system which comprises a plurality of lines including a multiparty line having a plurality of substations associated therewith and automatic switching apparatus operative to select said multiparty line and to signal one of the substations associated therewith in response to the digits of a predetermined plural digit directory number designating said one substation; a register sender including means directly controllable over said line from another of said substations for transmitting a portion of the digits of said directory number to said automatic switching apparatus, means for transmitting a signal to said other substation after said portion of the digits of said directory number have been transmitted to said automatic switching apparatus, means responsive to a switch release operation performed at said other substation for causing the remaining digit or digits of said directory number to be transmitted to said automatic switching apparatus, and means operative in response to the answering of the call at said one substation for transmitting a different signal over said line which indicates that the answered call is a reverting call.

69. In a telephone system which comprises a plurality of lines including a multiparty line having a plurality of substations associated therewith and automatic switching apparatus operative to select said multiparty line and to signal one of the substations associated therewith in response to the digits of a predetermined plural digit directory number designating said one substation; a register sender including means directly controllable over said line from another of said substations for transmitting all but the last digit of said directory number to said automatic switching apparatus, means responsive to the transmission of the next to last digit of said directory number to said automatic switching apparatus for transmitting a signal to said other substation, and means responsive to a switch release operation performed at said other substation for causing the last digit of said directory number to be transmitted to said automatic switching apparatus.

70. In a telephone system which comprises a plurality of lines including a multiparty line having a plurality of substations associated therewith and automatic switching apparatus operative to select said multiparty line and to signal one of the substations associated therewith in response to the digits of a predetermined plural digit directory number designating said one substation; a register sender including means directly controllable over said line from another of said substations for transmitting all but the last digit of said directory number to said automatic switching apparatus, means responsive to the transmission of the next to last digit of said directory number to said automatic switching apparatus for transmitting a signal to said other substation, means responsive to a switch release operation performed at said other substation for causing the last digit of said directory number

to be transmitted to said automatic switching apparatus, and means operative in response to the answering of the call at said one substation for transmitting a different signal over said line which indicates that the answered call is a reverting call.

71. In combination with directively controllable automatic switching apparatus which is operative to extend a connection from a calling line to a called line of a telephone system; a register sender including means for registering the digits of the directory number designating said called line, means controlled in accordance with the digits registered in said last-named means for directing said switching apparatus in its operation to extend a connection to said called line, and means responsive to the registration of the last digit of said directory number for transmitting a ring-back signal over the calling line.

72. In combination with directively controllable automatic switching apparatus which is operative to extend a connection from a calling line to a called line of a telephone system; a register sender including means for registering the digits of the directory number designating said called line, means controlled in accordance with the digits registered in said last-named means for directing said switching apparatus in its operation to extend a connection to said called line, means for automatically releasing said register sender after the directive control of said automatic switching apparatus to extend the connection to the called line is completed, and means for transmitting a ring-back signal over the calling line during the interval separating the registration of the last digit of said directory number and the release of said sender.

73. In a telephone system, a calling line, a register sender, a link operative to extend a connection from said line and including a selector, means responsive to the seizure of said link over said calling line for seizing said register sender, means responsive to the seizure of said register sender for establishing a circuit through said link over which said sender may be directly controlled over said line, means responsive to the registration in said register sender of the first digit of the directory number designating the desired line for initiating the operation of said selector under the directive control of said register sender, and means in said register sender revertively controlled in accordance with the operation of said selector for arresting the operation of said selector after the selecting operation directed by said first digit is completed.

74. In a telephone system, a calling line, a register sender, a link operative to extend a connection from said line and including a selector, means responsive to the seizure of said link over said calling line for seizing said register sender, a switching relay operative in response to the seizure of said register sender to establish a control circuit through said link over which the digits of a plural digit directory number may be transmitted to said register sender from said calling line, means responsive to the registration in said register sender of the first digit of said directory number for initiating the operation of said selector, means in said register sender revertively controlled in accordance with the operation of said selector for arresting the operation of said selector after the selecting operation directed by said first digit is completed, means for establishing a control path through the outlet contacts of said selector over which the

switches following said selector may be controlled by said register sender in accordance with the other digits of said directory number, and means in said register sender for releasing said switching relay after all of the digits of said directory number have been transmitted from said register sender.

75. In a telephone system, a link for extending connections from calling lines and including a relay operative to prevent said link from being seized over a calling line, a plurality of register senders, a register selector operative to search for an idle sender and to associate a selected idle sender with said link in response to the seizure of said link over a calling line, means responsive to an all busy condition of said senders for operating said relay, and means responsive to the operation of said relay during an interval when said link is occupied with a call and said register selector is searching for an idle link for opening the connection between the calling line and the link.

76. In a telephone system, a link for extending connections from calling lines and including a relay operative to prevent said link from being seized over a calling line, a plurality of register senders, a register selector operative to search for an idle sender and to associate a selected idle sender with said link in response to the seizure of said link over a calling line, means responsive to an all busy condition of said senders for operating said relay, means in a seized one of said register senders controllable over a calling line for also operating said relay in the event the link is occupied with a reverting call, and means responsive to the operation of said relay for opening the connection between the link and the calling line over which said link is seized.

77. In a telephone system, a plurality of register senders, a link operative to extend a connection from a calling line and including a pair of relays connected to be controlled over a common control path, a register selector operative in response to seizure of said link over a calling line to search for an idle register sender, to associate a selected idle register sender with said link and to extend said control path to the selected register sender, means in the selected register sender for selectively controlling said relays over said path, means responsive to the operation of one of said relays under the control of said last-named means for opening the connection between the calling line and the link, and means responsive to the operation of the other of said relays for establishing a control path between said link and the selected register sender over which the digits of a plural digit directory number may be transmitted from the calling line to the register sender.

78. In a telephone system, a plurality of register senders, a link operative to extend a connection from a calling line and including a pair of relays connected to be controlled over a common control path, a register selector operative in response to seizure of said link over a calling line to search for an idle register sender, to associate a selected idle register sender with said link and to extend said control path to the selected register sender, means in the selected register sender for selectively controlling said relays over said path, means responsive to the operation of one of said relays under the control of said last-named means for opening the connection between the calling line and the link, means responsive to the operation of the other of said relays for establishing a control path between said link and

the selected register sender over which the digits of a plural digit directory number may be transmitted from the calling line to the register sender, means responsive to an all busy condition of said register senders for energizing said one relay over 55 said common control path, and means responsive

to the operation of said one relay during an interval when said link is not occupied with a call for preventing said link from being seized over a calling line.
